UNITED STATES PATENT OFFICE

HERBERT M. FRIENDLY, OF PORTLAND, OREGON

TELEPHONE SYSTEM

Application filed February 10, 1922. Serial No. 535,430.

The present invention has for its broad objects the grouping or combining into a comprehensive, general subscriber exchange system a plurality of subscriber groups of telephones. Each of the latter groups, comprising a plurality of telephones or substations, are located on the premises of the concerned subscriber of the respective group. The substations of the said groups are arranged to directly inter-call within the concerned group to which it belongs, in a manner generally similar to that employed in so-called private automatic exchanges, or so-called private branch automatic exchanges. The former is usually abbreviated as "P. A. X.", and the latter "P. B. A. X." The P. A. X. denotes an isolated automatic exchange on the premises of a subscriber, and the P. B. A. X. denotes a similar automatic exchange on the premises of a subscriber, but with the added facility of trunk connection with a second exchange. The latter exchange is usually a comprehensive exchange operated by a public service concern serving subscribers generally.

Heretofore, so far as I am aware, each P. A. X. or P. B. A. X. has been employed as an independent unit, usually located on the premises of the concerned subscriber. The equipment, therefore, consists of a complete complement of apparatus generally similar to that used in a comprehensive exchange. That is to say, it is a complete unit in itself. It will thus appear that considerable capital, relatively speaking, is involved in equipments comprising the installation which is common to all substations thereof, and which would ordinarily be capable of serving a much larger number of substations. Many devices are employed involving first cost and current maintenance to afford automatic supervision. Aside from this, space on the premises of the subscriber is required, and the equipment must be periodically visited for inspection, and to correct operative failures.

Again, where exchange switching equipment is installed on the premises of a subscriber it occasions the use of more or less valuable space and the annoyance of visits by the maintenance employees of the operating concern,

and perhaps affects the fire insurance rate to the subscriber.

From the viewpoint of the operating concern such equipment occasions an investment out of all proportion to what a similar capacity switching equipment involves in a comprehensive, centralized installation. Then, if the service is discontinued, or the subscriber re-arranges his premises, further expense is entailed which amounts to perhaps wiping out a portion of the sum initially expended in the installation. In anticipation of growth, private installations, as a rule, initially involve more equipment than required, in order to forestall having to displace the equipment with a larger one in the event of the subscriber expanding his service. If the subscriber discontinues the service a loss is entailed by the operating concern, because, even if the equipment may be used elsewhere, the installation labor cost has been wiped out prematurely. In any event, the costs must be borne by the operating concern, or be reflected in the rates charged.

From the foregoing, it will appear that the smaller the number of substations in a subscriber's installation the greater the cost which will be apportioned to each substation because of the equipments not directly used in linking connections. Moreover, the percentage of common linking elements, such as local connectors, will be greater per substation in inverse proportion to the number of substations, because the divergency factor with relation to the traffic originating from the respective substations will not intermesh so uniformly as where a larger number of substations are served by a unit group of local connectors. The latter is to say, that the larger the group of substations the fewer local connectors per unit number of substations will be required. The fact this relation exists is well known to engineers practicing the automatic telephone art.

One of the features of the present invention involves grouping the switching equipment for a plurality of group subscriber's into one unit, preferably (though of course, not necessarily), as a part of a comprehensive exchange system, and installed as a part

of the main office to which it is tributary. To this end a common set of local connectors will serve a plurality of subscribers where each said subscriber has a plurality of substations adapted to be inter-switched. Means is provided so the telephones comprising a subscriber's group can obtain two-way trunk connection with the main exchange to which they are tributary, and in fact the entire exchange including the telephones of other subscriber groups of substations. However, for general inter-switching, the substations of the various subscriber groups are barred against each other, notwithstanding they are possibly served by the same local connectors.

A feature of the present invention as applied to subscriber groups wherein the number of substations comprising the respective groups are relatively small, say three to ten, for example, enables the local connectors to have access to ten or more levels of bank contacts, each level of which may contain more than one group; each group corresponding to a subscriber. That is to say, a local connector may serve as many, or more, subscriber groups than it has levels of bank contacts. Further, regardless of the level in which the group terminates, the calling party can send one digit only and complete connection to the desired substation, bearing in mind that the substation called belongs to the same subscriber group as the one calling. To this end, the substations of a subscriber group are each connected to a line switch in the main exchange over a pair of conductors as are individual line subscribers. The line switches of a plurality of subscriber groups have common access to a group of local connectors. However, when a call is initiated and a line switch seizes a local connector it also adapts the local connector to seize only the lines contained in the group to which the calling line belongs. When the local connector is thus seized, it forthwith automatically functions whereby it steps its wipers vertically to the level containing the lines of the group of which the calling line is one, and if the entire level is set apart for the said group or the first bank contacts only are, it will then be in readiness to be directly operated by a single digit series sent by the calling party to complete the connection, or obtain the usual busy signal. If the group, of which the calling line is one, occupies bank contacts other than the first ones set apart as a group in the level automatically attained incidental to the initiation of the call, the local connector will, after attaining the proper level containing the group to which the calling substation belongs, forthwith automatically rotate-in to the group. In this instance it will stop on a dead position, in readiness to be directly operated by a single digit series to set the wipers on any desired position of the group

to complete the connection or obtain the usual busy signal.

Having in mind that under the last foregoing method of operation, the local connector seized by the line switch of the calling line automatically sets itself with reference to the group containing the calling line, in case it desired to trunk the connection by way of extending the call to a general subscriber, rather than to a substation within the group containing the calling line, two methods are provided. One is for the calling party to send impulses constituting the digit "0". The other is by depressing a key on the substation set to introduce a resistance in the calling line effective to a marginal relay in the local connector. Where the key is provided, the calling party may employ either method. Certain substations only would be equipped with the key, if desired. Upon sending impulses corresponding to digit "0" or by depressing the key referred to, the local connector will be caused to rotate its wipers at the level (or the position in a level), previously automatically attained in the manner referred to, whereupon a set of last rotary position cam-springs will be caused to operate. The latter function causes an auxiliary trunk conductor leading to a bank contact engaged by a wiper of the line switch of the calling line to become grounded, which, in turn, causes the line switch to unseize, releasing the local connector, whereupon the line switch will rotate until it becomes into testing engagement and hunting relation with the first set of a group of bank contacts corresponding to trunks leading to the main exchange equipment having access to general subscriber lines. The first idle set of bank contacts corresponding to a trunk will be seized, after which the call can be completed by the calling party sending the digits corresponding to the telephone number of the desired line. It will be understood, in this connection that the said general subscriber lines in this instance may include the groups of subscriber lines of the class of which the calling line is one, because, unless specifically provided for, as will appear later, such lines cannot be reached directly even where the same local connector normally has access.

In view of the fact the switching equipment used by the group subscriber in inter-switching within his group and for extending connections to subscribers of the system generally is located in the main exchange, the trunk lines serving the subscriber groups will be local to the main exchange. An economic advantage is thus effected in that repeaters designed to translate from three-wire to two-wire operation (as where the trunk extends outside), and for other reasons, is not now necessary, since the wire distances concerned in three-wire operation within the

exchange building is not great, and at least, is more simple and involves smaller cost and carrying charges than employing a repeater. The trunk and associated switching equipments being wholly within the main exchange building to which the subscriber group concerned is tributary simplifies maintenance and conduces to more prompt discernment of operative failures than where the trunks and related equipments are not wholly within the building. Aside from this, the plan promotes the differentiation of operation desirable when calls emanate from the toll switchboard of the operating concern. For example, it is desirable to automatically signal the subscriber's attendant substation (or a secondary choice station thereto), forthwith automatically when a subscriber's trunk is seized when the call emanates from a local line, but to only signal by directive operation when the call emanates from the toll switchboard. Further, it is desirable to afford the toll operator specific supervision and to augment the transmission battery supply where the connection emanates from the toll switchboard. The system contemplated herein provides these facilities.

Under the plan contemplated under the present invention, it will appear, no trunk or service lines are run to the premises of a group subscriber, other than a pair of conductors for each substation of the group. In view of the relative costs of conductors and the low depreciation, obsolescence and other charges attaching to cable conductors as compared to the corresponding factors attaching to switching equipment isolatedly installed, the first cost of an installation and the carrying charges attending, will be less where the equipment is installed centrally. Of course, the distance the subscriber's premises is from the tributary main office, as well as the number of substations in the group, will have a bearing upon this. The latter fact permits relatively small groups to be arranged for interswitching economically, whereas other methods afford the facility to small groups only at great relative expense.

It is to be understood that the system herein contemplated is adapted to be isolatedly installed on the premises of a group subscriber, and under this condition would be a P. A. X. or a P. B. A. X. If the isolated installation serves a plurality of group subscribers it would become an aggregate private automatic exchange or an aggregate private branch automatic exchange.

The substation equipment used by group subscribers being generally similar to that used by subscribers for a single substation, the men installing and maintaining the substations of the system generally will be familiar with the substations and connections

of the group subscribers. This conduces to lower installation and maintenance costs and more prompt installations and repairs than where special corps of men must be provided for two widely different classes of work, as exists where switching equipments are installed on the premises of the subscriber.

The present invention also comprehends a pair of passing call connector elements of the general type as disclosed in the British patent to Friendly (the present applicant), No. 139,000. The pairs of connector elements shown herein are arranged for passing calls in-coming to the group after the main element automatically selects the attendant's line or the first disengaged alternative answering line, signaling upon same and obtaining a response. That is to say, the party responding (by removing the receiver from the switch-hook), resultant to the first idle subscriber's trunk to the subscriber's group being seized, can pass the call to a second line of the same subscriber group and cause the calling signal device thereof to operate. The passing can be continued under directive control of the last party called, or the last party called may restore his receiver and the party called previously can again pass the call, as contemplated in the foregoing cited patent.

Among the novel operative features of the passing call connectors of the present invention is the function wherein after a call has been passed, but not responded to, and the passing party restores his receiver while the passing connector element is still signaling the last called party, after a predetermined number of rounds of signals have been applied to the last called line, the passing party's line will be automatically signaled distinctively and the passing call connector element employed in the passing will be coincidentally restored, in readiness for the passing party to pass the call to an alternative line forthwith, if desired. Under the latter condition the passing party will be thus apprised before responding to the signal that the last called party failed to respond. If the line to which the connection is passed tests busy, evidenced by the tone heard, the last established connection can be released and a new one established by re-passing, etc. However, if upon passing the call the busy tone is perceived, indicating the desired line is busy, the passing party can instruct the passed party to hold the line awaiting the idleness of the desired line, and forthwith restore his receiver by way of disconnecting his line. The calling party (holding his receiver), will continue to hear the busy tone until the last called line becomes disengaged, whereupon the latter line will be signaled upon normally and the passed connection completed upon the said last called party responding. In this connection it is to be borne in mind

that while the passing connector element locks against seizing on encountering the busy condition, it is periodically unlocked so it may re-test the condition of the last called line. The various connectors concerned in a specific subscriber group are differently timed as relates to the said unlocking, so in the event two connectors are awaiting the opportunity to seize the same busy line, both cannot seize simultaneously, but only the one unlocked first after the busy condition terminates. Other waiting connector elements will be enabled to seize consistent with an idle condition ensuing, and the timing order.

Reference has been made to the first answering line of the subscriber group being automatically selected and signaled upon. The signaling current so applied will be of a specific character, so the distinctive tone of the signal bell or device will evidence to the auditor that the call is an initial call from over the trunk, for the lines designed to answer such calls may be any of the lines of the subscriber group. That is, certain lines will be arranged to receive initial calls in an order of preference. All lines of the subscriber group may be so arranged in an order of preference, or certain ones only. If all the answering (attendant) lines are busy (bearing in mind they may be adapted for normal local and trunk calling in addition to being answering lines), the party calling the subscriber's group will be so apprised by receiving a busy tone. Upon a first response being obtained, the signaling current as regards the pair of connector elements concerned will be changed, so that any party receiving a call through one of them subsequently, will be incidentally apprised by reason of the distinctive operation of the signal device that the call is a passed one. Again, if the passing party is re-called, as referred to, when the passed party does not receive a response after a predetermined number of rounds of signals have been applied, the signaling current as regards only the connector having access to the passing party's line will be changed in character, so the passing party on receiving the signal will be incidentally apprised of the condition. In this connection, it may be stated, that should the passing party remove the receiver after the first round of signals has been applied to the last called line, the connector element in engagement with the passing line will be restored, so the line switch of the line of the passing party will forthwith unseize and hunt, and seize an idle trunk leading to a local connector, by way of initiating a new call.

The lines, consisting of a loop circuit, simply, connecting the main exchange with the respective substations of the subscriber's groups may be directly connected to the sub-

station set concerned, or the said pair may loop through a cut-off springjack. Also, a busy indicator, connected in series relation with one of the conductors of the loop is provided to visually indicate the busy or the idle state of the concerned line. The said indicators and springjacks would be located visually and operatively convenient to the first choice answering substation (which has been referred to as the attendant's station), so that calls for lines which are busy may be held without first passing the call to ascertain the state thereof. A pair of switching cords may be provided whereby the attendant may communicate with a desired substation directly, or may inter-connect two substations. To guard against a switch seizing a line which may be cut at a springjack, provision is made through the agency of a set of auxiliary contacts on the springjack, whereby a resistance is applied in bridge of the exchange end of the line cut. The value of the resistance is such that the line relay of the line switch, which is marginal, will not fully operate, and, by its state, applies a guarding condition on the concerned line, but does not cause the line switch to hunt nor seize.

In order to provide an alternative line as a first choice line for non-office hours of a concerned group subscriber, such line is arranged so that a pre-arranged substation of the group, perhaps the attendant's substation, may call a predetermined local number and thereby set up a condition which will cause all calls to the subscriber group to be diverted to the said alternative line. This line may be one of the lines of the subscriber group concerned, or it may even be any exchange line normally selectively irrelevant to the group. The condition thus set up may be restored to normal by calling the same predetermined number from the said substation arranged to set up the condition. A circuit involving the line switch of the prearranged substation is employed in carrying out this function.

Reference has been made to the line switches being adapted to seize a trunk outgoing from its group. Incidental to this seizure, the main element of the passing call unit of the seized trunk will be rendered operative, as if the call had been made to the trunk from the far end. However, in this instance, the operative element of the said unit will be enabled to automatically introduce the passing call unit into the trunk so that the far end will be extended to the leading-in terminals of the passing call unit, and the wipers of the first operative element (the main element) of the unit will be in seized relation to the trunk leading from the line switch. That is to say, the calling substation now bears the relation to the trunk (bearing in mind the seized rela-

tion of its line switch in this instance), as if the call had been initiated from over the far end of the trunk. Under this condition, the calling party is enabled to operate his calling device and pass the call to any substation line of the concerned subscriber group as if the call were an in-coming one, in lieu of out-going. A system having the latter functions in a somewhat modified and restricted relation, in that there is a connector interposed between the line switch of the calling party and the trunk, as well as other limitations, is disclosed in my pending application, Serial No. 509,263, filed October 21st, 1921.

In a comprehensive exchange system supplying group inter-switching service, varied conditions and classes of the service are to be satisfied. This entails more or less radical adaptations in the basic equipments to meet the requirements. That is, for example, certain subscribers will have enough substation lines to fill two or more levels of the local connectors; certain subscribers will have only enough substation lines to fill one level, while other subscribers will have but four or five substation lines, or enough to fill, say, half of a level. Again, certain of the subscribers may be served manually, that is, the out-going service from the subscriber will be responded to by a main exchange operator, and then completed manually or otherwise. The latter manual condition, would perhaps be only temporary, in anticipation of changing to full automatic operation. However, under the manual method referred to it is desirable to make the operation as close to the eventual as possible in order to insure the least confusion at the time of the transition. Therefore, while various adaptations of the system generally referred to and generally described in the foregoing will be detailed presently, it will be understood at this time that the various said adaptations and modifications would, in the commercial embodiment of the invention occur in the same installation, perhaps. To have illustrated all these adaptations and modifications independently in the system chosen to exemplify the invention would have entailed a much larger number of drawings and a greater volume of descriptive matter. It is therefore believed that the plan chosen to illustrate the invention, in view of the last foregoing statements, will make the system contemplated in the present invention amply clear.

One type of the local connectors used in the system contemplates the subscriber groups will each occupy more than a level, there being perhaps fifteen or more substation lines in each group. Such group subscribers will have their substation lines accessible to the type of local connectors last

referred to, and which will be now described generally and which will be presently described in detail. When a call is initiated from a substation of this class of group, the line switch concerned will seize a connector, whereupon the connector will be caused to automatically function and step its shaft so that the wipers thereof align with the bank level one step below the lowest level reserved to the concerned group to which the calling line belongs. The calling party will then send the two digits involved in the substation number of the desired station of his group, whereupon the connector will function to seize it and signal. From this it will appear that where the subscriber's group contains more than nine lines, the calling numbers will consist of two digits, the first digit denoting the level that it occupies and the second digit, the position in the level. It will be understood that the local connectors may have any number of levels, perhaps fifteen or more, but in view of the fact that the connector will automatically set its wipers with relation to the levels reserved to the group containing the calling line, the level referred to with respect to the first digit will be the level with respect to the group and not the level with respect to the local connector itself.

Should the calling party, last above referred to, desire to secure connection with a line other than of his group, the connection may be trunked by calling digit "0" and thereafter annexing the telephone number of the desired line as listed in the general subscriber directory. This will cause the shaft of the local connector to step vertically and close a set of off-normal springs thereon which will cause the local connector to be restored to normal and the line switch of the calling line to forthwith hunt for and seize a trunk in the manner generally as hereinbefore referred to with respect to extending an initiated call to a local connector. In lieu of calling digit "0", depressing a key at the substation to include a resistance will cause a similar function.

The passing call connectors individual to the trunks used by both classes of group subscribers heretofore referred to, are generally similar. However, where the subscriber group does not involve more than one level, the passing call connector employed is not provided with a vertical movement (having only a rotary movement), and other changes are introduced into its functioning as are required to adapt it to the same general operative methods as used in the passing call connectors having a vertical movement and a rotary movement.

It is contemplated that certain of the group subscribers will have traffic of such characteristics as will make it advisable to have a special group of trunks reserved for

- out-going traffic only, which latter trunks will not be equipped for passing calls. To attain connection with one of the trunks of this class, the digit "9" will be called in lieu of the digit "0", whereupon the special line switch employed on the line of the substations permitted to thus call, will be caused to function in a manner generally similar to that mentioned in connection with calling the digit "0". However, when calling digit "9", a condition is set up in the line switch of the calling party's line wherein it will not select a trunk of the group obtained calling the digit "0", but will unseize the trunk primarily seized and forthwith select a trunk of the special group referred to, whereupon the calling party can annex the telephone number of the line wanted to complete the call.
- With relation to the specific functioning on calls emanating from the toll switchboard, provision is made so when the first idle attendant's line is seized, the signaling thereon will only initiate by directive effort on the part of the toll operator. Signaling current thus applied, and applied thereafter under passing conditions, will be from specific sources to index the call emanates from the toll switchboard. Also, if the group of attendants' lines are found busy, the toll operator can, at will, directly reinitiate the testing of same, or they will be periodically re-tested automatically, if the latter method is preferred.
- The foregoing general remarks concerning operative functions of the invention will be amplified in the detailed description of Figs. 1 to 44, inclusive, involving other functions (which have not been referred to), which belong to the invention.

30 With reference to the drawings, Fig. 24 shows an assembly of certain of the figures concerned in one organization of circuits as used in the system. The small numerals in the squares denote alternative figures which are used in other organizations of the circuits to be referred to. Figs. 33, 36 and 37 also show assemblies of the character of that shown by Fig. 24. When the various figures are assembled as indicated by the said Figs.

35 24, 33, 36 and 37, with due regard to the alternative assemblies contemplated as indicated by the small numerals in the squares, the lines extending toward the margins of the various sheets of drawings which register 40 with each other are to be understood as continuations of the same lines in the organization represented by the specific assembly regardless of the fact that these conductors may or may not have reference characters, or 45 reference characters which do not correspond. However, as far as is possible, these characters will correspond with the exception that a letter will be prefixed to indicate that the line concerned is involved in a circuit arrangement different from that described in a former description concerning one or more figures of the assembly. Specific reference to the various figures will be made hereinafter.

50 55 With reference to the assembly of the various figures as shown by Fig. 24, and further shown as a system lay-out in Fig. 43, a main exchange system in which is involved group subscriber equipment is illustrated.

60 60 In Fig. 1 a calling automatic substation S of any suitable type, such as A shown in the patent re-issued to Frank Newforth, No. 13,901, April 13th, 1915, leads to a line switch A of the general class shown in the patent to

65 Lamb, No. 1,193,160, granted Aug. 1st, 1916,

or of the exact type as shown on pages 53 to 55, inclusive, of the third edition of the book by Harry E. Hershey, entitled "Automatic telephone practice". The line switch A has access, in common with other line switches of general exchange subscribers, to the first selector B. Selector B is of the type of that shown on page 60 of the said book by Hershey, however, a set of off-normal springs ON' are arranged to be operated upon the selector shaft attaining the "0" vertical position, for example. The selector B of Fig. 1 has common access with other first selectors of its group to second selector C2 of the same type as selector B but not having an off-normal spring set corresponding to ON' of selector B. Selector C2 has access through its second level, in common with other selectors of its group, to connector L7. The latter connector is of the type of the connector shown on page 38 of the said book by Hershey. The selector C2 has access through its first level, in common with other selectors of its group, to the novel group selecting connector J6 in Fig. 6. In Fig. 4, 90 the operator's switching cord-pair C4 cooperates with springjack CJ4 to extend a connection from a toll switchboard, for example, to toll first selector F4, in common with other springjacks similar to CJ4. First selector F4 is well known in the art, belonging to same class as selector B. First selector F4, in common with other first selectors of its group, has access to second selector H5 in Fig. 5. Selector H5 is similar to selector F4. Selector H5 has common access through its 95 first level, with other selectors of its group, to connector J6. It will therefore be clear that connector J6 may be reached by calling the same digits ("1-1") from either substation S or from the operator's switching cord-pair C4 through the agency of calling device CD4. 100

105 In this connection it will be stated that the bank positions accessible to selectors C2 and H5 correspond. The bank contacts in Figs. 1, 2, 4 and 5, may be assumed as being the first contacts of the levels indicated. The first set of bank contacts of the second level of selector H5 has not been shown. These 110 contacts, not shown, may lead to a special toll connector or combination local and tool connector, well known in the art, having access to bank contacts in common with connector L7 so that local subscribers and the toll operators are thus enabled to reach substations S7 commonly, or may reach connector J6 115 commonly. However, the connector J6 will operate in a specific manner dependent upon whether it is seized by local selector C2 or by toll selector H5, as will appear presently. Connector J6, in common with other connectors of its group, has access to the passing call connector shown in Figs. 10 and 11, made up of main element M10 and auxiliary ele- 120 125 130

- ment N11, through the apparatus shown in Fig. 8. The apparatus shown in Fig. 9 is interlinked with the passing call connector elements M10 and N11 and involves equipments having to do with the functioning of the said passing call connector. The passing call connector, in common with other similar connectors of the concerned subscriber's trunk group, has access to the lines leading from the main exchange to the substations of the concerned subscriber's group, it being understood that the passing call connectors are specific to a certain subscriber's group only and that they are located, preferably in the main exchange building contiguous to the main exchange selectors and connectors referred to, which are antecedent. The substations of each subscriber group terminates in a line switch, such as P13 and Q13 of Fig. 13, and R14 of Fig. 14. The said line switches P13, Q13 and R14 are novel, but of the same general type as line switch A. The substation sets S20 and SJ20 shown in Fig. 20, and S17 in Fig. 17, are similar to substation S, however, the substation SJ20 shown in Fig. 20 has a key K20 for including the resistance $r'20$ in the path including the line relay of its line switch. The object of the latter arrangement will appear presently.
- 30 The line leading from line switch Q13 has a cut-off springjack J20 introduced intermediate of the said line switch and the substation SJ20 so that inserting a switching plug, such as is shown in Fig. 21, into springjack J20 will cause the resistance $r'20$ to be introduced in bridge of the line conductors leading to line switch Q13, and will also disconnect the said line conductors from the substation SJ20. The object of thus introducing the resistance $r'20$ will be discussed presently. The series, shunted visual indicator B20 is included in the talking conductors of the substation SJ20, and thus operates whenever the receiver is off the switch-hook at the substation, and therefore, indicates to the attendant on the premises of the subscriber, the state of the line. The novel line switch T16 in Fig. 16, (but which belongs to the same general class as line switch A), for the present is assumed to belong to a different subscriber group from that involving line switches P13, Q13 and R14. The substation S16 and associated subscriber equipments may be assumed similar to that shown connected to line switch Q13, with the exception that a key is not provided for introducing a resistance into the line conductor leading to the substation. It will appear, however, that the line switch T16 has access to the same local connector U18 of Fig. 18 as the line switches P13, Q13 and R14. In fact, a plurality of groups of line switches may have access to the said connector U18.
- Fig. 19 shows a portion of the auxiliary segment contact arrangement of connector

U18 and is concerned with the directive releasing functions of connector U18. Fig. 23, which alternates with Fig. 18, shows a connector Y23 generally similar to Fig. 18 but has its release off-normal springs ON'23, operated consequent to the sending of digit "0", effective at the "0" level, whereas the connector U18 has its release off-normal springs ON'18 effective at a higher level consequent to the sending of the digit "0". Further, the said release springs of connector Y23 will not operate responsive to digit "9", while the connector U18 (irrespective of springs ON'18), causes specific functioning of the cooperating line switch dependent upon whether digit "9" or digit "0" is sent. In both instances the sending of digit "0" will cause the cooperating line switch to release from its seizure of the connector and thereupon hunt for a two-way trunk individual to the group subscriber, while in the case of the connector U18, the sending of digit "9" will cause the cooperating line switch to unseize and thereupon hunt for an out-going trunk of a group individual to the group subscriber, perhaps, independent of the two-way trunks of the said subscriber. That is to say, the cooperating line switch will differentiate in operation in accordance with the digit "9" or "0" sent by the calling party at the group subscriber's substation. Of course, in the preferred location (in the tributary main office), of the various apparatus elements, the said trunks will be within the main office to which the lines leading to the group subscriber are tributary, and are therefore, exchange local trunks, rather than out-going trunks involved in outside line construction.

35 Figs. 3 and 6 may be attached as shown in dotted lines Fig. 24 (being duplicates of the equipment shown in Figs. 3 and 6 shown in solid lines, but belonging to a separate group to that containing Figs. 3 and 6 shown in solid lines), and would constitute an out-going trunk, such as would be reached by the calling of digit "9", for example, mentioned hereinbefore. Under the latter arrangement, a connector similar to J6 would not be employed, as the traffic concerned would be out-going from the group subscriber. The trunk would therefore, terminate in a line switch similar to B3 in Fig. 3 from whence the call can be extended directly from the calling substation to the general exchange 100 subscribers over equipments similar to those involved in traffic of corresponding direction where the trunk is arranged for two-way service as shown in the drawings. Fig. 22, which alternates with Fig. 15, shows the connections between the passing call connector elements M10 and N11 and line switches, with the group of common local connectors (such as U18) when the concerned group subscriber's lines terminate in the second and 105 110 115 120 125 130

third levels of the local connectors, in lieu of the first and second levels of the local connector, assumed when employing Fig. 15. The arrangement of the group subscriber's lines with reference to his passing call connector will correspond numerically to their local telephone number regardless of the levels involved in the local connector. That is, the lines may be shifted from one level 10 position to another in the local connectors without changing their relation in the passing call connectors, it being remembered that the passing call connectors are all individual to their corresponding group subscriber, in 15 the exampled arrangement, but that the local connectors are common to a plurality of such subscribers. Of course, it is entirely feasible to have a group of passing call connectors (terminating a group of trunks), serve a 20 plurality of group subscribers, by connecting the concerned subscriber lines to the bank contacts thereof. Under this method of operation one attendant would respond to the calls of a plurality of group subscribers (all 25 having the same listed telephone number), and then pass the call to the proper local station. Under this arrangement the groups would be barred against inter-switching between groups, through the local connectors, since a special barring feature is provided, which latter feature may obviously be omitted.

Out-going calls from a group subscriber will be terminated in the line switch D3 (or 30 alternative similar line switch) consequent to the first digit "0", (or "9") being sent, as referred to hereinbefore. The line switch D3 belongs to the same class of, and is generally 35 similar to the line switch A. The line switch D3 however, has a special relay and associated circuits introduced that become operative upon a ground being applied over an auxiliary conductor thereto. The object of 40 this arrangement is to enable group subscribers (or other subscribers of the general exchange through proper adaptations) to reach certain subscribers or groups by sending a fewer number of digit series than those indexed by the subscriber directory 45 number, and would also be employed to give the calling party concerned a shorter than normally provided route to the called line. This is particularly advantageous both to the subscriber and the operating concern where 50 the called subscriber's number involves routing the call through a number of selective switches, as for example, if two or three selectors similar to C2 were normally introduced intermediate of selector C2 and selector B, meaning that the subscriber would have to 55 introduce corresponding digits, and employ corresponding switches were the call normally routed. It will be noted that the line switch D3 has common access with the line switch A to the first selector B and therefore, when

the line switch D3 is seized the first selector B will be in turn seized, assuming of course, that it (selector B) is the one in order to be seized as a first choice. The calling party, upon sending digit "0", following the sending 60 of the digit to attain the trunk connection, wherein line switch D3 is reached, will cause the off-normal spring set ON' in selector B to apply a ground effective to unseizing the line switch D3 and to cause it to thereafter forthwith hunt for and seize a trunk 65 of an alternative group accessible to it, which latter group leads to a higher numerical order selector or receiving circuit than the numerical order of the selector B primarily seizable 70 to the line switch D3. The drawings show the arm switch SA7 closed, so that under that condition, the connector L7 would be forthwith seized. Were the said switch SA7 75 opened and the arm switch SA2 closed, second selector C2 would be seized, and were the arm switch SA3 the only one closed, the receiving circuit E3 would be seized. Of course, it is understood that there are a plurality of alternative trunks which the line 80 switch D3 will be adapted to hunt over consequent to the (second) digit "0" being sent by the calling party after attaining connection with the trunk terminating in D3, by first sending digit "0" or digit "9", which ever 85 the case may be, after initiating the call, one only being shown.

Attention is directed to the fact that substation S, being that of a general exchange subscriber, is also accessible to the concerned group subscriber by reason of a multiplied connection (shown as conductors 844 to 846 in the upper part of Fig. 12, and in other figures) however, calls from substation set S to substations of the group subscribers concerned will take the normal route throughout the general exchange equipment. This latter expedient of legging substation S into subscriber group equipment would be employed where it is desired to get direct and rapid connection with a certain general subscriber from a subscriber's group.

The detailed operation of the system with particular reference to the organization of the circuits shown in Figs. 24 and 43 will now 105 be discussed, by assuming various calls.

Assume a call from substation S of the general exchange to the group of the concerned group subscriber whose telephone number is "1111". Upon the calling party at 110 substation S initiating the call (by removing the receiver from the switch-hook), a circuit can be traced from slow-releasing line relay 1, upper armature of switching relay 2 through the receiver at substation S to 115 ground on resting contact 3, the line relay actuating to cause the line switch A to function in the well known manner to select and seize the first disengaged first selector B. Upon the calling party manipulating the 120

calling device 4 in accordance with the first digit "1", the selector B will be caused to operate its vertical magnet V and its rotary magnet R and select the first set of bank contacts in the first level thereof (assumed to be idle) leading to second selector C2. Upon the calling party then sending the second digit "1", the second selector C2 will operate its vertical magnet V2 and its rotary magnet R2 in the well known manner to select the first set of bank contacts in the first level thereof (assumed to be idle), leading to third selector J6. A circuit can now be traced from the upper winding of line relay 6 (Fig. 6), make-before-break spring 7, bank contacts 8, 9, 10, through the substation set S, bank contacts 11, 12, 13, make-before-break spring 14 to the lower winding of relay 6, the latter relay actuating. Slow-releasing relay 15 is operationally energized to ground on armature of relay 6. Ground on upper armature of relay 15 is applied to bank contacts 16, 17, 18 to maintain the line switch A and the selectors B and C2 seized, the said ground being applied before the relay 19 (Fig. 2) deactuates consequent to selector C2 seizing. Upon the calling party sending the third digit "1", the relay 6 will deactuate and reactuate one time responsive thereto. Upon the retraction of the armature of relay 6, its ground will be applied through the lower armature of relay 15, spring 20 of off-normal set ON6, spring 21, winding of vertical magnet V6, to the winding of slow-releasing relay 22, the vertical magnet and relay 22 actuating. The operation of the vertical magnet will cause its shaft carrying wipers 23 to 27 (inclusive), to be raised one vertical step into alignment with first level of bank contacts, incidentally operating the off-normal spring set ON6. Upon the calling party sending the fourth digit "1", the relay 6 will deactuate and reactuate one time as before whereby its armature upon retracting will apply its ground through the lower armature of relay 15, spring 20, spring 28, lower armature of relay 22 (now retracted), armature 29, winding of slow-releasing relay 30, armature 31' to the rotary magnet R6, the relay 30 actuating and the rotary magnet operating to advance the wipers into engagement with the first set of bank contacts 31 to 35. Assuming for the present that bank contact 32 constitutes ground potential because the corresponding bank contacts of a multipled trunk is in a busy condition. Bearing in mind that relay 22 is now normal, upon wiper 24 receiving ground from bank contact 32, this ground is communicated through make-before-break spring 35' upper armature of relay 30 to the winding of busy relay 36, the latter relay actuating. Upon the retraction of armature of relay 30 consistent with the slow-releasing characteristic thereof, a locking circuit

before-break spring 37, armature 36' of relay 36, make-before-break spring 38, upper contacts on relay 39 to grounded off-normal spring 40.

Assuming further that bank contact 31 is electrically tied to bank contact 32, and therefore, also constitutes ground, a circuit can be traced from ground through wiper 23, lower armature of relay 30, armature 41, interrupter contacts on the rotary magnet, armature 42, winding of relay 43, winding of relay 22 to battery, relays 43 and 22 actuating. A locking circuit for the said relays 43 and 22 is established from armature 41, armature 44 to grounded spring 40. In view of relay 22 being actuated, the relay 36 is maintained locked by way of the upper armature of relay 22, and the grounded wiper 24. A circuit can be traced from grounded spring 40, lower armature of relay 43, armature 31' to the winding of the rotary magnet, the rotary magnet operating to advance the wipers into engagement with the first successive set of bank contacts. At the time the rotary magnet operates, its interrupter contacts will unlock relays 43 and 22, and cause the relay 36 to be again locked to spring 40. Assuming that the second set of bank contacts now engaged by wipers 23 and 24 constitute ground due to their being tied together and the corresponding leading-out line being busy, a circuit can be traced from ground through wiper 23, lower armature of relay 30, and over the before traced path through relay 22 to battery, causing the rotary magnet to advance the wipers an additional step, resultant therefrom. It will now be assumed that the bank contact last engaged by wiper 24, consequent to the rotary magnet having operated three times constitutes ground but that the bank contact now engaged by wiper 23 does not constitute ground because it is unattached. Under the later condition there will be no energizing circuit established for relays 43 and 22, and therefore, there will be no energizing circuit established for the rotary magnet. However, the relay 36 remains locked to spring 40. Under the present condition grounded tone source T6 is applied to the lower armature of relay 36, lower armature of relay 22, and over the traced path including the substation S to grounded battery by way of the upper winding of relay 6.

It will thus be seen that the automatic rotary function is dependent upon the wiper 23 receiving ground and therefore, where a plurality of lines constitute a group which may be consecutively selectively tested, the disassociation of the bank contact of a set adapted to be engaged by wiper 23 will insure that the connector cannot automatically rotate beyond and will either seize there at or apply a busy tone audible to the calling party. The function of seizing referred to is dependent upon the wiper 24 encountering battery po-

70

tential in lieu of ground, whereupon the battery will be applied through spring 35', upper armature of relay 30, outside winding of relay 45, armature 36' of relay 36, spring 38, upper contacts of relay 39 to spring 40, the relay 45 actuating whereby a locking circuit is established from its inside winding, armature 46 to spring 40. The foregoing rotary functioning referred to in this paragraph applies to all types of rotary connectors herein.

Assume now that at the time the bank contacts 31 to 35 were engaged, the bank contact 32 received battery from motor magnet M3 through switching relay 47 and conductor 48. Relay 36 would not then be energized, so that upon the retraction of the upper armature of relay 30, a circuit can be traced from said battery through wiper 24, spring 35', upper armature of relay 30, outside winding of relay 45, armature 36' of relay 36, spring 38, upper contacts of relay 39 to spring 40, the relay 45 actuating and locking as described, to effect a seizure by the connector J6.

Assuming that the connector J6 seized the first set of bank contacts in the manner described, a circuit can be traced from the upper winding of line relay 50 of element M10, conductor 51, make-before-break spring 52, make-before-break spring 53, armature 54, conductor 56, bank contact 33, wiper 25, spring 7 (windings of relay 6 being disassociated), over the traced path including the substation S to spring 14, wiper 26, bank contact 34, conductor 57, make-before-break spring 58, armature 59, make-before-break spring 60, conductor 61, conductor 62 to the lower winding of relay 50, the latter said relay actuating. Slow-releasing relay 63 will be operatively energized due to the attraction of the grounded armature of relay 50, whereupon the grounded upper armature of relay 63 will apply its ground over conductor 64, bank contact 32, wiper 24, spring 35', armature 65 to the winding of relay 15, the latter circuit being completed before relay 15 has had time to deactivate consequent to the retraction of lower armature of relay 6, due to relay 6 having been disassociated at springs 7 and 14. Ground will thus be maintained to hold the antecedent switches seized, and since the relay 45 is maintained locked to the spring 40, the connector J6 will also retain its seizure. However, should the calling party replace the receiver at this juncture, thereby opening the energizing circuit of relay 50, and thus cause ground to be removed from conductor 64, relay 15 in connector J6 will deactivate and close a circuit from the armature of relay 6, lower armature of relay 15, off-normal 60 springs, to the release magnet Re6, the release magnet operating to restore the connector J6 to normal. At the time the upper armature of relay 15 retracts the antecedent switches unseize and complete circuits through off-normal springs of sets ON and ON2 to re-

lease magnets Re and Re2, respectively, restoring in the well known manner.

Going back to the condition ensuing at the time relays 50 and 63 actuate, upon connector J6 seizing, a circuit can be traced from ground 70 on the resting contact of armature 67 in Fig. 8, conductor 68, off-normal springs RO10, armatures 69, 70, 72, 73, 74, winding of slow-releasing relay 75, armature 76 to the winding of the rotary magnet R10, the said rotary 75 magnet operating to advance the wipers 77 to 80 a rotary step from normal position into testing engagement with the first set of bank contacts 81 to 84. Bank contacts 81 and 82 are electrically tied, and a conductor 86 leads 80 therefrom to armature 87 in Fig. 8 to ground on the resting contact of armature 88. Thus, said bank contacts 81 and 82 are grounded. Upon wiper 78 engaging bank contact 82 the ground on the latter will be conducted 85 through the upper armature of relay 75, make-before-break spring 90 thereon to the busy relay 91, the latter relay actuating.

Upon relay 75 deactuating consistent with its slow-releasing period, a locking circuit is 90 established from relay 91 by way of spring 90, armature 92, make-before-break spring 93 to grounded spring 94 of off-normal set ON10, the latter set of off-normal springs being adjusted to close upon the first rotary or vertical off-normal movement of the shaft of element M10. Relay 75 being now deactuated, a circuit can be traced from grounded bank contact 81, wiper 77, armatures 95 and 96, interrupter springs on the rotary magnet, armature 97, winding of relay 98, winding of slow-releasing relay 99 to grounded battery, relays 98 and 99 actuating and locking by way of armature 97, the said interrupter springs, armatures 95 and 100 to spring 94. A circuit 100 can now be traced from spring 94, lower armature of relay 98, armature 76 to the rotary magnet R10, the rotary magnet operating to advance the wipers 77 to 80 into engagement with bank contacts 102 to 105, respectively. 105 Bank contacts 102 and 103 are tied and connected to conductor 106, and the latter conductor is multiply connected with private bank contacts 107, 108 in Figs. 13 and 14, and over conductor 109 to private bank contact 115 110 in Fig. 18 and corresponding contacts accessible to other connectors of its group. Conductor 106 will also attach to bank contacts corresponding to 102, 103 and 108 accessible to other passing call connectors of 120 the concerned group subscriber. Conductor 111, attaches to conductor 106 and leads to the free winding terminal of switching relay 112 of line switch R14.

It will be assumed that conductor 106 is not 125 grounded, indicating that the line extending to substation S17 is idle, and under this condition wiper 77 will not receive ground to further advance the wipers in the manner before described when it received ground from 130

bank contact 81. So upon the retraction of the upper armature of relay 75 battery will be applied from the motor magnet M14 through the winding of relay 112, conductor 111, conductor 106, bank contact 103, wiper 78, upper armature of relay 75, outer winding of switching relay 113, armature 92 (relay 91 having deactuated when wiper 78 failed to receive ground from bank contact 103), spring 93 to spring 94. Relay 113 will actuate and lock its inner winding through armature 114 to spring 94. Ground will now be applied from armature 115, wiper 78, bank contact 103, conductor 106 to the attached bank contacts to guard the corresponding line against intrusion, and the ground will also be communicated over conductor 111 to operate the relay 112 of line switch R14 to disassociate the slow-releasing line relay 117 and the grounded resting contact 118, but will not operatively effect the other armatures and cooperating contacts of the relay 112. It will be understood in this connection that all of the line switches shown in the accompanying drawings primarily operate similar to line switch A, regardless of auxiliary elements contained therein.

Signaling circuit can now be traced from grounded interrupted signaling current source G9, conductor 119 in Fig. 9, armature 120, of relay 121 in element M10, conductor 122, upper winding of series relay 123 in Fig. 9, conductor 124, armature 126 of ring-cut-off relay 127 in element M10, conductor 128, armature 129, wiper 79, bank contact 104, conductor 131, conductor 132, conductor 133 through the bell of substation S17, conductors 134, 135, 136, bank contact 105, wiper 80, armatures 138 and 193, inner winding of relay 127 to grounded battery. The signal bell at substation S17 will operate but the relay 127 will not be operatively energized, due to the condenser in the said bell. Upon the party at substation S17 responding, a conductive circuit will be closed between conductors 133 and 134, and under this condition, relay 127 will operate, whereupon, its armature 140 will close a locking circuit from its winding through off-normal spring 142, conductor 143 to grounded spring 144 of the set RC9 in Fig. 9. Armature 145 of relay 127 now receives ground from its working contact. The object of the latter spring set will be set forth presently. The talking circuit from calling substation S will now be continued from the traced circuit including conductor 51, condenser 146, upper armature of slow-releasing relay 147, armature 126, conductor 128 and over the traced path including the substation S17 to armatures 138 and 139, lower armature of relay 147, condenser 150, conductor 62 and over the traced path including the calling substation S to conductor 51. The calling party at substation S is now in talking relation with the

called party at substation S17. In the latter instance the substation S17 may be considered the attendant's station. It is shown connected as a subscriber's substation, but it is manifest that a springjack and cooperating operator's plug, or a key and cooperative operator's set, could be substituted therefor.

It will now be assumed that the line leading to substation S17 is busy by reason of it having been previously called, or that a call had been initiated therefrom, causing the conductor 106 and attachments to constitute ground. Under this condition bank contacts 102 and 103 would apply ground to wipers 77

and 78 upon their engagement, so that relay 91 would be maintained actuated from the ground received through wiper 78 and the ground applied from wiper 77 to armature 95 of relay 75 will cause the rotary magnet R10 to further advance the wipers in the manner before described when it received ground from bank contact 81. The wipers 77

to 80 are now in testing engagement with bank contacts 152 to 155, respectively, corresponding to substation S20, which latter substation

may be considered the second order of choice attendant's station. It is manifest that the alternative arrangement mentioned with relation to substation set S17 also applies to the said S20, and in fact, substations S17 and S20

may be located convenient to the same answering party. Other substation lines not shown, for example, may also be accessible to the same answering party.

Upon the bank contacts 152 to 155 being engaged by wipers 77 to 80, respectively, wherein bank contact 153 does not constitute ground because of the corresponding line being idle, relay 113 will operate and lock following the retraction of upper armature of relay 75, in the manner as hereinbefore described.

In this connection it will appear that upon relay 113 actuating, wherein wiper 78 becomes grounded, this ground will be applied through engaged bank contact 153, conductor 166 and to attached bank contacts 167, 168 and to conductor 169, leading to bank contact 170 accessible to connector U18. The conductor 166 also attaches to the corresponding bank contacts accessible to the passing call

connectors of the concerned subscriber and to the private bank contacts corresponding to 170 of the local connector of the group containing U18 to guard the corresponding line against intrusion. It furthermore, has a branch 172 leading to the free winding terminal of switching relay 173 of line switch P13, the latter relay being energized whereby the slow-releasing line relay 174 and the

grounded resting contact 175 will be disassociated, but will not operatively effect the other armatures and cooperating contacts of the relay 173. The signaling current will be applied over the circuits traced to wiper 79, bank contact 154, conductors 178, 179, 180,

signal bell of substation S20, conductors 181, 182, 183, 184, bank contact 155, wiper 80 and over the before traced path including the inner winding of relay 127 to grounded battery, the said signal bell operating. Upon the party at substation S20 responding, the relay 127 will be operatively energized in the manner before set forth, whereupon the calling party at substation S is in talking relation with the party at substation S20. It will be noted in this connection that bank contact 152 is unattached, and therefore, the condition of bank contact 153 will not affect it. Thus, if the line leading to substation S20 is busy, evidenced by the conductor 166 constituting ground, the wiper 77 will not receive ground to cause the rotary magnet R10 to advance the wipers further. However, since wiper 78 receives ground, the relay 91 will be maintained actuated so that when the upper armature of relay 75 retracts, a locking circuit for said relay 91 will be completed through spring 90, armature 92, spring 93 to spring 94, it being noted that until relays 75 and 99 deactuate after the last impulse is applied to the rotary magnet, the locking circuit for relay 91 leads to wiper 78. The locking circuit finally established for relay 91 will not be opened should the conductor 166 become ungrounded since it is not dependent upon the latter ground after the deactuation of relay 99.

It will be manifest from the foregoing, that where the bank contact engageable to wiper 77 is unattached, the rotary magnet cannot be thereafter caused to automatically function, and that if ground is encountered by wiper 78 at the corresponding position, the relay 91 will be caused to remain locked until its locking circuit is opened at spring 94, which latter condition can only occur upon the shaft of the main element M10 being restored to normal position, in the manner as will be described presently. Under the condition of relay 91 being locked, the busy tone source T10 will be applied through armature 186, lower armature of relay 99, condenser 150, and over the traced path including the substation S to ground through the upper winding of relay 50, audible to the calling party.

Going back to the condition wherein a response is obtained from substation S20, and wherein the relay 127 actuated and locked. A circuit can be traced from the locking ground applied through armature 140 to the upper terminal of the lower winding of back-bridge relay 188, and over the traced path including the responding station (S20) and armature 126, upper winding terminal of relay 188, conductor 189, upper winding of retardation coil 191 in Fig. 8 to grounded battery, the relay 188 energizing and incidentally supplies transmission battery to the responding party. The object of retard-

ation coil 191 will appear presently. Consequent to the actuation of relay 188, slow-releasing relay 192 is operatively energized through the lower armature of relay 188. Ground from armature 145 is applied through armature 193 to conductor 194 and its attached conductor 195 as well as the conductor leading through make-before-break spring 197 to the winding of relay 121. Relay 121 will actuate and establish a locking circuit for itself from spring 197, armature 198 to grounded conductor 64, which latter conductor is grounded dependent upon the calling party maintaining relay 63 actuated. In this connection it will be noted, that consequent to relay 121 actuating, its armature 120 disassociates the signaling source G9 and associates grounded signaling source RG9 in lieu thereof, by way of conductor 199. The path traced from armature 67 in Fig. 8 is opened by armature 69 on relay 121, thus disabling the element M10 from automatically rotating on its normal level. The upper armature of relay 121 closes a path from the left hand terminal of the vertical magnet V10 to off-normal spring 201 of the set ON10, thus capacitating the said vertical magnet so that it can be thereafter directly operated in the manner as will appear presently.

In connection with the grounding of conductor 194 consequent to the response of the party at substation S20, which will be borne in mind is the first response of the call, a circuit can be traced from conductor 194, through upper armature of relay 200, in Fig. 8, lower make-before-break spring of relay 201' to the winding of the latter said relay, causing it to actuate to reciprocate the relationship of conductors 51 and 61 to make-before-break springs 52 and 60, respectively, so that the current traversing the receiver at the calling substation S is now in the opposite direction to that originally established and maintained until the said actuation of relay 201'. A locking circuit for relay 201' is closed through its lower armature to conductor 202'. The latter conductor would be grounded to off-normal spring 94 or to off-normal spring 231 of element N11, or both, depending upon the shaft of either, or both, the elements M10 or N11, being off-normal, and under this condition will insure that after the relay 201' actuates it will not deactuate until all connections to substation lines through the concerned passing call connector has terminated and the connector shafts have been restored. The current traversing the receiver of the calling substation S will then be restored to the direction primarily established consequent to the initiation of the call.

Assuming for the present that the calling party at substation S replaces the receiver on the switch-hook to terminate the service,

the traced energizing circuit for relay 50 will be opened, whereupon the dependent relay 63 will deactivate. A circuit can now be traced from ground on the upper armature 5 of relay 63, off-normal springs to the release magnet R₂₁₀, the release magnet operating to restore the shaft to normal position, unlocking relays 113, 127, 188, 192 and 121.

Going back to the condition of the circuits 10 after the response at substation S20 was obtained, and remembering that relays 127, 188, 192, 201' and 121 actuated resultant thereto, it will now be assumed that the party at substation SJ20, the local telephone number 15 which is "21", is wanted. The call will be passed in the following manner. The party at substation S20 will manipulate the calling device thereat in accordance with the first digit "2", opening the traced energizing circuit 20 for relay 188 two times, responsive thereto, whereupon a circuit can be traced from ground on its lower armature, armature 202, (relay 192 sustaining over the lapses), to the winding of slow-releasing relay 147, the latter relay actuating to open the talking circuit 25 towards the calling party to prevent his hearing disturbances consequent to the said two openings. The latter ground is also applied over conductor 203, off-normal spring 30 204 of off-normal set ON11 of element N11, spring 205, windings of vertical magnet V11, and slow-releasing relay 206 to grounded battery, the latter relay actuating and the vertical magnet operating to step the shaft 35 carrying wipers 207 to 210 two vertical steps into alignment with the second level of bank contacts, the off-normal spring set ON11 operating incidental to the first off-normal movement of the shaft, so that the spring 40 205 becomes disassociated and the path through the vertical magnet from spring 204 is now by way of alternative path including spring 212, lower armature of relay 206 and its working contact. Upon the party at substation S20 sending the second digit "1" constituted of one open impulse, having in mind 45 that relay 206 deactivated before hand, the relay 188 will cause its lower armature to apply its ground through armature 202 to 50 actuate relay 147 for the object before mentioned, and also apply ground over conductor 203, spring 204, spring 212, lower armature of relay 206, its resting contact, armature 214, winding of slow-releasing relay 215, armature 216 to the winding of rotary magnet R11, the relay 215 actuating and the rotary magnet R11 operating to advance the wipers 207 to 210 into engagement with bank contacts 217 to 220, respectively, corresponding to the 55 called substation SJ20.

Assuming for the present that bank contact 218 does not constitute ground, indicating that the line leading to substation SJ20 is idle, the busy relay 222 will not have been 60 energized, so that when the armature 227 of

relay 215 retracts following the impulse imparted to the rotary magnet, a circuit can be traced from the winding of motor magnet M'13 of line switch Q13, winding of switching relay 223, upper armature of slow-releasing line relay 224, conductor 225, private conductor 226, bank contact 218, wiper 208, armature 227 of relay 215, outer winding of switching relay 228, armature 229, make-before-break spring 230 on relay 206 to 70 grounded off-normal spring 231, a locking circuit for relay 228 being now closed through its armature 232 to grounded spring 231. This disables the rotary magnet by reason of armature 216 being now attracted. Grounded armature 234 applies its ground to conductor 235, and over wiper 208, bank contact 218 to conductor 226. One branch from conductor 226 applies this ground through the upper armature of relay 224, winding of switching relay 223, winding of motor magnet M'13 to grounded battery, operatively energizing the latter relay to disassociate the relay 224 and grounded resting contact 237, but will not operatively affect the other armatures and cooperating contacts of the relay 223. Under the condition of relay 228 being locked, the outer winding has both its terminals grounded, and are therefore, not energized. 80

A circuit can now be traced from grounded interrupted signaling source RG9 in Fig. 9, upper armature of relay 238, upper winding of series relay 239, conductor 240, armature 241 of ring-cut-off relay 242 in element N11, 100 armature 243, wiper 209, bank contact 219, conductors 244, 245, 246, through the upper talking spring of springjack J20, shunted indicator B20, signal bell at substation SJ20, lower talking spring of springjack J20, conductors 247, 248, 249, bank contact 220, wiper 210, armatures 250, 251, inner winding of relay 242 to grounded battery, the bell at substation SJ20 operating, however, the relay 242 will not operatively energize 105 over the path due to the condenser in the said bell. 110

Under the condition of applying the signaling current operative to the signal bell at substation SJ20, armature 145 on relay 115 127 of the element M10 is attracted, and therefore, ground can be traced from working contact, armature 145, conductor 253, armature 254 on relay 239 in Fig. 9, conductor 255 to armature 257 on relay 192, the 120 latter armature being attracted due to the fact, that the passing party at substation S20 is holding the receiver off the switchhook. However, assuming for the present that the latter said party now replaces the 125 receiver, and therefore, the relay 192 will deactivate, the circuit traced to armature 257 will now be continued over conductor 259 to the winding of the motor magnet M9 in Fig. 9, causing it to operate and advance 130

its wipers 260 and 261 into engagement with the first set of bank contacts, following the resting set.

In this connection it will be understood, 5 that the motor magnet M9, together with its wipers 260 and 261, and cooperating bank contacts, are a part of a rotary switch mechanism, generally similar in construction to the line switch A, however, the shaft carrying the wipers 260 and 261, also carries three cams shown in somewhat detail in Figs. 9A, 10 9B and 9C, respectively. The cam in Fig. 9A is designed to operate the set of off-normal springs RR9 consequent to the first 15 off-normal movement of the wipers 260 and 261. The cam in Fig. 9B is designed to operate the set of off-normal springs RC9 consequent to the fourth rotary step of the wipers 260 and 261, whereon they engage 20 bank contacts 262 and 263, respectively. The cam in Fig. 9C is designed to operate the set of off-normal springs R9 consequent to the fourth rotary step of the wipers 260 and 261. The signaling sources being de- 25 signed to apply interrupted current, the relay 239 (as well as relay 123 when concerned), will operate periodically corresponding with the applications of signaling current effective to the signal bell at the 30 called station. In this connection attention is directed to grounded interrupted source AG9, which is in multiple with the live terminal of source RG9, but timed to apply its current at the instant current from source 35 RG9 ceases. The current from source AG9 will sustain relay 239 (also relay 123), but will not be effective to a signal bell. The current from source AG9 is disconnected a brief period before the current from source 40 RG9 is applied, in order to allow relay 239 (or 123) to momentarily deactuate. The object of thus providing source AG9 will appear presently. It will thus be manifest 45 that the motor magnet M9 under the condition of signaling substation SJ20 will operate and advance the wipers 260 and 261 a step to the next successive set of bank contacts for each round of impulses constituting a signal. It will be noted that bank contact 50 262 engaged by wiper 260, at the fourth step, constitutes ground, also that the contact 264 following constitutes ground. The bank contact upon which the wiper 260 is shown resting, is the one engaged next successively to bank contact 264, there being six steps in the cycle. The present arrangement contemplates, therefore, that the wiper 260 will receive ground incidental to the 55 fourth signal being sent, though obviously, less or more contacts may be arranged for any correspondingly less or greater number of signals being sent to thus ground the wiper 260.

It will now be assumed that the called party 60 at substation SJ20 has not responded and

that four signals have been sent and that wiper 260 is in engagement with bank contact 262, having in mind that under this condition off-normal spring set RR9 will be normal; that off-normal spring set RC9 will be 70 normal; and that off-normal spring set R9 will be operated. The locking circuit for relay 127 will be opened at spring 144 of the off-normal spring set RC9. The spring set R9 operating at this juncture, closes a circuit 75 from grounded lower armature of relay 239, spring 265 to the winding of relay 266, causing it to actuate and lock by way of conductor 267, lower armature of relay 127 of main element M10, upper armature of relay 242 of auxiliary element N11 to spring 231. At the time relay 266 actuated and locked, its lower armature applied its ground through off-normal springs of set ON11 (over conductor 267') to the release magnet Re11, operative 80 to restore the shaft of element N11 to normal position, in readiness to be directly operated, incidentally disconnecting the line leading to substation SJ20. However, we are concerned at this time more particularly 85 with the functioning of the main element M10. A circuit can now be traced from grounded interrupted signaling current source BG9, armature 268, conductor 124, armature 126 and over the traced path includ- 90 ing the signal bell at substation S20 and back to grounded battery attached to the inner winding of relay 127, the signal bell at substation S20 vibrating responsive to the said application of current. In this connection it is to be understood that the character 95 of current emanating from source BG9 is of such frequency or of other character), as will distinctively effect the signal device at substation S20 so that the character of the received signal serves to prompt the party thereat, that the party at the substation to which the call had been passed failed to respond after the predetermined number of signals had been applied to his signal device. 100 Upon the party at substation S20 removing the receiver from the switch-hook, the relay 127, followed by relays 188 and 192, will actuate in the manner as hereinbefore described 105 when the substation S20 was initially called. 110 The party at substation S20 is now again in talking relation with the calling party at substation S. In this connection attention is called to the fact that an inductive relation exists between the windings of relays 127 and 124, respectively, and that the respective outer windings thereof are conductively related through a winding of the corresponding back-bridge relays 188 and 269, respectively, to one of the talking conductors leading to the calling substation S, so that tracings of the signaling current projected to a 115 called substation is reverted audible to the calling party. It will thus appear that the peculiarities characterizing the ringing cur- 120 125 130

rent source BG9 will be discernible, to index the condition to the calling party at substation S.

Upon the party at substation S20 responding to the re-call, if desired, the service may be terminated by the parties replacing their respective receiver, whereupon, element M10 will be restored to normal as described.

Assuming that in lieu of terminating the 10 service, it was desired to pass the call to the line leading to substation S17. The party at substation S20 will operate his calling device in accordance with the local telephone number "11" of the line leading to substation 15 set S17, to set the wipers 207 to 210 upon contact set 274—108—275—276, corresponding to the line leading to substation S17, in the manner as hereinbefore described with reference to passing the call to the line leading 20 to substation SJ20.

Going back to the condition of the circuits at the time the first signal is applied to the line leading to substation SJ20, it will be noted that while the party at passing substation S20 maintains his receiver off the switch-hook, that the energizing circuit for the motor magnet M9 traced from armature 145 of relay 127 is open at armature 257. However, when the receiver is replaced on 25 the switch-hook at substation S20, the said circuit is prepared to be operatively closed at armature 254 upon the first actuation of relay 239 thereafter, so that the re-ringing of the party passing the call is thus dependent 30 on the predetermined number of signals as sent after he has replaced his receiver on the switch-hook.

It will now be assumed that after the passing party (at S20) has replaced his receiver 40 on the switch-hook and the motor magnet M9 been caused to advance the wipers 260 and 261 consequent to the first signal sent thereafter, and bearing in mind that the off-normal spring set RR9 is now operated, a 45 circuit is prepared, operative upon the passing party removing his receiver from the switch-hook to initiate a new call out-going from his substation, which will cause the element M10 to be restored to normal position, 50 permitting the signaling to proceed to the substation line to which the call has been passed. Under the latter condition, upon the party at substation S20 removing the receiver from the switch-hook, a circuit will be 55 closed from the lower armature of relay 239, off-normal spring 280, conductor 281, armatures 282, 283, off-normal springs, to the release magnet Re10, the shaft of main element M10 thus restoring to normal position, inci- 60 dentally removing the ground applied to conductor 172 for maintaining the relay 174 of the line switch P13 disassociated. The relay 173 will restore and relay 174 will actuate from the circuit established thereby, includ- 65 ing conductor 180, the receiver of the sub-

station S20, conductor 181, to grounded resting contact 175 in line switch P13. Relay 174 actuating, its armature 284 applies its ground to conductor 172 and its attachments, to guard the line leading to substation S20 against intrusion. It will be assumed that the local connector U18 corresponding to the set of bank contacts upon which the wipers of line switch P13 are shown resting, is idle, and therefore, bank contact 286 does not constitute ground. Under this condition battery through the winding of rotary magnet M13 is applied through the winding of relay 173 to grounded armature 284, causing relay 173 to actuate (motor magnet M13 not being energized sufficiently to actuate due to the winding of relay 173 being included therewith), and continue conductors 180 and 181 to bank contacts 287 and 288, respectively, relay 174 becoming disassociated. In this connection it will be noted that had the bank contact 286 constituted ground due to its attached conductor 290 receiving ground from working contact 291 in connector U18 over conductor 292, thus indicating that the said U18 is busy, this ground applied through armatures 293, 294, 295 to the winding of motor magnet M13 operatively energizes the latter, preparatory to advancing the wipers to the next set of bank contacts consequent to 90 the armature on the said motor magnet M13 interrupting its circuit, whereupon it will seize or rotate-off as set forth, dependent upon the grounded or non-grounded condition found by wiper 296. A circuit can now 95 be traced from the upper winding of line relay 297 in connector U18, make-before-break spring 298, conductor 299, conductor 300, bank contact 287 and its engaged wiper, conductor 180, receiver of substation S20, conductor 181, engaged wiper and bank contact 288, conductors 301 and 302, make-before-break spring 303 to the lower winding of relay 297, the latter relay actuating. A circuit 100 can now be traced from grounded resting contact 304, its cooperating make-before-break spring, lower armature of relay 297 to the winding of slow-releasing relay 306, the latter relay actuating to apply the ground from working contact 291 over conductors 292, 290, 105 bank contact 286, wiper 296, armature 293, winding of relay 173 to the winding of motor magnet M13, thus maintaining the line switch P13 seized.

Returning to the condition of the circuits as ensued, immediately upon the party at substation S20 passing the call to the line leading to substation SJ20, it will be assumed that the line leading to substation SJ20 is busy, and therefore, bank contact 218 constitutes ground potential. Under this condition, this ground will be communicated over wiper 208, conductor 235, armature 227 of relay 215, to the winding of relay 222, the latter relay actuating, preparing a locking 110 115 120 125 130

circuit for itself upon the retraction of the armature 227, which may be traced from make-before-break spring 307, armature 229, spring 230 to spring 231, the relay 222 remaining locked dependent upon the opening of 5 the circuit at spring 231. Tone source T10 will be applied through the lower armatures of relays 222, and 206 to the talking conductor leading through the lower armature of slow-releasing relay 308, condenser 309, conductor 10 51, spring 52 and over the traced path including the receiver of the calling substation S, spring 60, conductor 61, condenser 310', upper armature of relay 308, upper winding of relay 269, lower winding of retardation 15 coil 191 in Fig. 8 to grounded battery, the tone being audible to the calling party at substation S and also, to the passing party at substation S20 over the interlinked talking circuits previously traced. Upon the passing 20 party noting the condition, he can directively restore the shaft of the element N11, looking toward repassing the call to an alternative substation line, by sending digit "1", or by equivalently flashing the switch-hook. Sending 25 digit "1", and thereby causing relay 188 to deactuate and reactuate one time, will cause relay 147 to actuate and a ground to be applied from the upper armature of relay 188, armature 310, conductor 311, upper armature of relay 215, armature 312, off-normal springs to the release magnet Re11, operative to restore the shaft of element N11 to normal position. Assuming that through inadvertence, the passing party at substation S20, fails 30 to take notice of the busy tone applied consequent to finding the line leading to substation SJ20 busy, as last assumed, and forthwith replaces his receiver on the switch-hook, believing the signal at the substation S20 to be 35 operating. Under this condition the upper armature of relay 222 will be attracted, whereupon a circuit can be traced from armature 312', engaged make-before-break spring 40 of relay 121, armature 313, lower armature of relay 192, conductor 314, upper armature of relay 222, conductor 315, lower winding of relay 239 in Fig. 9. This ground is applied to the first four bank contacts engageable to 45 wiper 261 in Fig. 9.

Ground thus applied to the bank contact normally engaged by wiper 261 will be applied through the interrupter contacts to the motor magnet M9, causing the wipers 260 and 261 to be driven to the next succeeding set of bank contacts incidental to the retraction of the armature of the motor magnet M9, and since the wiper 261 will there encounter a grounded bank contact, the motor magnet M9 50 will again operate to again advance the wipers as before. This cycle of operations will continue until wiper 260 encounters grounded bank contact 262, after which the wipers 260 and 261 will be returned to their 55 normally resting contacts in the manner as

has been hereinbefore described, incidentally operating the off-normal spring sets associated therewith. The locking circuit for relay 127 will be opened at spring 144 of off-normal set RC9 and the bell at substation S20 will 60 vibrate from the current derived from ringing current source BG9 in the manner described wherein the predetermined number of signals was applied to the bell at substation SJ20, without obtaining a response therat. 65 In this instance, due to the prompt re-ringing, in connection with the peculiar performance of the signal bell at substation S20, the party thereat will be prompted that the line to which he just passed the connection was busy. 70 Upon the party at substation S20, responding to the re-call, the relays 127, 188 and 192 will operate in sequence as before, the locking ground path having been closed through 75 spring 144 in Fig. 9. In case the closure through spring 144 should not occur until after the re-called party responds, relay 188 would be delayed in actuation a brief period until the said closure takes place. The element N11 being at normal, the call can be 80 again passed forthwith, through the element 85 N11, in the manner as before, as if the previous passing had not taken place.

With reference to the last foregoing paragraph, if it is assumed that the party at substation SJ20 responds within the predetermined number of signals, and therefore, the wiper 260 will not have progressed into engagement with bank contact 262, due to the conductor 195 becoming grounded incidental 90 to the response wherein armature 313 will be attracted, the motor magnet M9 will be caused to automatically function by way of returning the wipers to their normal position as shown in the drawing, in the manner as has been described. Incidental to this functioning of the motor magnet M9, conductor 143 will become disengaged from ground at spring 144 and therefore, the relay 95 100 105 110 115 120 125 130 135 140 145 150 155 160 10270 10275

line leading to substation S20. In commercial operation, a suitable time will be allowed to elapse before initiating a call after passing, where a doubt exists as to a prompt response. In any event, if the calling party at substation S replaces his receiver, wherein relays 50 and 63 of element M10 will reactivate as described, the retraction of the upper armature of relay 63 will apply ground over conductor 270, off-normal springs of set ON11, to the release magnet Re11, operative to restore the passing call connector to normal.

In this connection attention is directed to the solenoid relay 316 in Fig. 9. Its upper winding attaches to conductor 259. The latter said conductor becomes grounded periodically when a call is passed, and until a response has been obtained, and the wipers 260 and 261 have returned to normal position. The lower winding of the said solenoid relay attaches to conductor 195. It will thus appear that the latter said relay will be energized whenever a line connected through wipers of the passing call connector is in a responded state, or if the passing call connector is signaling on a passed call, but not an initial call wherein source G9 is concerned. The latter said relay has a plunger-arm 318 which is drawn upwardly when either or both its attracting windings are energized, and it will withdraw slowly by gravity under dashpot (or equivalent) restraint, upon the tractive force ceasing. Pivoted arms 319 and 320 are linked together by a link 321. The arms 319 and 320 have friction in their pivots whereby, when the arm 319 is moved upward under influence of the plunger-arm 318 until it engages contact attached to spring 197, it will not retract therefrom until the plunger-arm engages the linked arm 320 upon the predetermined period elapsing after the solenoid has become deenergized. It will thus appear that bar 322 will not be grounded on the upward stroke of the plunger-arm, but will be on the downward stroke. In view of the fact a predetermined period must elapse before the plunger-arm will retract, the bank contacts 323 and 324 adapted to be engaged by plunger-arm 318 in common with bar 322, cannot be so engaged and grounded until the said predetermined period has elapsed after the last line connected through the passing call connector wipers has been conductively opened by the receiver thereon having been replaced, or that the said predetermined period has elapsed after the last signaling application has terminated, in the case of a passed call wherein no response has been obtained. The object of both sustaining provisions will appear presently.

If it is assumed that when the substation S20 was first called, the responding party thereat replaced his receiver while the calling party at substation S still held the line, no

means is provided to restore the element M10 (or element N11 under generally similar corresponding condition), unless the calling party replaces his receiver. Under this condition the conductor 195 becomes ungrounded, and the plunger-arm will retract upon its sustaining period having elapsed, applying ground received from bar 322 to bank contacts 323 and 324. The ground applied to bank contacts 323 and 324 will be operative to either, or both, release magnets Re10 and Re11, depending upon if the corresponding element shafts are off-normal, the circuits having been previously traced. Allowing a period to elapse before the plunger-arm will operatively withdraw as set forth, permits ample time to remove the receiver after effacing a partly passed call, in the described manner for so effacing, for example. Were not the upper winding of the solenoid 316 provided, when a call is passed wherein the passing party replaced his receiver, the passing connector element shaft would become restored in a predetermined period, perhaps before the last called party has had time to respond. In the case of re-calling, the relay 123 (and 239) does not operate due to the fact its armature connects at the connector side of the winding of relay 123. Therefore, if no response is obtained from the passing party when recalled, the connector element connected with the passing line will be restored at the termination of the predetermined said period. By attaching the armature 268 to the other terminal of the upper winding of relay 123, in lieu of where shown, so the relay 123 will operate with each signal application, the element connected with the passing line will not become restored until the arranged for number of signal applications, referred to hereinbefore, have been applied to re-call the passing party, whereupon the concerned connector element will be restored, relays 50 and 63, being maintained until the calling party at substation S replaces his receiver.

It will now be assumed that at the time the call was passed to the line leading to substation SJ20, a response was obtained therefrom. Upon the party thereat removing the receiver from the switch-hook, the relay 242 will be operatively energized over the conductive path established thereby, whereupon its outer winding will be locked through its armature 325, off-normal spring 326, conductor 143 to grounded spring 144. A circuit can now be traced from ground received through armature 325, lower winding of relay 269, armature 251, armature 250 and over the traced path including the receiver at substation SJ20 and over the traced path therefrom to armature 243, armature 241, upper winding of relay 269, conductor 327, lower winding of retardation coil 191 to grounded battery, the relay 269 actuating. Attention

is called here to the fact, that while in the element M10, the battery winding of relay 188 is related to conductor 51, the battery winding of the corresponding relay 269 in the auxiliary element N11 is related to conductor 61, and that the ground winding of relay 188 is related to conductor 62, the ground winding of relay 269 in the auxiliary element N11 is related to conductor 51. In view of the inclusion of the windings of the retardation coil 191, it insures there will be no unbalanced condition presented to the talking conductors of the trunk.

Assuming that after the party at substation S20 passed the call to the line leading to substation SJ20 and thereafter replaced his receiver on the switch-hook, the party at substation SJ20 responded promptly, or at least before the predetermined number of signals had been sent to re-call the transferring party. Upon the said response at substation SJ20, whereupon relays 242 and 269 actuate, a local circuit is established from the winding of slow-releasing relay 329 to the grounded lower armature of relay 269, relay 329 actuating. A circuit can now be traced from attracted armature 145 in the main element M10, conductor 253, armatures 193 and 330, conductor 331, armature 332, conductor 333, springs of off-normal set ON10 to the release magnet Re10, operative to restore the shaft of the main element M10 to normal position.

Assume that the passing party did not replace the receiver on the switch-hook following the completion of the passing operation and was therefore, holding the connection when the party at substation SJ20 responds. Under this condition the calling party and the first and second called parties are in talking relation. The last called party can disconnect the first called party by sending digit "1" from his calling device thereby causing relay 269 to deactuate and reactuate one time responsive thereto, and apply a ground impulse from its lower armature and armature 334 to actuate relay 308, and upon the closure of the upper armature of relay 269 to apply its ground through armature 335, conductor 336, armature 337, springs of the off-normal set ON10 to the release magnet Re10, operative to restore the shaft of element M10 to normal, thus disconnecting the first called party. Under the last above stated condition wherein the three parties were in talking relation, the first called party could have disconnected the second called party by sending digit "1" from the calling device at substation S20 effective to causing relay 188 to deactuate and reactuate one time causing relay 147 to actuate in the manner as hereinbefore described with relation to relays 269, 229 and 308, the upper armature of relay 188 applying its ground through armature 310, conductor 311, armature 273, off-normal springs, to the

release magnet Re11, operative to restore the shaft of element N11 to normal position, thus disconnecting the second called party.

Assume that after the first called party was thus directly disconnected by the second called party, and that the calling party at substation S and the second called party at substation SJ20 are in talking relation and it now becomes desirable to pass the connection to substation S17. The party at substation SJ20 will operate the calling device thereat in accordance with digits "1-1" corresponding to the local telephone number "11", whereupon relay 269 will deactuate and reactuate two times responsive thereto, with the usual numerical order pause intervening between the two openings. Upon the first deactuation of relay 269, its lower armature will apply ground through armature 334, conductor 339, armature 72, off-normal spring 201, armature 341, winding of vertical magnet V10, winding of relay 99 to grounded battery, the vertical magnet operating to step the wipers of element M10 into alignment with the first level of bank contacts, bearing in mind that off-normal spring 342 will displace spring 201 incidental to the first off-normal movement of the shaft. Relay 99 will deactuate following the said impulse so that when the second impulse is applied by relay 269 through armature 72, spring 342, armature 73, armature 74, winding of relay 75, armature 76 to the rotary magnet R10, the wipers 77 to 80 will be driven one rotary step into engagement with bank contacts 343, 107, 344 and 345, respectively, corresponding to the line leading to substation S17.

Assuming that the last called line leading to substation S17 is idle, and that therefore, bank contact 107 constitutes battery potential, the main element M10 will seize, in the manner as before described, with relation to the calling of substation S20. However, in the present instance, the said latter element primarily operated its shaft vertically and then horizontally, under directive control of the party at substation SP20 while in its initial operation it automatically functioned on its normal level only, consequent to it being seized by the connector J6. Further, the substation S20 was signaled through the agency of source G9, but in the present instance the said latter source has been displaced by the source RG9, the signaling circuit being traced from the latter said source, upper armature of relay 266, conductor 199, armature 120, conductor 122, upper winding of relay 123, conductor 124, armature 126, armature 129, wiper 79, bank contact 344, conductors 131, 132, 133, bell of substation set S17, conductors 134, 135, 136, bank contact 345, wiper 80, armatures 138 and 139, inner winding of relay 127 to grounded battery, the bell at substation S17 vibrating consistent

with the type of ringing current emanating from the source RG9, and thus incidentally indicates to the party noting the signal that the call is a passed one, and furthermore, is related to a trunk connection. Upon the 5 party at substation S17 responding, the relay 127 will operate, followed by relays 188 and 192 in sequence, whereupon the calling party at substation S, the second called party at substation SJ20, and the third called party at substation S17 are in talking relation.

Assuming that the party at substation S17 now desires to disconnect the line leading to substation SJ20. He will operate the calling 10 device at his substation in accordance with digit "1", whereupon relay 188 will deactuate and reactuate one time responsive thereto, and establish a circuit from upper grounded armature of the latter said relay, armature 15 310, conductor 311, armature 316 to the release magnet Re11, operative to restore the shaft of the auxiliary element N11 to normal position. The auxiliary element N11 is now in condition to be re-operated under 20 directive control of the party at substation S17 in the manner as hereinbefore described.

Going back to the condition of the circuits at the time that bank contacts 343, 107, 344, and 345 were engaged by wipers 77 to 80, respectively, it will for the present be assumed that the line leading to substation S17 is busy and that therefore, bank contact 107 constituted ground potential. Bank contact 343 is disassociated and therefore, there 25 is no means for automatically operating the rotary magnet R10 to advance the wipers off from the latter said set of bank contacts. The upper armature of relay 75 being attracted when wiper 78 receives ground from bank contact 107, relay 91 will actuate and 30 prepare a locking circuit for itself through spring 93 to the said grounded bank contact to be effective upon the retraction of upper armature of relay 75, the said locking path 35 being disconnected from the conductor leading to wiper 78 and applied to the conductor leading to the grounded spring 94 upon the retraction of the upper armature of relay 99. Tone will be applied, due to armature 186 40 being attracted and the lower armature of relay 99 retracted in the manner as hereinbefore described, audible to the calling party at substation S and the passing party at substation SJ20. The party at substation SJ20 45 may restore the shaft of the element M10 by sending one impulse in accordance with digit "1", whereupon relay 269 will deactuate and reactuate one time responsive thereto and 50 establish a circuit from the upper grounded armature of the said relay, armature 335, conductor 336, armature 345, lower armature of relay 75, off-normal springs, to the release magnet Re10. The element M10 can now be 55 directly operated, in the manner as before

described, to set its wipers upon the bank contacts of any desired accessible line.

Assume that after the party at substation SJ20 passed the call to the line leading to substation S17, he replaced his receiver before a response was obtained. Upon the first signal being transmitted to the line from ringing current source RG9 over a circuit which may be traced from the said source, upper armature of relay 266, conductor 199, 70 armature 120, conductor 122, upper winding of relay 123, conductor 124, armature 126, armature 129, wiper 79, over the line including the bell at substation S17, wiper 80, armatures 138 and 139, inner winding of relay 127 to grounded battery, the bell operating but the relay 127 not operating. The relay 123 will actuate corresponding to its periodic energization and apply ground from off-normal spring 231 in element N11, upper armature of relay 242, conductor 346, armature 347 75 of relay 123, lower armature of relay 329, conductor 259 to the winding of motor magnet M9, the latter operating to advance the wipers 260 and 261 into engagement with the second set of bank contacts cooperative therewith. The latter motor magnet will be operated with each application of ringing current to the line leading to substation S17, and when wiper 260 engages bank contact 262, the off-normal spring sets RR9, RC9 and R9 will function as hereinbefore described, opening the locking ground from conductor 143, causing relay 242 to deactuate and to apply the ground from the lower armature of relay 123 through off-normal spring 347 to the winding of relay 238, the latter relay actuating and locking through its armature 348 to conductor 267 now grounded by way of the lower armature of relay 127 and the upper armature of relay 242 to spring 231. Ringing source BG9 is now applied through armature 349, conductor 240, armature 241 and over the line leading to substation SJ20, and back through the inner winding of relay 242 to 80 grounded battery, operative to the signal bell at substation SJ20, with due regard to the peculiar characteristics of the ringing current and its peculiar effect upon the signal bell for the purpose prompting the condition to the party responding. Upon the party at substation SJ20 responding to the re-call, the calling party at substation S and the former said party are in talking relation. Incidental to the relay 238 actuating whereby the party at substation SJ20 is re-called, ground on the lower armature of relay 238 is applied over conductors 350, 333, off-normal springs, to release magnet Re10, operative to 85 restore the shaft of element M10 to normal position, in readiness to be again directly operated from substation SJ20. The relay 238 will have its locking circuit opened consequent to relay 242 subsequently actuating, 90 upon the party at substation SJ20 respond- 95

ing, or upon both elements M10 and N11 restoring their shafts to normal position, the latter removing the ground from conductor 202' to which the upper armature of relay 242 is attached.

Assume that at the time the party at substation SJ20 passed the call to the line leading to substation S17 and the latter line was found busy causing relay 91 to actuate and apply the busy tone, the party at substation SJ20 replaced his receiver without taking due notice of the busy tone. Under this condition, a circuit is established from armatures 312', 313, lower armature of relay 192, conductor 314, lower armature of relay 91, conductor 351, lower winding of relay 123, to the first four contacts engageable to wiper 261. This will cause the motor magnet M9 to function as hereinbefore described under a generally like condition. The locking circuit for relay 242 is opened at off-normal spring 144, the release magnet Re10 will be operated, and the bell at substation SJ20 will vibrate from the current derived from the ringing source BG9, in the manner described wherein the predetermined number of signals was applied to the bell of substation S17 through element M10, without obtaining a response thereat. However, in this instance, the re-calling will occur forthwith upon the party at substation SJ20 replacing his receiver on the switch-hook.

A function of the passing call connector comprised of elements M10 and N11 is that, should the passing party make an error in sending the digits of the desired line, the passed portion of the call, which may be in process, can be effaced by the passing party replacing his receiver on the switch-hook for a prolonged period. For example, if when the party at substation S20 was passing the call to substation SJ20, and the first digit only had been sent, or in any event, if the element N11 had not yet seized, relay 188 will deactivate resultant thereto, causing relay 147 to actuate, followed by the deactivation of relay 192 and the deactivation of the said relay 147 in sequence, establishing a circuit from ground, armature 145, conductor 253, armatures 193, 330, conductor 352, upper armature of relay 228, off-normal springs, to the release magnet Re11. And, if the stated condition ensued in connection with the party at substation SJ20, when passing the connection to substation S17, for example, upon the party at substation SJ20 replacing his receiver, relay 269 will deactivate, causing relay 308 to actuate, followed by the deactivation of relay 329 and the deactivation of the said relay 308, in sequence, establishing a circuit from spring 231, conductor 352', upper armature of relay 242, conductor 346, armatures 353 and 354, conductor 355, armature 356, off-normal springs, to the release magnet Re10.

A function of the passing call connector, comprised of elements M10 and N11, is that should the call be passed and the called line seized, the passing element can have its shaft restored by the passing party sending digit "1," in lieu of replacing his receiver, as when an error has been made and recognized before the passing element seizes. The operation will concern the same circuit paths and functioning as when digit "1" was assumed sent to disconnect a called party to the connection wherein the calling, the first called and the second called parties are in talking relation.

Another function of the passing call connector is that if the shaft of one element thereof is at normal and a line is connected through the other element, if the party of the last said line replaces his receiver, thus causing the back-bridge relay of the concerned element to deactivate, an impulse will be applied operative to the vertical magnet of the companion element, whereby the shaft of the said companion element will be caused to step off-normal. The latter said shaft becomes restored, forthwith, by functioning (in the manner as described), as if an error in passing had been made, and the passing party replaced his receiver for a prolonged period to efface the set-up condition in the passing element.

The relay 50 and its dependent relay 63 is at all times under control of the calling party at substation S, and therefore, the elements M10 and N11 can be forthwith restored to normal by the said calling party replacing his receiver, due to the fact that the conductors leading through the upper pair of off-normal springs in each of the said elements include a path from a resting contact cooperative with the upper grounded armature of relay 63 and the corresponding release magnet.

It has been set forth how a line becomes guarded against intrusion upon the initiation of a call from a corresponding group substation; wherein its line switch extends the connection to a local connector, as detailed with reference to substation S20 and the line switch P13, which latter line switch is generally similar to line switch R14. By referring to line switch Q13, related to the line leading to the substation SJ20, it will be noted that a difference of the wiring and adjustments is made effecting line relay 224 and the switching relay 223. Retaining springs 358 and 359 are introduced to restrain their cooperating armatures to such a degree that when the line relay 224 is energized over a path including the resistance r20, the tractive effort of the said relay 224 will not be sufficient to overcome the said retaining springs and engage their cooperative working contacts. However, the upper armature thereof, will disengage from its rest-

ing contact under the latter condition, and the two lower armatures will operate in the normal manner, as when the relay is fully energized. It will thus appear that if the attendant at the subscriber's premises inserts plug CP21 of Fig. 21, into springjack J20, the anvils of the springjack will be disengaged, opening the line from the substation SJ20 and at the same time permits the attendant to manipulate the ringing key RC21 to signal the substation from source G21 and manipulate the listening key LC21 to place the attendant's circuit S21 in talking relation with the said called station upon a response being obtained therefrom, the indicator B20 operating incidental to the response. The plug AP21 may be employed in extending the connection to another line. The auxiliary contact on the springjack J20 will include the resistance r_{20} into an energizing path including the relay 224, and having in mind the adjustment of the upper armatures thereof, it will be manifest that armature 360 applies its ground over conductor 225 to conductor 226 and its attachments to guard the said line against intrusion. And since no circuit is closed which will energize the motor magnet M13 or the switching relay 223, the line switch will neither hunt nor seize.

To a call initiated at substation SJ20, wherein the relay 224 is normally energized, assuming that the wipers of the line switch are resting upon the bank contacts of an idle trunk, and therefore, bank contact 362 does not constitute ground, a circuit may be traced from grounded armature 360, upper armature of relay 224, and its working contact, winding of relay 223 to the winding of the motor magnet M'13, the relay 223 actuating. When ground is projected back over conductor 290 from the seized local connector U18, in the manner as hereinbefore described, with relation to line switch P13, this ground is communicated over wiper 363, armature 364, lower armature of relay 223, winding of relay 223 to the winding of motor magnet M'13, the latter circuit being established before the armature 360 retracts due to the disassociation of relay 224. Should bank contact 362 constitute ground potential, due to the corresponding local connector U18 being busy, this ground would be communicated over wiper 363, armatures 364, 365, to the winding of motor magnet M'13, energizing the latter magnet operatively by way of advancing the wipers upon its interrupter opening the said energizing circuit. As long as wiper 363 receives ground, the said motor magnet will continue to operatively energize upon its armature retracting by way of advancing the wipers successive steps hunting for an idle local connector. When the motor magnet M'13 fails to receive ground through the wiper 363, it will receive obstructed ground

from armature 360, upper armature of relay 224, and winding of relay 223, the latter relay only, operatively energizing to effect the seizure of the line switch. Whereupon, ground will be projected back from the seized local connector, applied through wiper 363 to maintain it seized.

Assume that the local connector U18 is idle when the call is initiated from the calling substation SJ20 and that the line switch Q13 seizes the trunk leading to the said local connector, wherein relays 297 and 306 are caused to actuate as hereinbefore described. In this connection attention is directed to the fact that the attracted upper armature of relay 223 of line switch Q13 applies ground through wiper 367, bank contact 368 to conductor 369.

Before proceeding further with the description, it will be understood that Fig. 15, which attaches to the left of Fig. 18 and above Fig. 13, connects the local stations into corresponding bank levels of connector U18 as they appear with relation to the elements M10 and N11, that is, they appear in the first and second levels in each instance. It is not necessary that there should be this correspondence as will appear presently when the alternative Fig. 22 is substituted for Fig. 15. The connector U18 has three (the lower three) vertical positions or levels shown, though in view of the general remarks preceding, it is to be understood that this number may be increased to any plurality. For the purpose of the description about to be entered into, conductor 370 which attaches to conductor 369, is to be assumed multiplied to each of the six bank contacts involved in the two lower levels engageable to wiper 372 of connector U18 as detailed in Fig. 38. The object of wiper 372 is to bar the local connector against completing a connection to a local line, unless the local calling line in control of the connector belongs to the same subscriber group as the called one. The subscriber group concerned, occupying the first and second levels of the local connector, the line switches thereof when seizing the connector U18, will ground the auxiliary conductor 369 individual thereto and in turn ground the bank contacts of the first and second levels, which are engageable to the wiper 372. That is to say, the conductor 369 is multiplied to corresponding bank contacts in each line switch of the concerned group only, the plan being followed in each set of bank contacts of the line switches of the group with respect to the corresponding local connector. By way of further explanation, should the concerned subscriber group appear in the eleventh and twelfth levels in lieu of the first and second, the conductor 370 would attach to the bank contacts in the corresponding levels engageable to the wiper 372. In the latter instance, the con-

ductor attached to conductor 370 leading to segment normally engaged by wiper 373 would attach to the eleventh vertical segment in lieu of the first, and be multiplied to the segment engageable by wiper 374 at the twenty-first level, if the connector were provided with that many levels; otherwise, it would not be attached to any segment other than the one referred to at the eleventh level.

10 The wipers 373, 374 and 375 engage segments corresponding to the levels when the shaft of the connector is at normal and while it is stepping vertically but disengages upon the shaft rotating-in. The object of the 15 said wipers 373 to 375 will appear presently.

It is not essential that the barring feature referred to shall be employed with reference to the group occupying the first level or levels, but it will appear that if a group 20 occupies a higher level, the fifth for example, and a calling party in the group occupying the first two levels referred to, sends the digit "5" or any digit corresponding to the levels used by any other, group sub-25 scriber than the one containing the calling substation, connection could be obtained and the call completed. The barring feature contemplates that the ground for maintaining the relay 306 actuated, so that ground will 30 in turn be applied back to maintain the line switch seized, shall be received primarily from the line switch having seized the local connector. This ground is applied from the upper armature of the switching relay (as 35 relay 223), of the line switches. It is, of course, manifest that the ground on resting contact 304 in connector U18 could be applied directly to the lower armature of relay 297, and in that event the barring wiper 40 372 and its cooperating bank contacts will be dispensed with, though the conductor 370 would have an operative function still, as will appear.

Forthwith, upon the connector U18 becoming seized by the line switch Q13, as set forth, wherein relay 306 actuates, a path can be traced from conductors 370, 376, wiper 373, make-before-break spring 378, armature 379 to the winding of slow-releasing relay 380, the latter relay actuating. The impulse source D18 applied through the springs of off-normal set ON'18 is thus disconnected at the upper armature of relay 380. The said off-normal set ON'18 is adjusted to be operated consequent to the shaft stepping to the highest level employed. It will thus appear that the impulse source D18 will have no operative function in the present instance, since it is disconnected forthwith upon the connector being seized. When relay 380 actuates, its lower, grounded armature is applied to its make-before-break spring 378, armature 379, to the winding of said relay 380, so that relay 380 is no longer dependent upon receiving ground through the wiper 373 from

the line switch Q13. At this juncture a path can be traced from grounded tone source T'18, off-normal spring set RO18 (which latter set is adjusted to operate on the first rotary off-normal movement of the shaft), 70 lower armature of relay 380, line conductor 383, condenser 384, conductor 302, and over the traced path including the receiver of substation SJ20, conductor 299, make-before-break spring 298, upper winding of relay 297 75 to grounded battery. The tone will indicate to the calling party that the connector U18 is in readiness to receive directive impulses from the calling device at substation SJ20. In this connection it will be stated that the 80 lower winding on slow-releasing relay 382 is of such value and so disposed, that it will not in itself operatively energize its said relay primarily, but if the relay has been operatively energized from the upper winding thereof, it will be maintained actuated if the lower winding is energized regardless of the upper winding being or not being energized.

Anticipating the description of the functions of connector U18, it will be stated that 90 if the levels of bank contacts engageable by wipers 386 to 389 and 372 are assumed to be the third, fourth and fifth, rather than the first, second and third, and that therefore, the concerned levels are the third and fourth, 95 conductor 370 in addition to being attached to the stated bank contacts engageable by wiper 372, attaches to segment 390 in lieu of the segment normally engaged by wiper 373, the traced energizing circuit for relay 380 which ensued consequent to the seizure of the connector will not be closed due to the fact that wiper 373 will not receive ground from conductor 370. Under this condition, the impulse source D18 will be applied through the upper armatures of relays 380, 306, spring 391 of off-normal set ON18 (which latter set operates on the first off-normal movement of the shaft), spring 392, 100 winding of vertical magnet V18, upper winding of relay 382 to grounded battery, the latter relay actuates and sustains over the impulse lapses and the vertical magnet operates responsive to the impulses.

Upon the shaft being stepped to the second level (being one level below the lowest level reserved to the group containing the calling line), wherein wiper 373 engages the segment 390, receiving ground from conductor 370, relay 380 will be caused to actuate 110 and lock in the manner as before set forth, but due to the lower winding of relay 382 receiving ground from segment 390, the latter relay does not deactivate. The calling party now perceives the tone from tone source T'18 over the path previously traced, and may proceed with the sending of the first digit corresponding with the local (private) telephone number of the wanted line. Upon sending the first digit series, the relay 297 115 120 125 130

will vibrate responsive thereto and apply the ground received through spring 378 and its engaged armature, armatures 379, 393, springs 391, 394, armature 395, winding of vertical magnet, upper winding of relay 382 to grounded battery, the vertical magnet thus directively stepping the shaft one level so that the wipers thereof now align with the level containing the wanted line. Incidental to the wiper 378 disengaging the segment 390 in the upward movement of the shaft under the directive control of the calling party, the lower winding of relay 382 is unenergized, so that at the termination of the first digit series 15 directly sent, this relay will deactivate consistent with its releasing period, preparing a circuit to the rotary magnet, so that when the calling party sends the second digit series and the relay 297 vibrates responsive thereto, the ground impulses thereby being applied to springs 391, 394, armatures 395, 396, winding of slow-releasing relay 397, armature 398 to the winding of the rotary magnet R18, is operative to set the wipers upon the called line. 20

25 The detailed operation of the connector U18 will be discussed with relation to the disposition of connections to the bank contacts as first referred to. However, it will be noted in view of the foregoing anticipated 30 statements, that the connector U18 automatically functions to set its wipers one level below the lowest level employed by the group containing the calling substation, having in mind that the bank contacts engageable by 35 wiper 372 are free of ground at all levels excepting the levels containing the concerned group. It will be manifest that if the first digit sent is not pertinent to the group containing the calling substation, upon the second digit being sent wherein the wiper 372 40 will not find ground, the line switch of the calling line will be unseized and the connector will restore in the manner as will be described presently.

45 Going back to the condition wherein the connector U18 was first seized by the line switch Q13, it will be assumed that the substation S17 is wanted, the local telephone number of which is "11". Upon sending the first digit "1" from the calling substation SJ20, relay 297 will deactivate and reactivate one time, applying a ground impulse from the engaged armature, spring 378, armatures 379, 393, springs 391, 392, winding of vertical magnet, upper winding of relay 382 to grounded battery, the relay 382 actuating and the vertical magnet operating to step the wipers into alignment with the first bank level, after which relay 382 deactivates consistent with the slow-release characteristic. 55 Upon sending the second digit "1", the relay 297 will operate as before and apply a ground impulse through armature 393, springs 391, 394, (in lieu of 392), armatures 395, 396, winding of slow releasing relay 397,

70 armature 398 to the rotary magnet, the rotary magnet operating to set the wipers 386 to 389 and 372 into engagement with bank contacts 401, 110, 402, 403, 404, respectively. Armature 405 on relay 397 serves to short-circuit the armature 396 and its resting contact, if the busy relay 406 operates due to wiper 387 encountering a grounded contact, (should the call have been to an inside bank contact), if the wiper 387 rotates over a contact corresponding to a busy line. 75

Assume the line leading to substation S17 to be busy and therefore, the bank contact 110 constitutes ground, in lieu of battery potential. A circuit can be traced from the ground on bank contact 110, wiper 387, make-before-break spring 411 to the winding of relay 406. Upon the deactuation of relays 397 following the impulse to the rotary magnet, the locking circuit prepared by the upper armature of relay 406 is completed from make-before-break spring 411, upper armature of relay 406, make-before-break spring 412, conductor 413, off-normal spring 414 to grounded working contact 291, so the relay 406 will be maintained actuated, irrespective of the fact that ground may become removed from bank contact 110. Busy tone from source T18 will now be applied through the lower armatures of relays 406, 382, conductor 383 and over the traced path through the receiver at substation SJ20, upper winding of reversing relay 416 in connector U18 to grounded battery, audible to the calling party. 95

100 The connector U18 is adapted to function in group selection, where it is desired to have predetermined alternative substation lines automatically connected with in the event the line called is found busy. The connector under the latter said condition testing over the one or more lines used alternatively. Assume that the line, not shown connected, having telephone number "12", and therefore, occupying the successive bank position to the one called, is an alternative or an auxiliary line to the line leading to substation S17. Under this condition, bank contacts 401 and 110 will be electrically tied, which condition will cause bank contact 401 to constitute ground (along with bank contact 110), at the time of testing. This ground will be communicated over wiper 386, lower armature of relay 397, armature 417, interrupter contacts of the rotary magnet, armature 418, winding of relay 419, upper winding of relay 382 to grounded battery, the latter two relays actuating. A locking circuit for the latter said relays, is closed from lower armature of relay 397, the upper armature of relay 419, conductor 413, spring 414 to grounded working contact 291, the relays 382 and 419 being thus now operatively energized, irrespective of receiving ground through wiper 386. Upon the actuation of relay 419, a circuit can be 115 120 125 130

traced from the ground on conductor 413, lower armature of relay 419, armature 398 to the winding of rotary magnet R18, the rotary magnet operating to advance the wipers into engagement with the next successive set of bank contacts, and incidentally, open its interrupter contacts to deenergize relays 382 and 419, causing them to deactivate. Assuming that bank contact 420, now engaged by wiper 387 constitutes ground due to the alternative line being busy, the connector will function as it did when its wiper 387 engaged bank contact 110, in the first description. And should we now assume, that bank contact 420 is tied to bank contact 419, and therefore, the latter said bank contact constitutes ground, the wipers will be caused to automatically rotate-off in the manner as when bank contact 401 was assumed to constitute ground. The relay 382 in this instance does not deactivate until the expiration of its slow-releasing period after wiper 386 fails to receive ground from an engaged bank contact.

Going back to the condition of wiper 387 engaging bank contact 110, and assuming that the line leading to substation S17 is idle and that therefore, the bank contact 110 constitutes battery potential received through motor magnet M14, winding of relay 112, conductors 111, 106, 109, bank contact 110, wiper 387, upper armature of relay 397, outer winding of switching relay 424, upper armature of relay 406, spring 412 to grounded conductor 413, the latter path being completed upon relays 397 and 382 deactuating. Relay 424, in connector U18, is thus caused to actuate, whereupon a locking circuit can be traced from its inner winding, armature 425 to grounded conductor 413, so that the relay 424 is now maintained dependent upon the ground received through working contact 291. That is, if relay 306 deactuates, relay 424 will deactivate resultant thereto. The rotary magnet is disabled by reason of the attraction of armature 398, and armature 426 applies its ground to wiper 387, engaged bank contact 110, conductors 109, 106, 111, winding of relay 112 to the motor magnet M14, the relay 112 attracting its inside armatures only, out of engagement with their resting contacts, but not into engagement with their working contacts, so that the line relay 117, and the ground on the resting contact 118 of the lower inside armature, are disassociated in the manner generally well known, having in mind that the line switch R14 is similar to line switch A, with the exception of certain circuit modifications, as will appear from the drawings and which will become further evident from the descriptions, presently. The line leading to substation S17 is now guarded against intrusion by normally accessible switches, and the line leading thereto is also clear of effective attachments. A circuit can now be traced from grounded interrupted signaling current source G18, upper armature of ring-cut-off relay 428, upper armature of relay 424, wiper 388, bank contact 402, conductors 429, 131, 132, 133, signal bell of substation S17, conductors 134, 135, 136, 432, bank contact 403, wiper 389, armature 433, lower armature of relay 428, inside winding of the latter relay to grounded battery, the signal bell at substation S17 operating, but the current traced through the latter said relay not being operatively effective to it, due to the condenser in the bell path. The party at substation S17 will recognize from the operation of the bell, due to the peculiar frequency of the source G18, that the call is one initiated from a local station and extended through a local connector. Upon the called party responding, the traced path including the inner winding of relay 428 will become conductive to direct current, whereupon the latter said relay will actuate to disconnect the signaling current source and to lock its outer winding to grounded conductor 413 and to also, apply this ground to the upper winding terminal of the lower winding of relay 416, whereupon, an energizing circuit involving both windings of the latter said relay will include the receiver at substation S17, the relay 416 actuating to reciprocate the relationship of the windings of relay 297 with respect to conductors 299 and 302, which include the receiver of the calling substation SJ20. Thus reversing the direction of current, upon a response, may be employed to operate supervisory signals in the well known manner. The calling party at substation SJ20, and the called party at substation S17 are now in talking relation. The established connection can now be destroyed under control of the calling party by replacing his receiver, opening the energizing circuit of relay 297, whereupon the dependent relays 306 and 380 will deactivate, opening the locking ground for relays 428 and 424 at working contact 291. A circuit can now be traced from the release magnet Re18, upper springs of off-normal set OÑ18, lower armatures of relays 306, 297, to grounded resting contact 304, operative to restore the connector to normal, ground being incidentally removed from conductor 292 to unseize the line switch P13.

It will be assumed that the calling party at substation SJ20 desires to secure a connection to substation S7, the telephone number of which is "1221", being that of a general individual subscriber in the main exchange, in lieu of the local substation S17. Upon perceiving the tone emanating from source T'18, the digit "0" will be sent, causing the relay 297 to operate in the manner as before described, but in this instance, deactuating and reactuating ten times responsive thereto, cor-

respondingly stepping the shaft ten vertical steps so that wipers 373 to 375 will now rest upon segments 435 to 437 (in Fig. 38), respectively. It will be noted that the segment 435 engaged by wiper 373 is free and that it therefore, will not energize the lower winding of relay 382, so that the latter said relay will deactivate consistent with its release period following the sending the last one of the ten impulses constituting the digit "0". Segment 436 is attached to conductor 438 and the latter is attached to conductor 376, and therefore, receives ground applied by the upper armature of relay 223, the conductor 438 therefore being individual to the group containing substation SJ20, the object of which will appear presently.

Having in mind that wipers 373 to 375 are now in engagement with segments 435 to 437, respectively, upon the retraction of relay 382 following the last impulse of the series of ten impulses referred to, a circuit can be traced from the ground on segment 436, wiper 374, armature 439, conductor 440, conductor 441, bank contact 442, wiper 443, make-before-break spring of slow-releasing relay 444 to the winding of said relay, causing it to actuate, its armature 445 applying ground to bar 446 engaged by wiper 447. The make-before-break spring cooperative with the upper armature of relay 444 is adjusted to retain its engagement with its resting contact until armature 448 of the latter said relay has attracted into engagement with its make contact to lock the latter said relay to the bar 446, after which the latter said resting contact becomes disengaged. A circuit can now be traced from grounded wiper 447, through the two lower armatures of relay 444, conductor 449 to the winding of motor magnet M'13, the latter operating. In this connection it will be noted that due to conductor 449 becoming grounded, relay 223 becomes deenergized and will therefore, de-actuate, there being ground on both its winding terminals. The relay 224 will therefore, be energized in a circuit path including the receiver of the calling substation SJ20 as when the call was initiated, but to no operative effect at this juncture, due to the lower armature of relay 444 being attracted. Upon the motor magnet M'13 interrupting its energizing circuit and the wipers thereof consequently advancing into engagement with the next successive set of bank contacts wherein the wiper 447 will still receive ground from bar 446, the motor magnet M'13 will again actuate by way of opening its energizing circuit to advance the wipers an additional step, upon it again opening its energizing circuit, this cycle of operations continuing as long as the wiper 447 receives ground from the bar 446, it being understood that the said bar embraces the contact sets which correspond to the local connectors, the number of

sets being in any required plurality, though only three sets are shown.

Upon the wiper 447 rotating-off the bar 446, the relay 444 deactuates resultant therefrom. The private wiper 363 is now capacitated to test out-going trunks, embraced by bar 450, the latter bar being now grounded, and in fact, is normally grounded at armature 445. The wiper 363 was disconnected at the lower armatures of relays 444 and 224 to prevent it falsely grounding passed over contacts while rotating under the grounded condition of bar 446. It will be noted that the line switch Q13 became guarded against seizure forthwith, upon the relay 223 deactivating because of armature 360 applying ground to conductor 225, immediately thereafter. Should the bank contact 451 constitute ground potential, due to the corresponding trunk being busy, this ground will be communicated over wiper 363, armature 364, armature 365, lower armature of relay 444 to the motor magnet M'13, causing it to function as when it was grounded from the bar 446, and the motor magnet will continue its cycles of operation as long as the wiper 363 receives ground, it being understood that there would be as many sets of bank contacts in the trunk group as there are trunks corresponding, and that the bar 450 embraces the said group, though only two sets are shown as thus embraced. Of course, it would be possible to have but one trunk, depending upon the subscriber's requirements.

Assuming that the bank contact 451 does not constitute ground potential, the last described energizing circuit operative to the motor magnet M'13 would not exist therefrom. The ground would also not exist on the lower winding terminal of relay 223, received coincident with the ground being applied to the motor magnet M'13. A circuit can now be traced from the motor magnet M'13, conductor 449, winding of relay 223, upper armature of relay 224, conductor 225 to grounded armature 360, the relay 223 actuating to effect the seizure of the trunk by the line switch Q13, the motor magnet M'13 not being operatively energized. It will appear presently how a ground will be received back over wiper 363 and applied through the lower armature of relay 223 to conductor 225 to maintain the seizure after armature 360 retracts consistent with the release period of relay 224.

A circuit can now be traced from the winding of slow-releasing line relay 476 in line switch D3, upper armature of relay 47, conductor 477, conductor 56, make-before-break spring 478, winding of relay 479, conductor 480, conductor 481, bank contact 482 of line switch Q13, wiper 483, conductor 246, receiver of substation SJ20, conductor 247, wiper 484, bank contact 485, conductors 486, 487, make-before-break springs 488, 58, conduc-

tors 57, 488', armature 489 in line switch D3 to its resting grounded contact, the relay 476 actuating. At the same time that relay 476 actuates, the relay 479 (in Fig. 8) actuates, whereupon the lower armature of relay 479 applies ground through armature 490 to the winding of slow-releasing relay 491, the latter relay actuating, establishing a circuit from the upper winding of relay 50 in element M10, conductor 51, springs 52, 53, armature 492, spring 60, conductors 61, 62, to the lower winding of relay 50, the latter relay actuating, followed by its dependent relay 63. The upper armature of the latter relay 15 applies its ground to conductor 64, however, the conductor 64 is also grounded from armature 493 in line switch D3, conductor 48, consequent to the actuation of relay 476. The ground on conductor 64 is communicated 20 through make-before-break spring 494, conductors 495, 496, bank contact 451 in the line switch Q13, wiper 363, armature 364 to conductor 225, to maintain the line switch Q13 seized, as referred to. Incidental to the actuation of relays 50 and 63, a circuit can be 25 traced from grounded resting contact, armature 67, in Fig. 8, conductor 68, armatures 69, 70, 72, 73, 74, winding of relay 75, armature 76 to the rotary magnet R10, operative to advance the wipers 77 to 80 into engagement 30 with the first set of bank contacts 81 to 84, respectively. In the previous descriptions, bank contacts 81 and 82 were normally artificially busy-grounded over conductor 86, 35 armature 87, armature 88 to its grounded resting contact, but in the present instance the relay 491 is actuated, and therefore, armature 88 receives battery potential which is applied to contacts 81 and 82. Under this condition, 40 the element M10 will seize in the manner as hereinbefore described and it will not therefore, rotate beyond and test local lines, as hereinbefore described. Signaling current will be impressed over wipers 79 and 80, in 45 the manner as hereinbefore described, the path being continued over conductors 497 and 498 leading to armatures 499 and 500 in Fig. 8, respectively, the latter armatures being unengaged. With further reference to relay 50, 50 479 (in Fig. 8), its armature 501, applies its ground operative to the slow-releasing relay 502.

It will be borne in mind, that at this juncture element M10 has seized the first set 55 of bank contacts on its normal level and that it is applying signaling current to the free armatures 499 and 500, of Fig. 8, and also, that relays 50, 63 and 113 of element M10 are actuated, and also, that relays 491, 479 60 and 502 of Fig. 8 are actuated, and also, that a short-circuit path from spring 52 to spring 60 is closed at the lower armature of relay 491 in Fig. 8 maintaining relay 50 in element M10 energized, and also, that the 65 relay 476 in line switch D3 is actuated. It

will now be assumed that the wipers 503 to 507 of the line switch D3 are resting upon a set of bank contacts corresponding to an idle first selector B in Fig. 1, it being noted that line switch A and line switch D have 70 common access with other line switches to the selector B over corresponding bank contacts. The line switch D3 is similar to the line switch Q13, and therefore, is arranged to alternatively hunt for trunks in a second group responsive to a directive operation on the part of the calling party. With the last foregoing statements in mind, it will not be necessary to trace the detailed operative functions of the line switch D3, and therefore, suffice it to say, that relay 47 therein actuates and therefore, automatically extends conductors 477, 488' and 48 over conductors 508, 509 and 510, and to 511, 512 and 513, respectively. The traced path, including the conductors 511 and 512, now include the upper and lower windings of line relay 514 in selector B, and in view of the well known functioning of the latter selector, slow-releasing relay 515 will actuate to apply ground from its upper armature to conductor 513, effective to maintain ground to conductor 48, which at this time is attached to conductor 64, as previously traced, so that no lapse of ground occurs to conductor 48 when armature 493 in line switch D3 retracts. Bank contact 18 accessible to line switch A will constitute ground to guard the trunk leading to selector B against intrusion. Bank contact 32 accessible to connector J6 constitutes ground, thus guarding the subscriber's trunk against intrusion. 95

The calling party at substation SJ20, after sending the digit "0" to obtain connection with the trunk, may forthwith annex the first digit "1" through the agency of his calling device to set the wipers of selector B into alignment with the first bank level, and into engagement with bank contacts 17, 9 and 12, the selector B functioning as before referred to, whereupon the second digit "2" may be sent and similarly set the wipers of selector C2 into engagement with bank contacts 516 to 518 of the second bank level thereof, the selector C2 functioning in the manner as before referred to. The conductors 511 to 513 inclusive, have now been continued to conductors 519 to 521, and to conductors 522 to 524, respectively, so that the windings of line relay 525 in connector L7, are now energized in a series path including the winding of relay 479 of Fig. 8, and the receiver of substation SJ20. The general functioning of connector L7 being well known, it will be manifest that slow-releasing relay 526 thereof will actuate and its upper armature will apply its ground to conductor 522, the latter conductor having been continued from conductor 64, so that conductor 64 is at present grounded 125 130

from the upper armature of relay 63 in element M10 and at the upper armature of relay 526 of connector L7, and that a tap from this conductor by way of spring 494 in Fig. 8, conductors 495, 496, bank contact 451, serves to apply ground to maintain the line switch Q13 seized. It will thus appear that the relay 525 in connector L7 and the relay 50 in element M10 separately control the releasing of selectors B and C2. The latter said relays likewise also control the unseizing of the line switch Q13, but it will presently appear, that upon the actuation of relay C8 in Fig. 8, that this condition with reference to the maintaining of the seizure of line switch Q13 will be altered. Upon the calling party at substation SJ20 sending the last two digits "2—1", the connector L7 will function in the well known manner and seize and signal upon the line leading to substation S7, incidentally disassociating the normally operative attachments from the line conductors thereof, it being understood that the line switch K7 is similar to line switch A, though a portion of its circuits have been omitted. Before detailing the conditions which will ensue upon the party at substation S7 responding, we will return to the functioning of the apparatus in Fig. 8 which ensued, coincident with the described functioning of selectors B and C2, and connector L7.

In Fig. 8, the motor magnet M8 controls a set of wipers 530 to 533; normally resting on unconnected bank contacts 534 to 537, respectively. Each wiper has access to six bank contacts equally spaced radially. Wiper 530 resting on bank contact 534 is detailed schematically in Fig. 8A. The motor magnet M8 and its mechanically controlled mechanism is generally similar in its details to the motor magnet M9 and its mechanically controlled mechanism, which has been discussed hereinbefore.

Upon the calling party sending the digit "1" following the digit "0" as stated, the relay 479 will deactuate and reactuate one time responsive thereto, its armature 501 applying its ground through armature 540 to operatively energize relays 541 and 542.

The dash-dot relay 542 has the characteristic of actuating under the influence of the said brief period of energization and then remain in an actuated condition over lapses of somewhat longer duration than would ordinarily occur between the sending of the digits of the numerical order digit train constituting a called telephone number. So it will be understood that upon the relay 542, actuating incidental to the first digit "1" of the called number being sent from the substation SJ20, it will not deactuate until a predetermined time after the final impulse of the last digit of the called number has been sent and the signal bell at the called

substation S7 has started to operate under the influence of the current from the signaling current source G7, or the busy tone has been applied back from connector L7 should the line leading to substation S7 have been found busy. The slow-releasing relay 541 will sustain its armature over the current lapses caused by the attractions of armature 501, but will retract following the last closure of a digit series. The attracting of the armature of relay 541 causes the motor magnet M8 to operatively energize and maintain it so until it retracts. The wipers 530 to 533 will be caused to advance one step consequent to the deenergization of motor magnet M8. Incidental to the off-normal movement of the wipers 530 to 533, a cam on the shaft therewith operates the off-normal spring set ON8, which connects ground to the lower armature of relay 502 and the lower inside armature of relay 542. Under the stated condition the motor magnet M8 will only be energized one time (in correspondence with the first digit impulse) regardless of the number of open impulses constituted in a digit series, and that therefore, in sending the four digits constituting the telephone number of substation S7, the wipers 530 to 533 will have become engaged with and be resting upon the fifth set of bank contacts. Under this condition grounded tone source T8 will be applied through wiper 530, conductors 545, 480, over the path including the receiver of substation SJ20, returning over conductor 487 to ground through the lower winding of relay 525 in connector L7. The object of this tone will appear presently. Wipers 531 and 532 will now receive ground from the engaged bank contacts, operative to cause relays C8, 200 and 546 to actuate. Relay C8 will lock through its lower armature to conductor 86, and it can therefore, not unlock until release magnet Re10 actuates and restores the shaft of element M10, wherein the relay 113 unlocks. Relay 200 will lock through its make-before-break spring and cooperating armature 547 to conductor 202', and it can therefore, not unlock until the shafts of both elements M10 and N11 have been restored to normal position.

Relay 546 will lock over a circuit from grounded battery, lower armature of relay 200 in Fig. 8, winding of said relay 546, armature 547, line conductor 57, over the traced path through the lower winding of relay 525 in connector L7 to ground. Another circuit previously traced now exists from grounded battery, upper winding of relay 525 in connector L7, conductor 56, upper armature of relay 546 in Fig. 8, through retardation coil 548 to ground thereon. It thus appears that the ground and battery windings of relay 525 in connector L7 are now applied to the grounded battery at the lower armature of relay 200 in Fig. 8 and

the ground on the retardation coil 548 in Fig. 8, respectively, the relay 525 in connector L7 thus remaining actuated. Otherwise, the latter said connector would be caused 5 to restore by completing a circuit through springs of off-normal set ON7 to the release magnet Re7, in the well known manner, it being borne in mind that the party at substation S7 has not yet responded. In view 10 of relays 200 and C8 having actuated and having in mind that the relay 491 will deactivate following the attraction of armature 490 on relay C8, it will be manifest that the short-circuit path between springs 52 and 15 60, traced through the armature 492 of relay 491 will have been opened, and that a path now exists, in lieu of the short-circuit path, from spring 52, armature 549, upper armature of relay 546, retardation coil 548 to ground, and from spring 60, armature 59, lower armature of relay 546, retardation coil 551 to grounded battery. That is to say, the battery and ground windings of relay 50 in element M10 are now connected to ground, 20 and grounded battery, through retardation coils 548 and 551, respectively, the relay 50 being maintained actuated to prevent the hereinbefore traced circuit operative to the release magnet Re10 being closed.

Incidental to the actuation of relay 200 in Fig. 8, its armature 552 applies a short circuit to the winding of relay 479 causing it to deactivate, followed by relay 502. Also, incidental to the actuation of relay 200, its upper armature opens the path from conductor 194 to the lower make-before-break spring of relay 201', thus disabling the latter said relay. Under the condition, that of an outgoing call, the relationship of the 25 line conductors 56 and 57 are not reciprocated with respect to the windings of relay 50 in element M10, incidental to the relay 188 or the relay 269 actuating, as occurs where the call is in-coming to the passing call connector involving elements M10 and N11. Relay 542 deactuates consistent with the last impulse sent, as set forth, but under the assumed condition wherein the called number constituted four digits, it has no operative 30 function beyond that of completing circuits upon its lower armatures retracting against their resting contacts. Ground through off-normal springs ON8 will be conducted through lower inside armature of relay 542 to the conductor attaching to the bank contacts engaged by wiper 533, with the exception of the first bank contact 537, upon which the said wiper 533 normally rests. So that it is manifest, that under this condition the 35 motor magnet M8 will be caused to automatically operate to return the wipers 530 to 533 into normal engagement with bank contacts 534 to 537, respectively. In this connection it will be noted that the tone source T8 applied through wiper 530 over

conductor 545, audible to the calling party, will endure until the wiper 530 re-engages its normally engaged bank contact 534. By providing more bank contact sets to be idly rotated over or by prolonging the slow-releasing period of relay 542, the application of the tone from source T8 can be correspondingly prolonged. The purpose of the latter tone source applied audible to the calling party, is to apprise him, that the element M10 has been interposed in the manner as will appear presently, and that the calling party can thereafter forthwith annex digits corresponding to any local or other telephone number accessible to element N11 and thereby pass the connection and introduce the corresponding line into talking relation with the connection which was first directly established from the calling substation SJ20, in the manner as has been previously set 40 forth wherein the call was initiated at substation S in the main exchange. The further passing and the handling of the call under directive control of substations thus introduced will be as hereinbefore described. 45 With reference to the relay 542, it is to be understood that in lieu of the dash-pot device therein, a relay of the general type of 316 in Fig. 9, may be employed, wherein the plunger-arm will normally apply ground 50 to its bank contacts corresponding to the three lower armatures of relay 542, and wherein, off-normal spring set thereon, will correspond to the upper armature and co-operating contact of relay 542. The conditions under which it has other operative 55 functions will be discussed presently.

Incidental to the actuation of relay C8, conductors 480 and 487 which have been traced to include the receiver at substation SJ20 are continued through armatures 499 and 500, over conductors 497 and 498, to bank contacts 83 and 84, engaged by wipers 79 and 80, respectively, in Fig. 13. From wiper 79, a path can be traced through armature 129, conductor 128, armature 126, conductor 124, upper winding of relay 123 in Fig. 9, conductor 122, armature 120 in element M10, conductor 119 to grounded interrupted signaling current source G9. From wiper 80, a path can be traced through armature 138, 60 armature 139, inner winding of relay 127 to grounded battery, the relay 127 actuating, whereupon a path from armature 126 will be continued through the upper winding of relay 188, conductor 189, upper winding of retardation coil 191 to grounded battery, and a path from armature 139 will be continued through the lower winding of relay 188, armature 140 and over the previously traced locking circuit of relay 127 to spring 144 in Fig. 9, the relay 188 actuating.

In view of the previous descriptions with relation to element M10, it will now be manifest that a talking path exists between the 65 130

calling party at substation SJ20 and the leading-in line conductors 523 and 524 of connector L7, having in mind the locked condition of relay 546 (in Fig. 8), upon which the 5 maintaining energized the relay 525 in connector L7 and the maintaining energized the relay 50 in element M10 depend. The actuation of relay C8, and other functioning in Fig. 8, has thus automatically changed the 10 primary connection between the calling substation and the group subscriber's trunk so that the element M10, including its wipers, is now interposed between the calling substation and the said trunk linked to include 15 connector L7.

It will be manifest, in view of the foregoing, that when armature 87 of relay C8 attracts, conductor 64 is disconnected from conductor 495, traced to bank contact 451 of line 20 switch Q13. However, the ground is maintained on said latter bank contact from armature 115 in element M10, conductor 115', wiper 78, bank contact 82, conductor 86, armature 87, spring 494, to conductor 495. 25 Therefore, no lapse of ground occurs to bank contact 451, so the line switch remains seized, now dependent upon ground applied from armature 115 of element M10.

Before detailing the operative functions 30 with relation to the party at substation S7 responding, or with passing operations with relation to the elements M10 and N11, it will for the present be assumed that the calling party at substation SJ20 replaces the receiver 35 to terminate the call. Relay 188 will deactivate, followed by relay 192, and relay 147 will actuate, whereupon a circuit can be traced from the lower armature of relay 188, armature 202, conductor 203, spring 204 in 40 element N11, spring 205, winding of vertical magnet V11, relay 206 to grounded battery, the vertical magnet V11 stepping the shaft one vertical step. Upon the armature 193 of relay 192 retracting, a circuit can be traced 45 therefrom, attracted armature 330, conductor 352, upper armature of relay 228 in element N11 to the release magnet Re11, restoring the shaft of element N11 to normal. However, no direct circuit path has been 50 closed to the release magnet Re10 to restore the shaft of element M10 to normal.

Having in mind the functioning of solenoid relay 316 in Fig. 9, and the fact relay 525 in connector L7 and relay 50 in element 55 M10 are held locked through the agency of locked relay 546 in Fig. 8, it is manifest the shaft of element M10 cannot be restored to normal unless relay 316 is caused to restore to normal to in turn restore the latter 60 said shaft. The winding of relay 546, applied to battery, is in series with the ground winding of relay 525 in connector L7. The connection not having been passed by element N11, in a predetermined time after 65 relay 188 deactuates, the plunger-arm of re-

lay 816 will restore to normal position, grounding bank contacts 323 and 324. Since the shaft of element M10 is off-normal, the release magnet Re10 thereof will operatively energize as before described. However, relay 50 is still locked through the agency of locked relay 546. When the shaft of element M10 restores, ground is removed from conductor 202', which latter condition causes relay 200 and dependent relay 546 to unlock and open the energizing path of relay 50, it deactuating, whereupon relay 63 will deactivate and ground will be removed from conductor 64 as applied from element M10. Relay 525 in connector L7 will deactivate, (due to the fact relay 546 has been disassociated), followed by dependent relay 526, connector L7 functioning to restore its shaft to normal as before set forth. The ground is now removed from conductor 86, so relay C8 deactuates. Upon relays 546 and C8 becoming deactuated, the battery and ground windings of relay 50 will be respectively opposed to the battery and ground windings of relay 525 in connector L7, so the latter said 80 relays will not mutually energize, but will remain deactuated.

In case the call had been passed (bearing in mind the called party at substation S7 has not responded), the restoring of the 95 shaft of the last element having its shaft off-normal will be as last before set forth, the relay 316 in that case restoring the shaft of the concerned element, it being understood that after relay C8 actuates the connection can be passed and re-passed as if the call had been an in-coming one to the trunk leading to the passing call connector, primarily.

It will now be assumed that the party at 105 substation S7 responds whereupon the connector L7 will function in the well known manner wherein the ring-cut-off relay 564 and back-bridge relay 565 will actuate and reciprocate the relationship of the windings of relay 525 with respect to conductors 523 and 524, incidentally, completing the talking path traced to conductors 523 and 524 through wipers 566 and 567, and engaged bank contacts 568 and 569 to include the 110 receiver at substation S7, so that the calling party at substation SJ20 and the called party at substation S7 are now in talking relation.

Going back to the condition ensuing upon the relays 564 and 565 in connector L7 actuating, it will be manifest that the grounded battery applied through the lower armature of relay 200 in Fig. 8 is now connected over the traced path including the winding of relay 546 to the battery winding of relay 525 125 in connector L7 and that the ground winding of the latter said relay is connected over the traced path to ground through retardation coil 548 in Fig. 8, having in mind that conductor 56 also leads to the battery wind- 130

ing of relay 50 in element M10. Conductor 56 will constitute battery potential but it is not essential that it shall be of sufficient value to maintain the relay 525 in connector 5 L7, from the fact that due to the battery applied through the lower armature of relay 200 and the winding of relay 546, in Fig. 8, opposing the battery winding of relay 525 in connector L7, to which conductor there 10 are no effective attachments, the relay 546 will unlock, whereupon the battery and ground windings of relay 525 in connector L7 will be respectively opposed to the ground and battery windings of relay 50 in 15 element M10, both said latter relays being thus maintained energized, the retardation coils 548 and 551 being incidentally disconnected.

Assuming that the called party at substation S7 now replaces his receiver, thereby causing the relay 565 in connector L7 to de-actuate to restore the current direction applied back to conductors 523 and 524 to that primarily existing from the battery and 25 ground windings of relay 525, the said battery and ground windings of 525 will now respectively oppose the battery and ground windings of relay 50 in element M10, so that both latter said relays will deactuate, the 30 connector L7 restoring in the well known manner and the element M10 restoring in the manner as hereinbefore described. Conductor 64 now being ungrounded, selectors B and C2 will unseize and restore in the well known 35 manner. Ground being now removed from conductor 202', relay 200 will unlock, and in view of the conductor 86 having become ungrounded, relay C8 will unlock, the circuits being now in normal condition.

40 Assume that the substation S7 is that of a subscriber called very frequently from the subscriber group to which the calling telephone SJ20 belongs, and that therefore, it is desirable both from the calling party's and 45 the operating concern's point of view to reduce the number of digits and involved equipments to the minimum. A more direct route will be established by the calling party annexing digit "0" (after first sending a similar initial digit), in lieu of sending the digit 50 "1". Under the condition of sending the second digit "0", the selector B will raise its shaft so that its wipers align with the "0" level thereof and there operate the off-normal 55 mal springs ON', effective to applying a ground to conductor 570, bank contact 571, wiper 505, and to the winding of slow-releasing relay 573, corresponding to relay 444 in line switch Q13. And having in mind, the 60 operation of the latter said line switch, which has been stated was similar to line switch D3, it will be manifest that the wipers 503 to 507 of line switch D3 will be caused to rotate into testing engagement with bank contacts 65 574 to 577 and bar 578. Assuming, that in

this connection the connector L7 is idle, the line switch D3 will seize the set of bank contacts 574 to 577, and the connection will be thus completed to conductors 522, 523 and 524 leading-in to connector L7, in the manner as hereinbefore described, with the exception that the selector C2 will not be introduced, and in fact, that the selector B will be caused to restore incidental to the wipers in line switch D3 rotating-off the corresponding bank contact set. As set forth at the outset, the advantage accruing to this method of operation will be increased in direct proportion to the number of numerical orders employed. In the present exemplified case, a 80 four-digit main exchange system is shown. In large cities it would involve six or more digits, perhaps, wherein there would be corresponding selectors (or links), similar to C2 introduced intermediate of selector B and C2. 85

In this connection attention is called to an operative difference with relation to Fig. 8, as described with relation to the four-digit call in that, since but three digits ("0—2—1") are required in the latter method, the wipers 530 to 533 in Fig. 8, will only be advanced into engagement with the fourth set of bank contacts, and therefore, the wipers 531 and 532 will not receive ground operative to relays 546, 200 and C8 as where four digits were sent. However, having in mind the described functioning of relay 542, upon its releasing period having terminated following the sending of the third digit series, ground can be traced through off-normal spring ON8, lower armature of relay 502, to the lower two armatures of relay 542. From the lower armature ground is applied operative to relays 200 and 546 as if wiper 531 had received ground from an engaged bank contact. The armature 580 of relay 542 applies ground operative to relay C8 as if wiper 532 had received ground from an engaged contact, so the circuits are thus brought into the state as if four digits had been sent. The lower inside armature of relay 542 applies ground effective to causing the motor magnet M8 to automatically operate as before, to return the wipers 530 to 533 to their normal position resting upon contacts 534 to 537, respectively. The functioning of the circuits with respect to the response being obtained from the substation S7 are as before described. 100 105 110 115

In lieu of the last foregoing descriptions, it will now be assumed that the switch-arm set SA7 is opened and the switch-arm set SA2 is closed. Under this condition, it will appear that when the line switch D3 seizes the bank contact set 574 to 577, it will seize the leading-in trunk to selector C2, in lieu of connector L7. And, under this condition, an extra digit "2" will be sent first following the second "0" sent after initiating the call, 120 125 130

in order to extend the connection to the connector L7.

It will now be assumed that switch-arm sets SA7 and SA2 are opened and the switch-arm set SA3 is closed. Under this condition, when the bank contacts 574 to 577 are seized by line switch D3, the connection will be extended to the attendant's equipment set E3. Attention is directed to the fact that the 5 battery and ground windings of relay 581 therein will be disposed to conductors 56 and 57 as were the battery and ground windings of relay 525 in connector L when it was seized, and it will be manifest that there is no 10 provision for reciprocating this relationship upon a response being obtained by manipulating the key K3 to introduce the operator's set S3 into the connection. It is a well known practice in automatic exchanges employing 15 measured or pre-payment service, the registration or collection of which is effected through the agency of reversing the battery supply to the calling party, to not thus reverse the battery supply when a substation 20 or switch-board of the operating concern is called. So, under the present condition after the second digit "0" has been sent and the line switch D3 seizes bank contacts 574 to 577, at the termination of the slow-release period 25 of relay 542 in Fig. 8, the stated operation of the motor magnet M8 will take place by way of causing relays 546, 200 and C8 to actuate, for the purpose as hereinbefore described. Upon a response being obtained through the 30 equipment E3, no operative effect will occur in relay 546 so that the retardation coils 548 and 551 will not be disassociated from the talking conductors 56 and 57, respectively. The calling party at substation SJ20, however, 35 can pass the connection and it can be repassed and operated generally, as has been set forth hereinbefore. The restoring of the interlinked equipments will be accomplished as described through the agency of relay 316 in Fig. 8 at the termination of the call, regardless of which element M10 or N11, is involved. In connection with the last foregoing descriptions, it will be manifest that the relay 581 will apply ground to conductor 40 48, and thence to conductor 64 and also, that when the selector C2 was concerned, that its relay 19 accomplished a similar result.

In view of the described functioning of the motor magnet M8 wherein wipers 531 and 532 are not directly rotated four steps into engagement with grounded bank contacts, respectively, but automatically complete their cycle, notwithstanding, through the agency of relay 542, it will be manifest 45 that where the called number involves a smaller than the maximum number of digits employed in calling certain numbers, the circuits will become capacitated automatically so the passing operations with reference to elements M10 and N11 can be proceeded

with as if the call had been an in-coming one to the trunk leading to the passing call connector, in lieu of an out-going one to the trunk. It is only necessary for the party calling to await a short, predetermined period after sending the last digit in order to allow for the relay 542 to deactivate. The tone perceived, projected from source T8, upon wiper 530 engaging the fifth bank contact, in the manner before described, indexes that the 55 passing may be proceeded with. In this connection, attention is directed to the fact that if the wipers 530 to 533 should be resting on the second set of bank contacts, for example, and the call destroyed, wherein relays 479, 502 and 542 will deactivate, the latter said wipers will be caused to automatically return to normal position by reason of ground being applied through the springs of off-normal set ON8, lower inside armature of relay 542 to the bank contacts engaged by wiper 533. This will cause the motor magnet M8 to function by way of returning the wipers to normal and incidentally, open the springs of the set ON8.

Attention is directed to an automatic restoring function in the line switch D3 (and other similar switches), wherein, upon the said latter switch unseizing, it forthwith closes a circuit operative to the motor magnet 55 by way of driving the wipers to the normally resting position thereof. The relay 573 in the line switch has a low resistance, and is marginally adjusted so that it will not be maintained energized from ground derived 100 serially through relay 47. It thus has the same characteristic, in this one respect, as that of motor magnet M3 with which it is in multiple when actuated, due to armature 578' of the relay 573 closing a path from its winding to the conductor leading to the motor magnet M3. So the relay 573 unlocks and deactuates and thus opens its energizing circuit at its armature 578', consistent with its slow-releasing characteristic, at the time the 105 wiper 507 rotates off its normally resting bar, it having been maintained actuated from ground derived through the wiper 507 while rotating over the said bar normally engaged.

If any grounded bank contacts are hunted 110 over after wiper 507 engages bar 578, the operation will be as in line switch A. When relay 47 deactuates in unseizing the line switch at the termination of the service, a circuit can be traced from grounded bar 578 (relay 573 being now deactuated), wiper 507, lower armatures of relays 47, 476, 573 to the motor magnet M3, causing the motor magnet to operate by way of driving the wipers until 115 wiper 507 moves off bar 578 and into its normally resting position shown in the drawing. It will appear that there will be a tendency for the line switches to be normally resting upon corresponding bank contact sets, being 120 the set upon which the wipers are shown 130

resting in the drawing, regardless of the busy or idle condition of the said set of bank contacts. This will mean that an initiated call will involve a hunting operation on the 5 part of the line switch if the selector B is busy. The latter condition can be altered by slipping the multiplied connections between the banks of the line switches of the group.

10 It will now be assumed that Fig. 22 is substituted for Fig. 15, and that Fig. 16 is employed where indicated in Fig. 24, and that the line switch R14 and the line leading to substation S17 indicated by Fig. 17 is disconnected from the attached conductors. That is, the substation S16 and its line switch 15 T16 have displaced substation S17 and line switch R14, it being noted that they concern the corresponding set of bank contacts accessible to the elements M10 and N11 and the connector U18. However, having in mind that for the purpose of illustration, the two levels involved in the concerned subscriber's group are the second and third levels accessible to the connector U18 in lieu of the first and second, as assumed wherein Fig. 15 was employed. The relationship has not been changed with respect to the bank contact sets accessible to the elements M10 and N11; 20 that is, their bank positions corresponds to their local telephone numbers. In order to avoid confusion, the letter "a" will be prefixed to the conductor designations, wherein they refer to conductors extending on Fig. 25 16, and Fig. 22, however, they will be understood to be continuations of the correspondingly numbered conductors, not having the letter prefixed. It will be understood in this connection that Fig. 16 may be employed 30 in conjunction with Fig. 15, and under that condition Figs. 14 and 17 would also be displaced thereby.

Assuming that the party at substation S16 35 removes the receiver from the switch-hook thereat to initiate a call, a circuit can be traced from the winding of slow-releasing line relay 584, armature 585, line conductor 586, lower spring of springjack J16, receiver of substation S16, winding of signal device 40 B16, upper talking spring of springjack J16, line conductor 587, armature 588 to grounded resting contact, the relay 584 actuating. Having in mind that the line switch T16 is similar to line switch Q13, with the exception 45 that the left hand relay and the attached circuits shown in T16 have been introduced, it will be manifest that if the local connector U18 corresponding to the set of bank contacts upon which the wipers are shown resting 50 is idle, that the line switch will forthwith seize, and that if it is busy, that it will hunt. It will be assumed that it seizes. In view of the fact that the second and third levels of the local connector U18 are concerned, the 55 bank contacts engageable to wiper 372 in the

second and third levels will be tied to conductor 589 which attaches to conductor a369 and shown in detail in Fig. 39. A circuit can now be traced from trunk conductors 299 and 302 leading to the local connector U18, which will 60 include conductors a299, a300, bank contact 590, wiper 591, armature 588, the traced path including the receiver at substation S16, armature 585, wiper 592, bank contact 593, conductor a301 to conductor 302, the relay 297 65 in local connector U18, actuating as in the manner as before described, wherein the latter said connector was seized. In line switch T16, a circuit can be traced from grounded 70 working contact and its cooperative armature 595, wiper 596, bank contact 597, conductors a369, 589 to the bank contacts of the second and third levels engageable to wiper 372 referred to hereinbefore. Also, conductor 598 75 attached to conductor 589 applies this ground to segment 599. From segment 599 conductor 600 leads to segments 601 and 437, segment 601 being ten levels above segment 599 and segment 437 being nine levels above segment 599. In this connection it will be remembered that when connector U18 was 80 seized as assumed in previous descriptions, conductor 370 was caused to become grounded from the line switch incidental to its seizure of the latter said connector, so that wiper 373 85 became grounded forthwith to cause relay 380 to actuate, disassociating the impulse source D18. This has not occurred in the present instance, and therefore, upon the actuation of 90 relay 306, which occurred responsive to the 95 actuation of relay 297, the impulse source D18 was applied through the upper armatures of 100 relays 380 and 306, spring 391, spring 392, vertical magnet V18, upper winding of relay 382 to grounded battery, the vertical magnet and 105 relay 382 functioning as before described, by way of stepping the shaft one vertical position. Incidentally, substituting spring 394 110 for spring 392 of the off-normal set ON18, preparatory to including armature 395 in the 115 impulse circuit to the vertical magnet, wherein the vertical magnet would continue to receive ground impulses operative to it from the source D18. However, upon the wiper 373 receiving ground from segment 599, the 120 hereinbefore described functioning of local connector U18 will ensue wherein relay 380 will be caused to actuate and disconnect the 125 impulse source D18, and incidentally, apply the tone source T18 audible to the calling party, to index that the connector is in condition to receive the first directive impulses. It will be clear from the foregoing that had the wiper 373 not received ground at segment 599, that the shaft (also carrying wipers 386 130 to 389 and 372) would move upwardly until the wiper 373 did encounter ground, or until, the off-normal set ON18 operated to open the impulse circuit from source D18. When relay 380 is caused to actuate, the wipers of the 135

connector U18 align with the first level of bank contacts, and therefore, directively sending an impulse corresponding to digit "1" or impulses corresponding to digit "2", which will be the first digit of the levels of local telephone numbers of the (two-level) group subscriber to which substation S16 belongs, will cause the wipers to be stepped vertically, into alignment with the desired bank level, 5 in readiness to receive the last directive series to set them upon the desired bank contacts. From the last foregoing it will be clear that the actual level position or positions occupied by a local line, or lines, will not have to be 10 taken into account in the directive calling, because the connector automatically sets its wipers one level (being the indexed number of the lower most level of the concerned subscriber), below the lower-most level occupied 15 by the group subscriber to which the calling substation belongs.

Assume that a trunk connection over one of the two-way trunks is desired. As in the previous similar instance, the digit "0" will be 20 sent, whereupon wipers 373 to 375 will come into engagement with segments 602, 601 and 603, respectively, wiper 374 receiving ground from segment 601, which will cause a ground to be applied over conductor 440, conductor 25 a440, conductor a441, bank contact 604, wiper 605, make-before-break spring 606 to the winding of slow-releasing relay 607, the latter relay actuating and locking to bar 608 grounded through armature 609 of relay 607, 30 in the manner as described with relation to line switch Q13. Remembering that bar 610 is normally grounded, and that this grounded condition has not been disturbed, and due to the attraction of armature 609, bar 611 which 35 is normally grounded has become ungrounded incidental to bar 608 becoming grounded, it will appear that the only sets of bank contacts that are subject to seizure are those embraced by the bar 611 and it will be assumed 40 that the first set of bank contacts 612 to 617 of said group which correspond to trunk conductors a481, a486, and a496, and which lead over conductors a495, a487 and a480 to conductors 495, 487 and 480, respectively. It will 45 be further assumed that this trunk is seized and that the same operative condition is set up in the circuits of the system as was hereinbefore described under a similar condition wherein line switch Q13 was concerned. The 50 call can be directively extended from the calling device at substation S16 as when the call was extended under a similar condition from the calling device at the substation SJ20. The detailed operation with relation to a call 55 extended from substation S16 will be manifest in view of the previous description referred to.

Assume that in lieu of sending the digit "0" to obtain connection with the said two-way trunk, the calling party desired to gain

connection with a trunk of a separate group which may be a two-way trunk or a trunk of an out-going trunk group, reached through generally similar equipment at the main exchange end with that employed in the outgoing calls hereinbefore detailed. This is indicated by the dotted squares in Fig. 24, referring to Figs. 3 and 6, the significance of which has been discussed, so suffice it to say, that a second or alternative trunk group is 75 wanted.

In view of the last foregoing paragraph, when the digit "9" is sent, after initiating the call and perceiving the tone emanating from source T'18, the wipers 373 to 375 will be directively stepped from their automatically assumed position of alignment with the first level and into engagement with segments 435 to 437, respectively. Upon the retraction of armature 618, of relay 382, the ground received from segment 437 is applied through wiper 375, armature 618, conductors 619, 620, bank contact 621, wiper 622, make-before-break spring 623 to the winding of slow-releasing relay 624, the latter relay actuating. 80 Incidental to the latter relay actuating, its armature 625 removes the ground normally existing on bar 610 and applies it to bar 608, the relay 624 thus being locked from armature 625, bar 608, wiper 626, and armature 85 629. The latter ground will also be applied through armature 624' of relay 624 to conductor 630, operative to the motor magnet M16. The wipers of the line switch T16 will now be advanced in the manner as described 90 with reference to line switch Q13, until wiper 626 disengages bar 608; and also, the grounded bar 611. However, upon ungrounded bar 610 being engaged by wiper 626, the conductor 630 will not receive ground through 95 the wiper 626 and the attracted armature 624' of relay 624, but in view of the fact that switching relay 631 was caused to deactivate and unseize the line switch T16 consequent 100 upon relay 624 actuating in the manner as 105 described with relation to line switch Q13, the relay 584 is now actuated and the conductor 630 will be grounded dependent upon the private wiper 632 receiving ground from an engaged bank contact. In other words, the line 110 switch T16 is now hunting for an idle set of bank contacts corresponding to the group of trunks embraced by the bar 610, which latter group has been designated (from the sending 115 of digit "9"), as the alternative set of trunks sought. It will be assumed that the first set of bank contacts embraced by bar 610 is idle and therefore, will be seized by the hunting line switch, bearing in mind that, due to the slow-releasing characteristic of relay 624, if 120 the wiper 632 should have received ground, the latter said relay would remain locked until an appreciable time after it failed to receive ground. And remembering that forthwith upon the wiper 632 failing to receive ground, 125 130

the short circuit condition is removed from the winding of relay 631, so that it will actuate because of becoming in series with the winding of motor magnet M16, the line switch 5 T16 then being in a seized condition.

Upon the seizure of the line switch T16, a circuit can be traced from the winding of relay 476 in line switch D3, upper armature of relay 47, conductors 447, 56, a56, 632, bank 10 contact 633, wiper 592, armature 585, conductor 586, over the traced path including the receiver of substation S16, conductor 587, armature 588, wiper 591, bank contact 634, conductor 635, conductors a57, 57, 488', armature 489 in line switch D3 to resting grounded contact, the relay 476 actuating, whereupon armature 493 applies its ground over conductors 48, 64, a64, 636, bank contact 637, wiper 632, armature 638, lower armature of 15 relay 631, winding of relay 631 to the winding of motor magnet M16, the ground thus applied back from armature 493 in line switch D3 occurring before armature 639 in line switch T16 has had time to retract and re-20 move ground from the upper winding terminal of relay 631 (applied through the upper armature of relay 584), so the line switch T16 is now held seized from the ground received back from the armature 493 in line 25 switch D3. The line switch D3 will forthwith hunt in the manner as previously described, by way of automatically extending the connection to the first idle first selector B. The seized first selector will then main-30 tain ground on conductor 64 from the upper armature of its relay 515. The calling party at substation T16 can now send the first digit of the telephone number of the desired line, or can send digit "0", and cause the off-35 normal set ON' in selector B to function by way of unseizing the line switch D3 thus causing it to hunt for and seize an alternative trunk of the group embraced by the bar 578, by way of obtaining a short path to the desired line, in the manner hereinbefore de-40 scribed. At the time line switch D3 unseizes and its relay 476 reactuates over the path including the receiver at substation S16, as primarily, its armature 493 re-applies ground to conductor 64, but it will be borne in mind that until the wipers of the line switch D3 rotate-off the set of bank contacts corresponding to the selector B the ground will be maintained on conductor 64 from the armature 45 515 in the selector. The relay 584 in line switch D3 will actuate and apply ground to conductor 64 from its armature 493 before the wipers rotate-off, as referred to, so no lapse of ground will occur to conductor 64 50 under the condition. Where the line switch D3 is adapted to seize the connector L7, selector C2 or the equipment E3, through the agency of switches SA7, SA2 and SA3, respectively, the ground will be applied to conductor 64 therefrom, in a similar manner to

that described with reference to selector B. In the foregoing, where line switch T16 has been described as having access to Figs. 6 and 3, it will be borne in mind that the described circuits will not be the identical 70 circuits designated in foregoing descriptions, but will be circuits similar thereto, possibly of the same group (or a companion group having a different destination, perhaps), containing them, though the passing 75 call connector and associated equipments at the same end of the trunk would ordinarily, but not necessarily, be omitted, so the trunk would become a one-way trunk for traffic originating at the premises of the group 80 subscriber concerned. Under the condition, originating calls from the premises of the group subscriber would not be passable when the primary trunking digit sent is "9", but would be when the digit "0" is sent in lieu 85 thereof, because the latter will divert the call from the local connector to a two-way trunk, while the former will divert the call from the local connector to a one-way out-going trunk. In this connection, it will be understood that 90 a group subscriber may have two groups of two-way trunks, having different destinations, so the calling of digit "9" will attain one group and the calling of digit "0" will attain the other. The value of the preliminary 95 digit sent thus serves to selectively determine the called group, as well as serving to incidentally eliminate the connector involved in the said selective operation.

It being now clear that the calling party 100 at substation S16 can, through the agency of the line switch T16, obtain connection through a local connector, and to local sub-105 stations there-through, or to either of two groups of trunks, directly, after directively releasing the connector from the connection, it will now be assumed that the calling party terminates the service by replacing his receiver. Ground will be removed from conductor 64 and attachments, in the manner 110 as hereinbefore described. This will unseize line switches D3 and T16, the connector U18 having been unseized and restored to normal 115 in the manner as before described, incidental to the bar 608 becoming grounded when the digit "9" was sent, wherein the wipers of line switch T16 rotated-off the bank contacts corresponding to connector U18. Upon relay 631 in the line switch T16 deactuating, a circuit can be traced from conductor 630, 120 lower armature of relay 584, armature 640, wiper 626, bar 610 to grounded armature 625, the motor magnet M16 actuating to move the wiper 626 (and companion wipers), out of engagement with bar 610, whereupon 125 wiper 626 will become engaged with ungrounded bar 608.

Employing connector U18, it will appear that regardless of what level the wipers may be in alignment with from having been au-130

tomatically stepped consequent to the said connector becoming seized by a line switch, the sending of digit "9" or digit "0" will cause a specific operation with reference to the digits sent. In commercial installations, all subscribers would not require service over two trunk groups as contemplated where a line switch such as T16 is employed, so that in choosing levels for a group subscriber, 10 they will be so chosen that those group subscribers that have access to two trunk groups will be in the lower levels. For example, under the sixth level, as otherwise it would mean that a large number of levels would 15 have to be employed to allow for ten levels above the primary position automatically assumed by the wipers. The off-normal spring set ON'18 being adjusted to operate upon the wipers attaining the uppermost level position, will cause the conductor 619 to become 20 grounded as if the digit "0" has been sent, there being no provision for simulating a condition equivalent to that set up by the digit "9", though it is manifest that levels 25 involving segments engaged by wipers 373 to 375 could be added to any desired number to provide for this.

It will appear that if plug AP21 or CP21 in Fig. 21 is applied into springjack J16 30 (having in mind that the characteristics of relay 584 are the same as those of relay 224 in line switch Q13), the resistance $r'16$ will be involved in the energizing circuit of relay 584, and therefore, ground will be applied 35 from armature 639, conductors 641, $a106$, 642, (in Fig. 22), and attachments leading to bank contacts to guard the line leading to substation S16 against seizure.

In this connection, attention is called to 40 the fact that Fig. 16 may be substituted for Figs. 14 and 17 by attaching Fig. 16 above Fig. 15. However, under the latter condition, the first two levels of bank contacts accessible to the connector U18 would be involved, rather than the second and third levels thereof, as are concerned when Fig. 22 is employed, in lieu of Fig. 15.

Referring to Fig. 23, being that of a local connector Y23, designed for alternative use 50 as indicated in Fig. 24, it will be noted that the bank contacts are disposed like those accessible to connector U18, having in mind that the bank contacts arrangement with reference to the lower wiper of connector Y23 correspond to that shown in Figs. 38 and 39 with reference to connector U18, depending upon whether Fig. 15 or Fig. 22 is joined to the left thereof in the manner as referred to with reference to connector U18.

60 In connector Y23, a series, marginally adjusted relay 643 has its upper and lower windings in series with the upper and lower windings, respectively, of line relay 644, the adjustment of relay 643 being such that if the energizing current for the said relays is at-

tenuated, as by the inclusion of resistance $r'20$ at substation SJ20, the relay 643 will deactivate while the relay 644 will remain sustained. For the purpose of the description about to be entered into, the arrangement shown in Fig. 70

24 will be assumed, but with Fig. 23 substituted for Fig. 18. Also, that a call is assumed as initiated from substation SJ20 as in a description hereinbefore given. It will therefore be assumed that the call has been initiated from the substation SJ20, and that the line switch Q13 has seized the trunk corresponding to connector Y23 having in mind that conductors $a292$, $a302$ and $a299$ are joined to conductors 292, 302 and 299. Relays 644 80 and 643 will be operatively energized over a path including grounded battery and upper windings of relays 644 and 643, make-before-break spring 645, conductors $a299$, 299, the previously traced path including the receiver 85 at substation SJ20, conductors 302, $a302$, make-before-break spring 646, lower windings of relays 643 and 644 to ground. A circuit can now be traced from grounded resting contact and engaged make-before-break 90 spring 647, lower armature of relay 644 to the winding of slow-releasing relay 648, the latter relay actuating and applying ground from working contact and cooperating armature 649, conductors $a292$, 292, and over the traced path, to maintain relay 223 in line switch 95 Q13 energized. The upper armature of relay 223 in line switch Q13 has applied ground to conductors 369, 370, $a370$, to the bank contacts of the lower two levels engageable by wiper 669 as shown in Fig. 40, and over conductor 655 to segment 656, wiper 657, lower winding of relay 653 to grounded battery, the latter relay not actuating, due to the fact 100 that it is adjusted and its winding disposed so it will maintain the armatures attracted, if attracted through the influence of the upper winding, but will not attract them from normal. This ground is also applied through make-before-break spring 658, armature 659 to the winding of slow-releasing relay 650, the upper armature of the latter relay opening the path from the impulse source D23. Grounded tone source T'23 is applied through 105 off-normal spring set RO23, which is adjusted to operate on the first off-normal movement of the shaft, lower armature of relay 650, conductor $a302$, and over the traced path including the receiver at substation SJ20, through the upper winding of relay 644 to 110 grounded battery, the tone being audible to the calling party. Upon perceiving the tone, the calling party will know that he can proceed to directly operate the connector 115 Y23 in a manner as set forth with relation to connector U18, having in mind, however, that relay 643 will operate coincidentally with relay 644.

120 In this connection it will be noted that had Fig. 22 been substituted for Fig. 15, ground 130

from conductor 369 would have been communicated over conductor $a369$, conductors 589, $a589$, 660, to segment 661. The bank contacts of the second and third levels engageable by wiper 669 are attached to conductor $a589$, as shown in Fig. 41, under the latter assumed assembly. Under this condition the relay 650 would not be caused to actuate forthwith upon the connector Y23 being seized and that therefore, a path will exist from impulse source D23, springs of off-normal set ON'23, upper armatures of relays 650 and 648, spring 662, spring 663, winding of vertical magnet V23, upper winding of relay 653 to grounded battery, the latter said relay actuating and the vertical magnet operating to step the shaft so that its wipers will align with the first level of bank contacts, whereupon, wiper 657 will receive ground from segment 661 and apply it to sustain the armatures of relay 653 and also through spring 658, armature 659 to the winding of relay 650, the latter relay actuating and incidentally opening the path traced from the impulse source D23 at its upper armature. Spring 664 has been substituted for spring 663 in the off-normal set ON'23, which operated upon the first off-normal movement of the shaft. The tone source T'23 is applied audible to the calling party consequent to the relay 650 having actuated, and having in mind, that relay 653 is maintained actuated, it will appear that the connector Y23 is in readiness to receive directive impulses in the manner as set forth with reference to connector U18. However, in this instance, the relay 643 will operate coincidentally with relay 644 but to no operative purpose at this juncture. It will thus appear that upon the seizure of connector Y23, its shaft will be caused to automatically step vertically into alignment with the bank level one step below the lower-most level reserved to the group subscriber to which the line leading to the calling substation SJ20 belongs, as in the case of connector U18. However, the connector Y23 has but ten levels, for example, and the off-normal set ON'23 is adjusted to operate upon the wipers aligning with the "0" level. It will thus appear that if the calling party now sends "0" and thereby operates the latter said off-normal spring set, conductor $a440$ will become grounded upon the retraction of the upper armature of relay 653, and this ground will be applied over conductor 440, conductor 441, bank contact 442, wiper 443, upper make-before-break spring of relay 444 to the winding of the said relay, the line switch Q13 thereafter functioning as hereinbefore described under similar conditions, wherein it unseized from the trunk leading to connector U18 and seized the two-way trunk leading to elements M10 and N11, by way of extending the connection to the first selector available in the main exchange. Regardless of what level the wipers may be in alignment with at the time the digit "0" is sent, the said functioning will take place upon the off-normal set ON'23 becoming operated subject to the retraction of the upper armature of relay 653, even though the entire series of ten impulses constituted thereof have not been transmitted, as would occur, for example, if the lower-most level of the subscriber group containing the calling line is above the first level.

It being now clear that the calling party can send impulses corresponding to the digit "0" and can thereby cause his line switch to disassociate from its primarily seized connector and thereafter automatically seize a main exchange trunk, it will now be assumed that the calling party in lieu of sending the digit "0", depresses the key K20, and thereby includes the resistance $r'20$ into the path traced involving the receiver at substation SJ20 and the relays 643 and 644. However, the relay 643 will now deactivate, due to its marginal adjustment, whereupon a circuit can be traced from ground, upper armatures of relays 344 and 343, outer winding of ring-cut-off relay 665 to grounded battery, the latter relay actuating and removing the ground from lower make-before-break spring thereof, thus ungrounding spring 658 and thereby causing relay 650 to deactivate, the relay 665 locking through its armature 666, off-normal spring 667 to grounded conductor $a292$. It will thus appear that even though the key K20 is depressed but momentarily, the relay 665 will be caused to actuate and lock, followed by relay 650, and that the relay 650 will be thus disabled against reactuating. Relay 648 being now actuated, and relay 650 deactivated, a path can be traced from the impulse source D23, springs of off-normal set ON'23, upper armatures of relays 650 and 648, springs 662, 663, winding of vertical magnet V23, upper winding of relay 653 to grounded battery. In view of the fact that relay 650 cannot again actuate, it will appear that the shaft will be stepped vertically until the off-normal spring set ON'23 is operated and causes conductor $a440$ to become grounded upon the upper armature of relay 653 retracting consequent to the impulse source D23 becoming disconnected and the hereinbefore described functioning with relation to the line switch Q13 wherein it unseizes and thereafter hunts and seizes a main exchange trunk, will ensue. In connection with the latter functioning, it will be manifest that had the wipers of the connector Y23 been automatically stepped into alignment with the first level below the lower-most level of the group containing the calling line, and under which condition the relay 653 will be locked actuated, the impulses described as applied from spring 662 to spring 663 initially, would be applied from spring 662 to spring 664, ar-

5 mature of relay 653, vertical magnet and upper winding of relay 653 to grounded battery. Of course, the automatically applied impulses following the first impulse of a series of impulses applied through the agency of key K20, would be by way of spring 664 in lieu of 663.

It will appear that upon the seizure of the connector Y23, wherein lower armature of relay 668 actuates, the ground applied through the make-before-break spring 647, must come from a bank contact engaged by wiper 669, and the only bank contacts accessible to the wiper 669 are those grounded by the upper armature of relay 223 in line switch Q13 over conductor 369 specific to connector Y23, and refer to the group containing the calling line. So unless, the wiper 669 receives ground from an engaged bank contact, meaning that the called line belongs to the group containing the calling line, ground will be removed from the winding of relay 648, whereupon it will deactivate and remove the ground from conductor $a292$. This will cause the line switch Q13 to unseize, followed by the restoration of the connector Y23, the latter functioning as follows: Upon conductor $a292$ becoming ungrounded, the locking ground for relay 668 will be opened, re-establishing the ground from resting contact to spring 647 and whereupon relay 644 will deactivate, due to the unseizing of the line switch Q13. Ground will be communicated through the lower armature of relay 644, lower armature of relay 648, upper pair of off-normal springs to the release magnet Re23, operative to restoring the connector Y23 to normal.

40 In view of the descriptions with reference to connector U18, and the general similarity of the circuits of the latter said connector, with that of connector Y23, it is thought a further specific detailed description of the operative functioning of connector Y23 is unnecessary to a full understanding of it.

45 In the foregoing descriptions, wherein the call originated at local substation S, local selectors B and C2 were involved. It will now be assumed that the call emanates from the toll switchboard in Fig. 4, and that the
50 switching cord-pair C4 is employed wherein plug CP4 is inserted into springjack CJ4 by way of seizing toll first selector F4, the said selector being well known in the art. A circuit can be traced from the winding of line
55 relay 670, upper armature of switching relay 671, auxiliary contacts of springjacks CJ4, sleeve of plug CP4, make-before-break spring of key K4 to the winding of supervisory relay 672, the said relays actuating.
60 The relay 672 is marginally adjusted so that it will not sustain when a resistance r_6 in connector J6 is included in its energizing circuit. Relay 673 will actuate from the ground applied from the armature of relay 670.
65 Upon manipulating key K4 and thereby in-

Introducing the calling device CD4 into the energizing path including the winding of relay 670, in lieu of the winding of relay 672, and manipulating the calling device CD4 in accordance with the first digit "1", the wipers of selector F4 will be caused to be set upon the bank contacts 674 to 677 by way of extending the connection to second toll selector H5, whereupon a circuit can be traced from line relay 678, armature 679, bank contact 675, upper armature of relay 671, auxiliary contacts of springjack CJ4, sleeve of plug CP4 to ground by way of contacts and calling device CD4. Upon manipulating the calling device in accordance with the second digit "1", the second selector H5, which is well known in the art, will be caused to function in the well known manner, to set its wipers upon bank contacts 680 to 683. A circuit can now be traced from the winding of relay 39 in connector J6, (resistance r6 short-circuited), bank contact 681, armature 679, bank contact 675, upper armature of relay 671, auxiliary contacts of springjack CJ4, sleeve of plug CP4 to ground through the calling device CD4, the relay 39 actuating. A circuit can now be traced from the upper winding of relay 6, spring 7, armature 684, inner winding of electro-polarized relay 685, spring 14, lower winding of relay 6 to ground, relay 6 actuating, applying its grounded armature to operatively energize relay 15. The current traversing the inner winding of relay 685, and that established through the outer winding thereof to grounded armature 686 energize the core of relay 685 differentially, so that its armatures are not operatively attracted. The upper armature of relay 15 applies ground to bank contact 680, armature 687, bank contact 674, armature 688 to conductor 690, which latter conductor is grounded to auxiliary spring 691 of springjack CJ4. The connector J6 and selectors F4 and H5 are thus guarded against being seized. Upon the calling device CD4 being manipulated in accordance with the third digit "1", relay 39 will deactivate and reactivate one time responsive thereto, whereupon the energizing circuit of relay 6 will be correspondingly opened and it will therefore deactivate and reactivate one time responsive thereto by way of stepping the wipers of connector J6 into alignment with the first level of bank contacts, in the manner as hereinbefore described, wherein the relay 6 was caused to thus operate responsive to the calling device 4 at substation S. Upon the calling device CD4 being now manipulated in accordance with the fourth digit "1", the relay 6 will again function in deactuating and reactuating one time responsive thereto, by way of setting the wipers 23 to 27 into engagement with bank contacts 31 to 35, respectively, as when the relay 6 was caused to thus

function and set the said wipers upon the latter set of said bank contacts in previously assumed calling. However, in the present instance, a circuit can be traced from ground 5 on armature of relay 692 in Fig. 6, lower armatures of relays 39 and 45, wiper 27, bank contact 35, to the winding of relay 695 in Fig. 8, the latter relay actuating by way of removing ground from armature 67. It will 10 be remembered here that the grounded condition of armature 67 caused the shaft of element M10 to automatically initiate a hunting movement on its normal level consequent to the seizure by connector J6, when the call 15 originated at substation S. Thus, in the present instance, the element M10 is disabled against such functioning on its normal level, because of armature 67 being attracted. Upon the key K4 being restored, whereupon the 20 winding of relay 672 displaces the ground path through the calling device CD4, the supervisory lamp 696 is caused to re-glow, it having glowed when plug CP4 was first inserted, and extinguished when key K4 was 25 first manipulated. Upon the calling operator manipulating key C4, the operator's telephone circuit S4 is introduced into the connection, so that a possible busy condition will be discerned, in fact, the said key C4 would 30 ordinarily be operated upon the initiation of the call. The operator now knows that the connection has been completed, and the trunk leading to the passing call connector of the called subscriber is seized, because of the absence 35 of the busy tone. At any convenient time thereafter, the ringing key R4 may be operated to apply the signaling current source G4 over the tip conductor of the plug, conductor 697, bank contact 676, bank contact 40 682, winding section of repeating coil C6, upper armature of relay 685, winding of relay 692, section of latter said repeating coil, bank contact 683, bank contact 677, conductor 698, sleeve of plug CP4 to the latter said current source, the relay 692 actuating responsive thereto, and thus opening the energizing 45 circuit for relay 695 in Fig. 8 to permit the armature 67 to receive ground from its resting contact, whereupon the condition will 50 ensue, before described, to start the hunting movement of the shaft of the element M10 on its normal level wherein its wipers 77 to 80 will seize the first set of unguarded bank contacts 102 to 105, respectively, which are 55 assumed to be the first unguarded set, as in the descriptions hereinbefore. So the line leading to substation S17 is seized and signaled upon in the manner as before described. Upon the key R4 being restored, and relay 692 60 therefore restores, and relay 695 will re-actuate. The latter may occur before the line leading to substation S17 has been seized, since the element M10 will automatically hunt after stepping off-normal under the directive 65 initiation through the agency of the

key R4. Relay 695 being maintained actuated, the windings of retardation coil 191 are short-circuited so that the battery supply through back-bridge relays 188 and 269 will be augmented in strength. The latter is to insure that the transmitters will be more strongly excited under the condition of a toll connection. 70

Upon the called party at substation S17 responding, wherein relay 188 will actuate, followed by the actuation of relay 201', the current traversing the inner winding of relay 685 derived through the windings of relay 50 in element M10 over the circuits hereinbefore traced from springs 7 and 14 will now be reversed in direction, and therefore, cumulative with the outer winding of said relay 685. Under the latter condition the relay 685 will actuate and remove the short-circuit from resistance r6 and open the path including the winding of relay 692. Due to the inclusion of resistance r6, the relay 672 of cord-pair C4 will deactivate, extinguishing lamp 696 to indicate that the called party has responded, in this case being on the first choice attendant's line. The talking circuits from springs 7 and 14 in connector J6 to and including the substation S17 are as when the call was made from substation S, while the talking circuits from the switching cord-pair C4 are as 80 traced to bank contacts 682 and 683 of selector H5, the said sections being united inductively through the primary and secondary sections of the repeating coil C6, including the respectively interposed condensers. From previous 90 descriptions, it will be manifest that the conductor 64 will remain grounded as long as the inner winding of relay 685 is included in the energizing path of relay 50. The latter will endure until relay 39 will be caused to 100 deactivate by removing ground from conductor 690 in Fig. 4, which condition is controlled by the plug CP4 being in the said springjack. Thus, removing plug CP4 from the springjack will cause relays 39 and 50 105 to deactivate in sequence, by way of restoring element M10 to normal. 110

In previous descriptions, wherein the application of busy tone source T6 was described, it was disclosed how, after the busy tone was once applied by relay 36 it would be maintained until the connection was destroyed, regardless of the fact that the trunk upon which the wipers are resting becomes un-busy, subsequently. This condition was effective to locking the relay 36 through spring 38 and the make-before-break spring of relay 39 to grounded off-normal spring 40. However, under the condition of the call being effected to the connector J6 from a toll selector, such as H5, wherein relay 39 is caused to be actuated, the said locking circuit is opened at the said make-before-break spring on relay 39 and applied through the attracted upper armature of relay 36 to wiper 24, so that when 115 120 125 130

relay 22 deactuates, there is no alternative locking path provided from retracted spring 38 to maintain the relay 36 actuated after the bank contact engaged by wiper 24 becomes ungrounded and then constitutes battery potential in lieu thereof. Under the latter condition (relay 36 deactuated), the connector J6 will seize forthwith, by reason of battery being derived from wiper 24, outside winding of relay 45, upper inside armature of relay 36, spring 38, upper armature of relay 39, upper armature of relay 36 to spring 40, the relay 45 actuating and locking through armature 46, as before set forth. The absence of busy tone will index to the calling operator the condition, whereupon the key R4 may be manipulated by way of initiating the hunting operation of the element M10, as has been described.

The foregoing described equipments for enabling the toll operator to directly initiate the primary hunting movement of the element M10 does not insure that an attendant's line is available, so that under the condition of attaining the connection with the group subscriber's trunk leading to the passing call connector, there is still the possibility of being barred from the called line. By reference to Fig. 42, having due regard for the reference characters applying to Figs. 8, 9, 10 and 11, a preferred modification of the circuits before described, is shown. The said modification may be introduced into the two types of passing call connector circuits employed in the exemplified system. An object of the modification, which was not shown in the main drawings, to avoid complexity of description thereby, is to enable the calling toll operator to complete the connection to the group subscriber's trunk as before, whereupon the element M10 (or A25) will forthwith automatically function to extend the connection to the first available attendant's line and seize it if it is not busy, but not signal upon it automatically. If the latter said line is busy, a tone indicative thereof will be applied, audible to the calling toll operator. The element M10 will lock on busy, and incidentally, restore its shaft to normal position. The toll operator can by applying current through the agency of key R4, unlock the set-up busy condition. Upon the restoration of the latter said key, when applying the signaling current, the shaft of the element M10 will forthwith automatically reoperate on its normal level. The element M10 will function after the directive initiation of its hunting as if it had been automatically initiated. If there are no idle lines in the attendant's group, the busy tone will be again applied, whereupon the automatic restoring of the shaft will re-occur, and the re-testing of the group may be directly initiated, as before. If the line of an attendant's group is seized under either the primary

hunting or a subsequent hunting, the signaling upon the seized line can be initiated by applying signaling current, as before, whereupon a special signaling current will be applied to the seized called line, indicative that the call is both a primary call and that it is from the toll switchboard. The call may be passed after the response, as before described, however, all calling signals (excepting recalls) will be from signaling current sources specific to the toll switchboard calling, so that by reason of the peculiar code or character, the called party will be prompted as to the origin of the call. An alternative method of employing the said preferred organization of the circuits in which Fig. 42 is introduced is effectuated by setting a switch-arm so that in lieu of automatically causing the restoration of the wipers of the element M10 forthwith, a common device causes periodic closed impulses to be applied, the purpose of which are to restore any shafts on busy to normal position, if the call emanates from the toll switchboard, and to forthwith automatically re-test the group of attendant's lines. This cycle of operations continuing until an idle said line is found, upon which the element will seize, preparatory to the operator directly initiating the application of signaling current to the seized line as before, upon the seized condition being noted, evidenced by the absence of the busy tone.

With reference to the last foregoing general statements, and with reference to the Fig. 42 and co-operating figures, it will be noted that retardation coil 191 is not changed in its relation to the circuits. Relay 695', operated from bank contact 35 in Fig. 6, serves to short-circuit the windings of the retardation coil 191, as before. However, relay 695' involves addition functions in the present instance. It will be noted that upon the relay 63 in Fig. 10 actuating, the element M10 will forthwith rotate its shaft in a hunting operation, due to conductor 68 being grounded at the resting contact of the upper armature of relay 701'. Relay 695' being actuated, when the shaft moves off-normal conductor 202' will become grounded, causing relay 701' to actuate and lock to conductor 64. It will remain so locked throughout the call. This will disconnect sources G9 and RG9, to disable the connector against applying signaling current. Ground is applied through switch-arm SA42, armature 702' to resting contact leading from terminal n, and to armature 313 in element N11, so that if the line last tested is found busy the relay 123 will be caused to actuate and cause the motor magnet M9 to function as before described, wherein the release magnet Re10 will operate to restore the shaft of element M10 to normal position. The upper armature of relay 695' being attracted ties arm-

ture 312' by way of terminal *t* to terminal *m*. This insures that the locking ground for the busy relay 91 will not be opened, notwithstanding that the off-normal springs ON10 restore, and the busy tone will be maintained and the rotary magnet will be disabled at armature 74, so the shaft will not automatically rotate-in. When the toll operator wishes to re-test the lines of the normal level, the key R4 will be depressed, whereupon the relay 692 in connector J6 will operate and relay 695' will deactivate. This will cause armature 703' to apply its ground through armature 704' to the winding of relay 705'. The latter relay will operate momentarily, to no operative purpose, since conductor 202' is not grounded. The path between terminals *t* and *m* will be opened at the upper armature of relay 695', so that relay 91 will unlock and disconnect the busy tone. Under the condition last existing, conductor 68 is ungrounded due to the retracted condition of armature 703', so the rotary magnet R10 will not be energized. However, upon the cessation of the application of signaling current from key R4, wherein relay 695' reactivates, ground from armature 703' will be applied through the upper armature of relay 701', conductor 68 to the rotary magnet R10, to initiate the hunting operation as primarily automatically initiated from the upper armature of relay 701'. If the lines hunted-over are found busy, the shaft will be automatically restored as before, the busy tone being maintained until directly disconnected, and re-testing incidentally re-initiated. If a line is seized on the second testing (or if seized the first time tested incidental to the primary seizure of the trunk), no signaling current will be applied to the said seized line due to the fact that relay 701' is actuated and relay 705' is normal. However, upon the toll operator applying signaling current, operative to relay 692, wherein relay 695' will deactivate, the relay 705' will actuate and lock to conductor 202'. This will connect signaling current sources TG9 and TRG9 in lieu of signaling current sources G9 and RG9, respectively, it being understood that short conductors *p* and *q* in Fig. 9 are removed when introducing Fig. 42. Under this condition, the seized line will be signaled from source TG9. And since source TRG9 has been substituted for source RG9 lines called from a passing operation will be signaled from the source TRG9. In view of armature 312' being attracted and locked incidental to the first response, the false locking of the busy relay 91 cannot occur under a passed condition.

The cam E42 is arranged to be operating continuously so that the spring set *e*42 will be operated periodically. This will close the ground to the switch-arm SA42 if it is placed in the position indicated by the dotted lines.

Then, under this condition, if a busy line is encountered by the element M10 in the initial hunting operation, the release magnet R10 will not be operated until the spring set *e*42 operates to close the ground to terminal *n*, 70 so the relay 238 will operate, but not lock because of its locking path being open at off-normal spring 231 in element N11. This will cause the shaft of element M10 to be restored to normal, and due to relays 695' and 701' being actuated, the automatic hunting operation will be forthwith automatically re-initiated. The absence of busy tone will index to the toll operator that the element M10 has seized an attendant's line, whereupon the key 80 R4 may be depressed, causing relay 695' to deactivate and relay 705' to actuate and lock, applying the signaling current sources as set forth before.

In this connection it will be noted that if 85 the toll operator should inadvertently apply signaling current effective to causing relay 695' to deactivate and relay 705' to actuate and lock under the last before method of operation, under the condition of the wipers of element M10 resting on the bank terminals of a busy line, no signaling current will be applied to the line the wipers may be resting upon, due to the fact relay 113 has not actuated due to relay 91 being actuated. Then, 90 when the cam E42 causes ground to be applied to terminal *n* to effect the restoration of the shaft of element M10 the relay 705' will unlock, the shaft forthwith automatically re-initiating its hunting operation. 100

In this connection, it will be understood that the various signaling current sources may be of different character, or interrupted differently, perhaps, so that definite code signals may be applied therefrom, indicative of the condition under which the signaling current is applied, due to the source operating. While different characters of current, such as different frequencies, for example, may be employed, differently effective to the same signal device, it will be further understood that the signal devices may be responsive to a particular character only, and that therefore, a plurality of signal devices may be employed on a called line, only the signal device specific to the character of current applied being operative. The signal device functioning will thus index the condition ensuing. 111

The organization of equipments shown in Figs. 24-43 and in 33-44 are generally similar and do not effect the switching equipment to the left of the passing call connectors. In assembling the figures in accordance with Fig. 33 lines in Figs. 9 and 26 which do not register with lines on adjacent sheets are to be ignored. It will however, be pointed out that the passing call elements A25 and B26 do not have a vertical movement, and therefore, are limited in capacity to the number of bank contact sets in the normal level in which they 125 130

respectively operate. This type of passing call connector will be used in the present system where a concerned subscriber's group involves but a single level in the local connector, though it will be manifest that it could be employed to the limit of its level capacity by proper adaptations, such as are employed in connectors well known in the art, wherein they have access to twenty-five lines or more on a normal level. The greater simplicity and lower cost involved in the passing call connector wherein it does not have a vertical movement, lends itself to one of the objects of the present invention directed to making it commercially practicable to arrange subscriber groups of a relatively few substations, three or four, for example, so that they may inter-call through the agency of main office equipment.

It will be remembered that in the case of element M10, the normal level thereof was reserved for completing the primary call to one of the lines of the subscriber's group designed to respond to in-coming traffic. The levels above in the case of both elements M10 and N11 were reserved for passing calls only. With relation to the respective corresponding elements A25 and B26, the lines of the subscriber's group reached through a directive passing operation, occupy the first bank positions while the lines arranged to be automatically hunted over and seized, consequent to the trunk being seized, occupy bank positions following. That is to say, when a call has been completed to the trunk, the element A25 will automatically rotate its wipers over the lines reachable by a passing operation, ignoring their busy or idle state, and will then hunt and seize the first idle answering line encountered, it being borne in mind, that the answering lines may, and in most cases would, be multiplied into the contacts before passed over primarily. However, they may be subsequently reached in a passing operation.

In carrying out the foregoing plan involving elements A25 and B26, when the trunk is seized by connector J6, the element A25 will automatically initiate the operation of its shaft through the agency of the rotary magnet R25. The private and rotary wipers are normally disassociated from the circuits of the element A25. A cam C25 operating the spring set c25 serves to apply a ground on the circuits of the element A25 corresponding to the private and the rotary wipers, respectively, so that the rotary magnet will be caused to continue its cycle of operation automatically as long as this condition of the circuit exists, the rotary features of the element A25 (also element B26), being similar to the rotary features of elements M10 and N11, and in fact, generally similar to the rotary features in themselves in well known types of automatic switches. However, the cam C25, mounted on the shaft of

the element A25, is so designed that it will operate its cooperating set of springs c25 incidental to the first rotary movement of the shaft and will maintain the set c25 operated until the wipers have rotated-off of the last set of bank contacts reserved for reaching the substation lines of the group through a directive passing operation only. The cam D25, which is mounted on the shaft of the element A25, is designed to operate its cooperating set of springs d25 incidental to the wipers engaging the first set of bank contacts following those last referred to. That is to say, the spring set d25 will operate upon the wipers testing the set (being the first set following local group) of bank contacts corresponding to the trunk. The contacts c25 remain operated over the further, forward movement of the wipers. In view of the fact, that the spring set c25 is in its normal state when the set d25 is operated, it will appear presently that the element A25 is now capacitated to hunt and seize as a group selecting connector, wherein it will cause a busy tone to be projected audible to the calling party if the last set of bank contacts tested presents a ground to the private wiper 709 but does not present a ground to the rotary wiper 708 due to the cooperating bank contacts not being tied together. It will be understood in this connection, that the answering lines occupying the last group of bank positions may be multiples of local lines appearing in the first group passed over automatically, wherein their busy or idle conditions has been ignored, due to the false condition set up in the circuits of the element A25 through the agency of the spring set c25.

It will appear presently that upon a response being obtained from an attendant's line, that relay 701 in element A25 will be caused to actuate and lock in the manner generally similar to that wherein relay 121 of element M10 actuated, and under this condition, the set of springs c25 will be disabled against affecting the circuits of the element A25, so that the element A25 will be capacitated to be operated directly and will function dependent upon the conditions existing upon a set of bank contacts engaged by its wipers.

With the last foregoing general statements in mind, and in view of the statements made at the outset, it will be assumed that the figures are assembled in accordance with the diagram shown in Fig. 33, and that a call initiated at substation S to the first trunk terminated by the passing call connector elements A25 and B26 has been effected in the manner as hereinbefore described wherein the passing call connector involving elements M10 and N11 were concerned in lieu of those now assumed. A circuit can now be traced from the upper winding of relay 702, conductors a51 and 51, spring 52 and over the

traced path including the receiver of the calling substation S, spring 60, conductors 61, 62 and a62 to the lower winding of relay 702, the latter said relay actuating. A circuit can now be traced from the winding of slow-releasing relay 703 to the grounded armature of relay 702, relay 703 actuating by way of applying its grounded upper armature to conductors a64 and 64, and over the 10 path previously traced. However, in the present instance, in view of Figs. 27, 28 and 29 having displaced Figs. 15, 13 and 14, respectively, the ground on conductor 495 will be communicated over conductors b495, 930, 15 and attachments, to guard the trunk against seizure through a line switch such as D28, E28 and F29. Ground received from armature 67, conductors 68 and a68, off-normal set RO25 (set RO25 operating incidental to 20 the first off-normal movement), armature 704, lower armature of relay 703, armature 705, winding of slow-releasing relay 706, armature 707 to the winding of rotary magnet R25, operates to advance the wipers 708 to 25 711 into engagement with the first set of bank contacts 712 to 715, respectively. Conductors 716 and 717, which attach to the rotary wiper 708 and the private wiper 709, respectively, are free and therefore, the condition found by wipers 708 and 709 can have 30 no operative effect upon the functioning of element A25. However, in view of the spring set e25 being operated, wherein the armatures 718 and 719 are grounded, this 35 ground can be traced through the make-before-break spring 720, conductor 721, make-before-break spring 722 (relay 706 having actuated coincident with the operation of the rotary magnet R25), to the winding of busy relay 723, the latter relay actuating, incidentally, closing a circuit from the upper winding of slow-releasing relay 725, upper armature of relay 723 to ground through contact set b25. In this connection 40 it will be stated that the contact set b25 is periodically operated through the agency of cam B25, driven by a continuously running mechanism, and may be common to the exchange. The spring set b'25 operated by the 45 cam B'25 is similarly driven, perhaps on the same shaft with the cam B25, but timed differently as indicated. There would be as many cams of the type of B25 and B'25 and cooperating spring sets b25 and b'25, respectively, as there are passing call connectors belonging to a single subscriber's group, the result being that regardless of the number of passing call connectors, that a subscriber may have, terminating corresponding trunks, 50 a spring set corresponding to b25 may be chosen for each passing call connector, all being timed differently, the object of which will appear presently.

Continuing the descriptions, upon the relay 706 having deactuated, the relay 723 is

locked through spring 722, armature 724, armature of relay 725, conductor 721, armature 719 to ground through the spring set c25.

The set of off-normal springs ON25 is designed to operate upon the first off-normal movement of the shaft of element A25, and therefore, should the spring set b25 open at this juncture or was open, wherein the relay 725, either did not actuate as described, or has deactuated, the locking circuit for relay 723 would be by way of make-before-break spring on relay 725 to grounded spring 726.

Upon relay 706 deactuating its period after the ground impulse from armature 67 through it terminated, and bearing in mind that relay 723 is still maintained locked either to spring 726 or over conductor 721, a circuit can be traced from spring set c25, armature 718, conductor 727, armatures 726', 728, interrupter contacts of rotary magnet R25, armature 729, winding of relay 730, lower winding of relay 725 to grounded battery, relay 730 actuating, and relay 725 actuating if it is not already actuated under the influence of cam B25. A locking circuit for relay 730 was thus established through armature 729, interrupter contacts on the rotary magnet, armature 728, upper armature of relay 730 to spring 726. Incidental to the actuation of relay 730, a circuit is established from spring 726, lower armature of relay 730, armature 707 to the winding of the rotary magnet, operative to advancing the wipers 708 to 711 into engagement with bank contacts 731 to 734, respectively, the locking circuit for relay 730 being incidentally opened by the interrupter contacts of the rotary magnet, whereupon it deactuates to be again energized and locked upon the interrupter contacts of the rotary magnet closing the circuit previously traced, the rotary magnet again operating to advance the wipers 708 to 711 into engagement with bank contacts 735 to 738, respectively, whereupon the cam C25 causes the spring set e25 to disengage its contacts and the cam D25 causes its set of contacts d25 to operate by way of connecting conductors 717 and 721, and conductors 716 and 727, respectively, so that the wipers 708 and 709 are now connected to conductors 727 and 721, respectively, and that wipers 708 and 709 are free of ground derived through the spring set c25. The last foregoing assumed that there are three local lines reachable through a directive passing operation, and it will be borne in mind that if there were a greater number, that the cams C25 and D25 would be adjusted to operate upon the wipers rotating-off the last set of bank contacts so reserved. Bank contact 739 is normally grounded over conductors 740 and 86, armature 87, armature 88 to ground- 120 ed resting contact. Bank contact 741 is electrically tied to bank contact 739 and thus,

both wipers 708 and 709 will receive ground, and in view of the fact, that spring set $d25$ is now operated, the circuits of the element $A25$ are as if armatures 718 and 719 were receiving ground from the spring set $c25$, and therefore, the rotary magnet $R25$ will continue its operation by way of rotating the wipers 708 to 711 into engagement with bank contacts 742 to 745, respectively. A circuit can be traced from bank contact 742, conductor 746, upper armature of relay mechanism $C27$, conductor 747 to bank contact 743, conductor 747 being grounded through armature 748 and its resting contact, so that bank contacts 742 and 743 are not only tied together, but are grounded, and therefore, the wipers 708 to 711 will be rotated into engagement with bank contacts 749 to 752, respectively, corresponding to the attendant's 10 15 20 25 30 35 40 45 50 55 60 65 70 75 80 85 90 95 100 105 110 115 120 125 130 substation $S17$. The purpose of relay mechanism $C27$ will appear presently.

The line leading to substation $S17$ will be assumed to be disengaged, and therefore, bank contact 750 will not constitute ground potential but will constitute battery potential derived through motor magnet $M29$, switching relay 753, conductors 754 and 755. The relay 723 which has been held actuated, in view of the slow-releasing characteristics of relay 725, has been maintained locked during the automatic rotation of the wipers described, from ground received over wiper 709. But in further view of the fact, that wiper 709 does not now receive ground but does receive battery in lieu thereof, the relay 723 will deactivate, followed by relay 725. A circuit can now be traced including the battery applied to wiper 709, conductor 717, contacts of spring set $d25$, conductor 721, upper armature of relay 706, outer winding of switching relay 756, armature 724, make-before-break spring of relay 725 to spring 726, relay 756 actuating, whereby a locking circuit for same is closed from its inner winding and cooperating armature to spring 726. The upper armature of relay 756 applies its ground to the upper armature of relay 706, thus placing ground on the outer winding of relay 756, which just previously derived battery, and applies ground over conductor 721, contacts of spring set $d25$, conductor 717, wiper 709 to bank contact 750 and attachments. The line switch $F29$ being like line switch $R14$, it is thought that a detailed explanation of its operation is not necessary for a clear understanding of its functioning in this relation, and in descriptions to follow.

A circuit can now be traced from grounded signaling current source $G9$, conductors 119 and $a119$, lower armature of relay 701, conductors $a122$ and 122, upper winding of relay 123, conductors 124 and $a124$, upper armature of ring-cut-off relay 757, armature 758, wiper 710, bank contact 751, conductors 759, 65 70 75 80 85 90 95 100 105 110 115 120 125 130 135 140 145 150 155 160 165 170 175 set of bank contacts corresponds to the line leading to substation set S20 which will be assumed to be busy, and therefore, conductor 777 leading from line switch D28 and attaches to conductor 778 causes ground to exist on bank contact 774. The line switch D28 being like line switch R14, it is thought that a detailed explanation of its operation is not necessary for a clear understanding of its functioning in this relation and in descriptions to follow.

Under the condition of wipers 708 to 711 engaging bank contacts 773 to 776, respectively, wherein bank contact 774 constitutes ground, the wipers will not be caused to automatically rotate-off, due to the fact that bank contact 773 is free, and therefore, it does not constitute ground. It being borne in mind that the automatic rotation is dependent upon the conductors attached to or corresponding to the wiper 708 receiving ground, either from an engaged bank contact or from a false condition applied through the agency of the spring set b25, as has been described. Therefore, under the condition, relays 730 and 725 will not become energized from ground derived through wiper 708, so that upon the retraction of the upper armature of relay 725, the locking circuit for relay 723 will be to spring 726, in the manner as before described, and therefore, not dependent upon the ground continuing through the wiper 709, it being remembered that this ground on wiper 709 will continue only as long as the line leading to substation set S20 remains busy. Relay 725 being deactuated, and relay 723 being actuated, grounded tone source T25 will be applied through armature 779, lower armature of relay 725, lower armature of slow-releasing relay 780, condenser 781, conductor a62 and over the traced path including the receiver at calling substation S, conductor a51, condenser 782, upper armature of relay 780, upper winding of relay 767, conductors a189 and 189, upper winding of retardation coil 191 to grounded battery.

One of the novel features of the passing call connector involving elements A25 and B26 is in connection with the cam B25 and contact set b25 hereinbefore referred to. Having in mind the periodic operation of the spring set b25, it will appear that the relay 725 will periodically actuate due to its upper winding becoming energized through the upper armature of relay 723, and the spring set b25, and under such condition, the locking circuit described maintaining relay 723 will be opened at the make-before-break spring of relay 725 and transferred to conductor 721 leading to wiper 709. If the wiper 709 is grounded at this time, relay 723 will not unlock, and when the contact b25 opens and relay 725 deactuates resultant thereto, it will cause the locking circuit of relay 723

to be re-applied to off-normal spring 726. However, if when the relay 725 actuated from spring set b25 as last described, the line leading to substation set S20 was not then busy, and therefore, the wiper 709 will not constitute ground, the locking circuit for relay 723 will become opened and it will deactuate, whereupon when relay 725 deactuates, a circuit can be traced from spring 726, make-before-break spring on relay 725, 75 armature 724, outer winding of relay 756, upper armature of relay 706, conductor 721, spring 720, conductor 717, wiper 709, bank contact 774, conductors 778, 777, winding of switching relay 783 to the winding of motor magnet M28, the relay 783 actuating in the manner set forth with reference to the corresponding relay in line switch R14, and the relay 756 in element A25 actuating (and locking in the manner as before described in effecting the seizing functions of the latter said element when the line leading to substation set S17 was assumed seized), and the signal bell at substation S20 operated.

Going back to the condition, wherein the party at substation S17 responded, it will be assumed that the calling party desires connection with substation SJ20, the telephone number of which is "3". Upon the party at substation S17 manipulating the calling device thereat in accordance with the said digit "3", the relay 767 will deactivate and reactuate three times responsive thereto, whereupon ground will be applied from its lower armature, armature 784 to the winding of relay 780, causing it to actuate momentarily, and over conductor 785, armature 786, winding of relay 787, armature 788 to the winding of rotary magnet R26, operative to advancing the wipers 789 to 792 into engagement with bank contacts 793 to 796, respectively. It will be assumed that the line leading to substation SJ20 is idle, and therefore, conductors 797 and 798 do not constitute ground, but does constitute battery potential, it being understood that the line switch E28 is like line switch R14, and it is therefore, thought that a detailed explanation of its operation is not necessary for a clear understanding of its functioning in this relation, and in descriptions to follow. Upon the wiper 790 engaging bank contact 794 and deriving battery therefrom, will insure that busy relay 799 will be deactuated, even though it may have actuated due to wiper 790 passing over antecedent grounded bank contacts, so that upon the relay 787 deactuating following the last impulse to the rotary magnet R26, a circuit can be traced from the battery derived through motor magnet M'28, switching relay 800, conductors 797, 798, bank contact 794, wiper 790, conductor 801, upper inside armature of relay 787, outside winding of switch- 120 125 130

ing relay 802, armature 803, make-before-break spring 804 to grounded spring 805 of off-normal set ON26. The latter said off-normal set is adjusted to operate upon the 5 first off-normal movement of the shaft carrying wipers 789 to 792. The relay 802 will actuate under this condition and will be locked from its inner winding and cooperating armature to spring 805.

- 10 Attention is called at this time to a function with relation to relays 767, 780, 802 and 787, and under certain conditions relay 799 in lieu of relay 802. It is to be understood that the functions about to be described with 15 relation to the latter said relays, will apply to corresponding relays 806, 807, 756, 706 and 723, respectively. And, it will also apply to the corresponding sets of relays in elements M10 and N11. At the time that the relay 767 20 deactuated and reactuated three times, wherein in the relay 780 actuated and sustained over the lapses as did, also relay 768, it is necessary that the relay 787 shall be adjusted to have a releasing characteristic that will insure that 25 it will not deactuate until after relay 780 has done so, as otherwise, a circuit will exist from the upper armature of relay 767, armature 808, conductor 809, upper armature of relay 787, armature 810, through off-normal 30 springs to the winding of the release magnet Re26. Under the condition, as will appear presently, wherein the relay 799 will actuate in lieu of relay 802, and in fact, may actuate while the wipers are rotating over busy 35 bank contacts under directive control, the attracted condition of the upper armature of relay 787 prevents a false restoration of the shaft of the element B26.

- Upon the relay 802 actuating and locking, 40 upon wipers 789 to 792 engaging bank contacts 793 to 796, respectively, a circuit can be traced from signaling current source RG9, upper armature of relay 238, upper winding of relay 239, conductors 240 and a240, armatures 812 and 813, wiper 791, bank contact 795, conductors 814, 815, a246, 246, and over the previously described path including the receiver at substation SJ20, conductors 247, a247, 816, 817, bank contact 796, wiper 792, 45 lower armature of relay 802, armature 818, inner winding of ring-cut-off relay 819 to grounded battery, the signal bell at substation SJ20 operating but the relay 819 not actuating due to the condenser in the traced 50 path.

- Assume that the party at substation SJ20 55 responds and that a conductive path including the inner winding of relay 819 is closed, whereupon the latter said relay will actuate and lock its outer winding through armature 820, spring 821, conductors a143, 143, to spring 144 in Fig. 9. A circuit path can now be traced from grounded armature 820, lower winding of relay 806, armature 818, lower armature of relay 802, wiper 792, bank

contact 796, and over the traced path including bank contact 795, wiper 791, armatures 813, 812, upper winding of relay 806, conductors a327, 327, lower winding of retardation coil 191 to grounded battery, relay 806 actuating. Slow-releasing relay 822 will be operatively energized to the lower armature of relay 806. The calling party at substation S, the first called party at substation S17 and the party at substation SJ20 are now in talking relation. 75

Assume that the party at substation SJ20 wishes to directly disconnect the line leading to substation S17. He will send one open impulse constituting digit "1" to cause relay 806 to deactuate and reactuate one time responsive thereto, wherein the slow-releasing relay 807 will be caused to actuate so that when the upper armature of relay 806 re-attracts it will close a circuit through 85 armature 823, conductor 824, armature 825, off-normal springs to the release magnet Re25, operative to restoring the shaft of element A25 to normal position. And likewise, should the party at substation SJ20 90 desire to disconnect the line leading to substation S17 from the connection, he will send digit "1" to cause relay 767 to deactuate and reactuate one time wherein relay 780 will actuate and a circuit will be completed from 95 the upper armature of relay 767, armature 808, conductor 809, armature 810, off-normal springs to the release magnet Re26, operative to restoring the shaft of element B26 to normal position. 100

Assume that the bank contact 794 constituted ground when engaged by wiper 790, to the line leading to substation SJ20 being busy. Under this condition, the relay 799 would be actuated due to a path being completed from said ground, wiper 790, conductor 801, armature 826, make-before-break spring 827 to the winding of said relay 799, preparing a locking circuit at armature 803, so that when relay 787 deactuates, the relay 799 will be locked by way of spring 827, armature 803, spring 804 to spring 805. Tone will be applied from grounded source T25, lower armature of relay 799, lower armature of slow-releasing relay 828, lower armature 110 of relay 807, condenser 829, conductors a51, 51, spring 52, over the described path including the receiver at substation S, and also, the receiver at substation S17, conductors 61 and a61, condenser 830, upper armature of relay 807, upper winding of relay 806 to grounded battery, over the before traced 115 path. 120

Upon the parties perceiving the busy tone, the call passed to the line leading to substation SJ20 can be destroyed by the party at substation S17 replacing his receiver on the switch-hook for a prolonged period, whereupon a circuit path can be traced from ground on armature 769, armatures 771, 831, conductors 125 130

tor 832, upper armature of relay 802, off-normal springs to release magnet Re26, operative to restore the shaft of element B26 to normal position. In lieu of restoring the receiver for a prolonged period, sending the digit "1" (or flashing the switch-hook), will cause a ground impulse to be applied from the upper armature of relay 767, armature 808, conductor 809, upper armature of relay 787, armature 833, off-normal springs to release magnet Re26. If it is desired to permit the calling party to hold the connection awaiting the idleness of the line leading to the substation SJ20, the party at substation 15 S17 will replace his receiver, but under such condition his line will not be disconnected from the connection (as release magnet Re25 will not operate because thereof), as long as the busy condition endures. Bearing in 20 mind the functioning of cam B25 and the fact that the upper armature of relay 799 is attracted, it will be manifest that the upper winding of relay 828 will be periodically energized to disengage spring 804 from its resting contact, so as to periodically substitute the path through the wiper 790 for the path through spring 805, in order to effect the seizure of the line corresponding to the engaged bank contacts in the event it becomes 25 idle, in the manner as has been fully described with relation to the element A25. When the bank contact 794 is found idle, the element B26 will seize and apply signaling current as if the line were found idle primarily, armature 834 applying its ground to guard the seized line against intrusion and to disassociate the line relay 835 in the line switch E28. Element A25 is still engaged with the bank contacts corresponding to the line leading 30 to substation S17, but since the current from source RG9 applied through the bell of substation SJ20 is derived through the upper winding of relay 239, the latter relay will actuate corresponding to the periods of application of the current, bearing in mind that current from the source AG9 will sustain the relay for a further period, the current from the source AG9 not being effective to the signal bell. In view of the previous descriptions with reference to Fig. 9, it will be manifest that ground on armature 769 (in Fig. 35 25) will be applied over conductors 770, 253, armature 254, conductors 255, a255, armature 836, conductors a259, 259, to the motor magnet M9, causing it to advance its wipers 260 and 261 into engagement with the second set of bank contacts. Bearing in mind that spring set RR9 is now operated, should the party at the substation S17 remove the receiver to initiate a new call, or perhaps, to 40 ascertain if the calling party is still waiting, a circuit can be traced from the release magnet Re25, off-normal springs, armatures 837, 838, conductors a281, 281, spring 280 in Fig. 45 9, to the lower armature of relay 239, the latter circuit being completed consistent with the actuated state of relay 239, which due to the source AG9 and its timing, will be practically constant, there being but a short lapse between ringing periods. Of course, 50 the well known expedient may be employed wherein grounded battery is substituted for the signaling current source at off ringing periods. The shaft of element A25 will thus be restored to normal position so that the line switch F29 will function as contemplated 55 when a call is initiated.

Assuming that in the latter described functioning, element B26 seized, upon the line leading to substation SJ20 becoming idle, 60 and, no response was obtained after five rounds of signaling current had been applied (the party at S17 not having initiated a new call), and therefore, the wipers 260 and 261 will have progressed into engagement with 65 the fifth set of bank contacts, spring set 144 will have opened, in the manner as has been set forth, unlocking relay 757. This will cause relay 266 to actuate, and its lower armature to apply ground to conductors 267'. 70 a267', through off-normal springs to the release magnet Re26, operative to restore the shaft of the element B26 to normal position, and by reason of the upper armatures of relay 266 being attracted and the said relay locked 75 over conductors 267, a267, lower armature of relay 757, upper armature of relay 819 to off-normal grounded spring 805, the signaling current source BG9 has been substituted 80 for the source RG9 with reference to the element A25, and the circuits of the latter said element are in the condition they were in after the line leading to substation S17 was seized, so that the party at the latter said substation is now receiving signals peculiar 85 to the source BG9, apprising him of the condition, whereupon he can respond. And in view of the shaft of the element B26 being in its normal position, is in readiness to receive 90 directive passing impulses from substation S17 by way of setting its wipers upon an alternative desired line.

Assuming that the party at substation SJ20 responded, wherein relays 819, 806 and 822 actuate responsive thereto, and having in 95 mind that the party at substation S17 has replaced his receiver, a circuit can be traced from the release magnet Re25, off-normal springs, conductor 839, armature 840, in element B26, conductor 841, armatures 831, 100 771, 769 to grounded working contact, operative to restoring the shaft of element A25 to normal position.

The shaft of element A25 being now at 105 normal position, the party at substation SJ20 can, if desired, pass the call and introduce the line leading to substation S17 by manipulating the calling device in accordance with digit "1", it being understood, of course, that any accessible substation line 110 115 120 125 130

would be similarly called by sending impulses corresponding to the digit representing the telephone number thereof. Upon the party at substation SJ20 sending the digit "1", whereupon relay 806 will deactivate and reactuate one time responsive thereto, a circuit can be traced from the lower armature of relay 806, armature 842 conductor 843, armature 705, winding of relay 706, armature 707 to the winding of the rotary magnet R25, the rotary magnet operating by way of setting the wipers 708 to 711 into engagement with bank contacts 712 to 715, respectively. Assuming that the line called is idle, the element A25 will function in the manner as described with relation to calling the line leading to substation S17 when it automatically functioned and its wipers 708 to 711 seized bank contacts 749 to 752, the bank contacts 713 to 715 being in multiple relation with bank contacts 750 to 752, respectively. Bank contact 712, companion to bank contact 713 is free, while bank contact 749 and its companion bank contact 750 have an electrical connection between them. It will therefore be noted, that if bank contact 713 constitutes ground, due to the line leading to substation S17 being busy, the wiper 708 (resting on bank contact 712), will not receive ground to cause the wipers to be advanced automatically as would be the case where the corresponding bank contact 749 engaged. Upon the party at substation S17 responding, wherein relays 757, 767 and 768 will actuate in sequence, the parties at substation S, SJ20 and S17 are again in telephonic relation this time however, the element A25 was directively operated. Relay 701 will remain locked until conductor a64 becomes ungrounded, thus maintaining armature 704 attracted to disable the automatic initiation of the rotary operation of the shaft of the element A25, and also, to maintain a circuit continuity between wiper 708, conductors 716, 727, and to maintain a circuit continuity between wiper 709, conductors 717 and 721.

Assume that it is desired to have all calls incoming to the group subscriber diverted to the substation S, which is directly tributary to the main exchange system, but which is provided with a branch connection over conductors 844, 845, 846, accessible to the passing call connector of the group subscriber and the local connectors associated therewith, so that direct connections may be affected to the substation S as if the latter said substation was a substation line of the group subscriber without other main office connection, though it will appear from previous descriptions that the line switch terminating the line from substation S is a part of the main exchange system. The arrangement contemplated in this connection would be employed, for example, wherein it

is desired to have all non-office hour calls received at a predetermined local substation, perhaps at the residence of someone connected with the subscriber's business affairs. It also affords constant direct access to substation S from the group.

In carrying out the last foregoing objects, the relay mechanism C27 is introduced, consisting of a duplex relay having a magnet 847 for attracting its cooperating armatures 75 wherein a dog 848 will retain them from retracting after the magnet 847 has become deenergized. A slow-operating magnet 849 is provided to attract the dog 848 out of engagement with the armatures so that they 80 will return to their normal position from their resilience. It will be noted that the winding of magnet 847 is connected to a wiper 850 in line switch D28. The latter line switch is individual to the attendant's or second choice responding line of the group subscriber, though manifestly, it could be so connected into any line switch of the group subscriber. It will thus appear that the relay mechanism C27 can only be controlled from 85 a single station though it will be manifest that the conductor leading to wiper 850 could be connected in multiplied relation with corresponding wipers of other line switches which would have access to bank contacts in 90 multiple relation with the bank contacts accessible to wiper 850. The object of having the relay mechanism C27 controlled from a specific line switch is to insure that unauthorized persons will not be able to operate it, 95 which could of course, result in diverting the traffic when it should not be.

It will now be assumed that the party at substation S20 desires to operate the relay mechanism C27 so that all incoming calls will thereafter be diverted to the substation S. A call will be initiated in the normal manner, whereupon the line switch D28 will seize the first disengaged trunk, which will be assumed to be the trunk leading to the local connector H30. Before proceeding with the functioning of the apparatus, consequent to the seizure of the trunk to the connector H30, it will be stated that the said latter connector contemplates that the 100 groups of lines leading therefrom will not occupy more than a level and that two groups may occupy a single level, if desired. Assuming that the levels have ten sets of contacts, though they would not be limited to this number, it would be possible to have a group of four and a group of five in a single level, for example. The connector forthwith, upon its being seized by a line switch 105 will automatically function by way of vertically stepping its shaft carrying its wipers into alignment with the level of bank contacts corresponding to the group containing the calling line, in readiness to be directly operated so that it will set its wipers 110 115 120 125 130

upon the set of bank contacts corresponding to the called local line, responsive to a single digit series. In case the first line of the group occupies bank contacts a plurality of 5 steps in from normal vertical position, the connector will be caused to further automatically function by way of setting its wipers one step preceding the first set of bank contacts thereof, preparatory to the connector 10 being directively operated by a single digit series to set the wipers upon the bank contact set of the called line. Another function of the connector H30 is that a set of off-normal springs ON'30 is provided equivalent to the off-normal sets ON'18 in connector U18 and ON'23 in connector Y23. However, in the present instance, the referred-to off-normal set ON'30 will operate 15 at the last rotary position at all levels. It 20 will appear presently that this operation can be effectuated by the calling party sending a digit series of ten open impulses, for example, to thus operate the shaft of the connector, or that a resistance of the value of $r'20$ may be introduced to cause the equivalent functioning. That is to say, for example, that impulses corresponding to the digit "0" may be sent and cause the line switch antecedent to the connector to un- 25 seize therefrom and hunt for a trunk to the main exchange, ignoring local trunks to connectors of the group containing H30, or that this can be similarly accomplished by depressing a key corresponding to K20, whereby 30 a resistance corresponding to $r'20$ is introduced into the calling line wherein the line switch will be unseized. It will forthwith hunt for a trunk to the main exchange in the manner as if impulses corresponding 35 to the digit "0" had been sent. When the line switch is caused to function by way of hunting for a main office trunk as stated, the connector will forthwith restore, available 40 for subsequent use.

45 Going back to the condition wherein the party at substation S20 removes the receiver from the switch-hook by way of initiating a call, a circuit can be traced from the upper winding of line relay 851, upper winding 50 of relay 852, make-before-break spring 853, conductors 854, 855, bank contact 856, wiper 857, armature 858; conductors $\alpha 180$, 180, through the receiver of calling substation S20, conductors 181, $\alpha 181$, armature 859, wiper 860, bank contact 861, conductors 862, 863, make-before-break spring 864, lower windings of relays 852 and 851 to ground, relays 851 and 852 actuating, whereupon a circuit can be traced from the winding 55 of slow-releasing relay 865, lower armature of relay 851 to resting grounded contact on make-before-break spring 866', the relay 865 actuating, its armature 867 engaging its cooperating grounded contact, 60 whereby ground is applied over conductors

868, 869, bank contact 870, wiper 871, armature 872 to conductor 777 before armature 873 of slow-releasing line relay 874 has had time to deactivate, consequent to the seizure of the line switch through the actuation of 70 relay 783. A circuit can now be traced from grounded working contact and upper armature of relay 783 in line switch D28, wiper 875, bank contact 876, conductors 879, 880, to the bank contacts of the first level in connector H30 accessible to the wiper 881 of the wiper set 881 to 884. The conductor 880 also attaches to segment 885, adapted to be engaged by wiper 886 while the shaft is moving vertically, but which becomes disengaged upon the shaft rotating-in. In the same manner, wiper 887 is adapted to engage (and disengage) segment 888. 75

A circuit can now be traced from grounded impulse source D30, off-normal springs, 85 upper armature of relay 851, upper armature of slow-releasing relay 889, upper armature of relay 865, spring 890 of off-normal set ON30 (the latter said off-normal set ON30 being adapted to operate upon the first off- 90 normal movement of the shaft), spring 891, winding of slow-releasing relay 892 to the winding of the vertical magnet V30, the latter said relay actuating and the vertical magnet operating to step the shaft carrying the 95 wipers 881 to 884, and 886 and 887 vertically. Upon the wiper 886 encountering ground on segment 885, this ground will be communicated through make-before-break spring 893, lower armature of relay 852, armature 894 100 to the winding of relay 889, the latter said relay actuating to open the path traced from the impulse source D30. The wipers 881 to 884 are now in alignment with the first level of bank contacts. It is manifest that the vertical operation referred-to would have continued had not the energizing circuit become opened by reason of the attraction of upper armature of relay 889, consequent to the wiper 886 encountering ground on segment 105 885, so should the conductor 880 have concerned a higher level, the shaft would have been automatically stepped into alignment with such higher level. In this instance, the lines leading to substations S17, 110 S20, and SJ20, are assumed to lead from the first level of the connector H30, though the level that it occupies is of no concern to the calling party, since the wipers do not have to be directly set into alignment therewith. The conductor 880 is individual to the connector H30 and to the group of line switches associated with the lines of the first level. 115

In view of the last foregoing it will appear, 120 that the only bank contacts and segments engageable by a wiper of a seized connector will be those specific to the group of lines of which the calling line is one, and that no other connector of the group com- 125

prising the seized connector will be concerned. It will appear presently that the connector will not be enabled to complete a connection through a set of bank contacts unless the wiper 881 receives ground from an engaged bank contact, so it will be manifest, that since only the bank contacts in the connector engageable to wiper 881, related to the group containing the line calling there-through will constitute ground, that the connector will therefore not be enabled to complete a connection through a set of bank contacts irrelevant to the group containing the calling line. In view of the fact that the connector will automatically set its wipers into alignment with the level containing the calling line, it will appear that where the entire level is reserved to the group containing the calling line, it will be impossible for the wipers to be set upon a line belonging to a different group because directive impulses will not be effective to the vertical magnet and will only be effective to the rotary magnet after a level has been automatically selected. However, if the level concerning the calling line contains two groups of which the calling line belongs to the first group, if the rotary position of a set of bank contacts of the companion group of the level is such as to be embraced by the limit of a series which may be transmitted from the sending device at the calling substation, it would manifestly be possible, to send such a digit series and thereby set the wipers upon the bank contacts of a line in the companion group. However, since the wiper 881 will not then receive ground, the connection cannot be completed, as will appear presently. Of course, if it is desired to have the substations of the two groups, occupying the single level, arranged for inter-calling, the ground connection to the bank contacts engaged by wiper 881 would be omitted, and in fact, the wiper 881 may be then omitted, but spring 866 will require permanent grounding. It will be manifest that since the wipers will become automatically set with relation to the inside group of the level, beyond the bank contact sets of the first group, calls cannot be completed from the second group to the first group, as to do that, the wipers would have to be rotated backward. So to carry out such a plan as the latter, the two group subscribers would need to be connected as a single group, so far as the bank contacts of the connector H30 are concerned, but would be handled as independent groups, as far as the passing call connectors are concerned having in mind the fact that the attendant's lines would be individually related to the passing call connectors of each group, but that the connections relating to the bank contacts of the passing call connectors concerned in directive passing of calls, would be connected to correspond with the bank positions

as they appear in the level of the connector H. That is to say, primary calls to the group subscriber, would be automatically completed to the answering lines of the called group, after which they may be directly passed to either group by sending a digit series corresponding to their numerical bank position. The wiper 881 (and cooperating bank contacts) would have no function in the latter case.

Returning to the relay mechanism C27, it will now be assumed that upon the initiation of the call wherein the connector H30 automatically functions as has been set forth, wherein its wipers have become into alignment with the first level of bank contacts, that the condition is to be set up wherein all calls to the concerned group will be automatically diverted to substation S. To effectuate this condition, the calling party will send digit "3", being that digit reserved for the specific purpose. Relays 851 and 852 will deactivate and reactivate three times responsive thereto, wherein three ground impulses will be applied from grounded conductor 880, segment 885, wiper 886, upper armature of ring-cut-off relay 895, spring 895, lower armature of relay 852, armature 894, armature 896, spring 890, spring 897, armature 898, armature 899, armature 900, to the rotary magnet R30, the rotary magnet operating by way of setting the wipers 881 to 884 upon bank contacts 901 to 904, respectively, and wherein slow-releasing relay 905 will operate to multiple with the rotary magnet for objects hereinbefore set forth with relation to connectors, having generally similar rotary mechanisms. It will be manifest from the foregoing that had conductor 880 not constituted ground, the described impulse path to the rotary magnet R30 could not have been completed, and in any event could not be completed when the wiper 881 engages a bank contact without the group containing the calling line, as would be the case if the wipers were rotated into a second group of a level by calling a single digit wherein the calling line belonged to the group occupying the first division of the level.

It will now be assumed that upon the wipers 881 to 884 engaging bank contacts 901 to 904, respectively, the relay mechanism C27 is normal, and therefore, a circuit can be traced from ground, through winding of magnet 847, wiper 850, conductor 906, bank contact 902, wiper 882, make-before-break spring 907, upper armature of relay 905 and its make-before-break spring, armature 908 to the winding of busy relay 909, the latter said relay actuating, and upon its actuation prepares a locking circuit for itself and its upper armature, so that when relay 905 deactivates, a circuit can be traced from the winding of relay 909, armature 908, make-before-break spring of relay 905, upper armature 130

of relay 909 to grounded armature 867. The calling party will perceive tone from grounded source T30, lower armature of relay 909, conductor 910, conductor 863, over the traced path including the receiver at the calling substation, conductor 854, conductor 911, upper winding of reversing relay 912 to grounded battery. The armatures of magnet 847 will become attracted consequent to the establishment of the traced path, whereupon magnet 849 will become energized in parallel with magnet 847, but due to its slow-actuating characteristic and the stiff adjustment of the dog 848, its energizing circuit will become opened at the upper armature of relay 909, before the dog can be operatively attracted, so that the armatures attracted by the magnet 847 will remain in their operated positions. Ground will thus be removed from conductor 747 leading to bank contact 743 and the short-circuit will be removed from between conductors 746 and 747. Furthermore, bank contact 743 is now connected through armature 748 to conductor 913 which attaches to bank contact 732 and to conductor 844, which latter leads to the winding of relay 2 in line switch A, and, to private bank contact 914 accessible to connector L7. It will thus appear that if the line leading to substation S is busy, and that therefore, conductor 844 will constitute ground, that this ground will be communicated to bank contact 743, so that under the condition of the element A25 initially functioning from normal, as has been described, it would not be enabled to rotate beyond the set of bank contacts 742 to 745, by reason of the fact that the wiper 708 will not receive ground from bank contact 742. However, the relay 723 will actuate and lock to apply the busy tone audible to the calling party in the manner as hereinbefore described. If the bank contact 743 does not constitute ground, due to the fact that the line leading to substation S is idle, signaling current from source G9 will be applied over wiper 710, bank contact 744, conductors 915, 845, through the bell at substation S, conductors 846, 916, bank contact 745, wiper 711, the bell at substation S operating and the element A25 functioning as hereinbefore described when applying signaling current to a primarily seized line. Upon the party at substation S responding, he will become in talking relation with the calling party in the manner as hereinbefore described, excepting, of course, that in the present instance, it will be assumed that some other substation of the main exchange is the calling line. It will be manifest that nothing has occurred to restrict the calling of the lines of local substations, either as affecting passing operations, wherein the party at substation S may pass the call in the manner as has been described, or that local substations can pass and inter-call normally, and moreover, nothing has occurred affecting the line leading to substation SJ20, so that local substations can reach it through connectors of the group containing H30, or pass calls to it through the agency of the passing call connectors of the concerned subscriber's group by providing corresponding bank contacts accessible to the wipers of the respective switches. The latter have been omitted in order not to unduly involve the drawings.

It now being clear how the primary calls can be diverted to a predetermined substation, it will be manifest that this feature can be carried out concerning any plurality of the answering lines with respect to a corresponding plurality of other lines (which may be exchange lines or a line, or lines), of the concerned subscriber's group. Where a plurality of lines would be concerned, contacts would be added to the magnet 847, connected to correspond with those shown, but with reference to the next succeeding set of bank contacts, for example.

To restore the condition, so that calls will go to their normally arranged lines, the party at the station having set up the condition previously will initiate the call and send the digit "3" as before, whereupon the connector H30 will function in the like manner, but due to the winding of magnet 849 being applied to ground through the lower armature on magnet 847, it will operatively attract the dog 848 at the time the armatures are attracted by the magnet 847, and due to the magnet 849 having a slow-releasing characteristic, the armatures of magnet 847 will retract upon the circuit energizing the magnet 847 being opened by relay 909 before the dog 848 has retracted. The calling party will perceive the busy tone in the manner before described when setting up the condition in the relay mechanism C27. Upon replacing the receiver, under either condition, the energizing circuit for relays 851 and 852 will become opened, causing relay 865 to deactivate and unlock 909, whereupon a circuit can be traced from spring 866, lower armature of relay 851, lower armature of relay 865, off-normal springs, to the release magnet Re30, operative to restore the shaft.

In this connection, it will appear that if the conductor leading to spring 866, be detached and then attached to spring 866', if the wipers are set upon a set of bank contacts wherein wiper 881 does not receive ground, when the connector H30 seizes and spring 866' is flexed from its grounded contact, the relay 865 will deactivate and restore the shaft, as set forth.

It will be assumed that the party at substation S20 desires to call the party at substation S7. The call will be initiated as before wherein the connector H30 is seized, and automatically functions to set its wipers into

130

alignment with the first level of bank contacts. It will be further assumed that the digit "0" is sent to rotate the shaft operative to the off-normal set ON'30 in the manner as hereinbefore described with reference to the sending of digit "3". Ground will be applied to conductors 917, 918, bank contact 919, wiper 920, upper make-before-break spring of slow-releasing relay 921, operative to the said latter relay in the manner as hereinbefore described with reference to line switch R14. The line switch D28 will therefore unseize and rotate its wipers, so that wipers 871, 875, 857, 860 and 922 are now in engagement with bank contacts 923, 924, 925, 926 and bar 927, respectively. The line switch D28 will seize due to the fact that wiper 871 will not encounter ground potential due to the corresponding trunk being idle, as will appear presently.

A circuit can now be traced from the winding of relay 476 in line switch D3, conductors 477, 56, make-before-break spring 478, winding of relay 479, conductors 480, b480, 928, bank contact 925, wiper 857, armature 858, conductors a180, 180, receiver at substation S20, conductors 181, a181, armature 859, wiper 860, bank contact 926, conductors 929, b487, 487, spring 488, spring 58, conductors 57, 488', armature 489 to grounded resting contact, the relay 476 actuating, and the line switch D3 functioning, in the manner as before described, to seize selector B. Relay 479 (in Fig. 8), will actuate followed by relay 502, and relay 491 will actuate in the manner as hereinbefore described. A circuit can now be traced from the upper winding of relay 702 (in Fig. 25), conductors a51, 51, spring 52, spring 53, armature 492, spring 60, conductors 61, 62, a62, to the lower winding of relay 702, the relay 702 actuating, followed by its dependent relay 703. Ground is applied from the upper armature of relay 703, conductors a64, 64, spring 494, conductors 495, b495, 930, bank contact 923, wiper 871, armature 872, winding of relay 783, to motor magnet M28, operative to sustaining the seizure of line switch D28 preparatory to armature 873 therein retracting.

The condition as regards the element A25 is as described with relation to the trunk leading thereto, having been seized by the connector J6, however, due to the relay 491 (in Fig. 8), being actuated, its armature 88 is applied to battery potential, so that the bank contacts 741 and 739, accessible to wipers 708 and 709, respectively, of element A25, will now constitute battery potential in lieu of the normal ground condition. Under the present condition, the wipers will not rotate beyond the latter said bank contacts. Bearing in mind that armature 67 in Fig. 8, is resting upon its grounded contact, and that the rotary movement of the shaft of element A25 is thus automatically initiated, and in

view of the functions of cams C25 and D25, the wipers 708 and 709 will be caused to rotate off the first three sets of bank contacts and into testing engagement with bank contact sets 741 and 739, respectively. In view of the latter two contacts constituting battery potential, the relay 756 (in A25), will be caused to actuate by way of seizing the corresponding set of bank contacts. A circuit can now be traced from the source G9 over the hereinbefore traced path, the upper armature of relay 757, armature 758, wiper 710, bank contact 931, conductors 932, b497, 497 to armature 500, and from grounded battery, inner winding of relay 757, armature 763, lower armature of relay 756, wiper 711, bank contact 933, conductors 934, b498, 498 to armature 499, the armatures 499 and 500 being free. The line switch D3 having seized the first selector B, the operation of first selector B, second selector C2 and connector L, responsive to the sending of the digits "1-1-2-1", will be as hereinbefore described when the substation S7 was called. Also, the relays 479, 502 and 542 in Fig. 8, will operate resultant to the sending of the impulses as before described, wherein the motor magnet M8 is caused to advance its wiper set into engagement with the fourth set of bank contacts, causing relays 546, 200 and C8 to actuate, resultant thereto. Under the latter condition, the armatures 499 and 500 will be attracted, so that a path can be traced from armature 499, spring 478, armature 552, conductors 480, b480, 928, bank contact 925, wiper 857, armature 858, conductors a180, 180, receiver at substation S20, conductors 181, a181, armature 859, wiper 860, bank contact 926, conductors 929, b487, 487, spring 488 to armature 500, thus closing the before traced path from the source G9, causing relay 757 to actuate, followed by the actuation of relays 767, 768, and 701, in a manner as has been hereinbefore described. Due to the said actuation of relays 200, 546, and C8, the path from the connector L7 traced to conductors 56 and 57, in Fig. 8, is now extended from conductor 56, armature 549 to spring 53, spring 52, conductors 51, a51, to the upper winding of relay 702, and from conductor 57, armature 59, spring 60, conductors 61, 62, a62, to the lower winding of relay 702. Due to a condenser being interposed between conductor 57 and armature 59, the relay 702 would not have its lower winding energized, were it not for the retardation coil 551 applying battery to spring 58. The upper armature of relay 546 applies ground through retardation coil 548, effective to the upper winding of relay 702, so that the relay 702 is maintained actuated in the manner hereinbefore described with relation to relay 50 in element M10, under the condition of an outgoing call. Similarly, the relay 725 in connector L7 is maintained actuated, due to the 133

condition of relay 546. The connector L7 will function as before to signal the substation S7, and upon a response being received therefrom, wherein relay 565 in connector 5 L7 will actuate, the relay 546 in Fig. 8 will deactivate, whereupon the calling party at substation S20 and the called party at substation S7 are in talking relation. The condition of the circuits in Figs. 8 and 9, are 10 as described with reference to the call extended to substation S7 involving elements M10 and N11. Relay 701, having actuated responsive to the actuation of relay 768, will alter the circuits as hereinbefore described, 15 so that if the party at S20 now desires to pass the call, it may be accomplished in the manner as before described, through the agency of element B26, and it may be thereafter passed through the element A25, and in fact, any of 20 the passing and other operations described wherein the call was incoming, may now be accomplished.

In view of the general similarity of the 25 circuits in elements A25 and B26 with those of M10 and N11, respectively, and the fact that these pairs of elements of the passing call connectors, and their associated circuits are interchangeably cooperative with the circuits shown in Figs. 12, 8 and 9, it is thought 30 that a detailed description of all operative features will not be necessary here in order to convey a full and clear understanding of the operation with respect to elements A25 and B26, organized as in the assembly shown 35 in Fig. 33.

Going back to the condition assumed 40 wherein the party at substation S20 initiated a call wherein the line switch D28 seized connector H30. It will be assumed that the substation equipment shown at substation SJ20 displaces that shown at substation S20, the 45 two types of substations being generally similar, but it will be observed that the substation SJ20 involved a key K20 for introducing a resistance $r'20$ into its circuit path including the line conductors. The type of substation used will depend upon the facility it is desired to afford the users. In the description 50 with relation to an out-going call from the substation S20, involving the line switch D28, the digit "0" was sent. In the description about to be entered into, in lieu of sending the digit "0", the alternative method referred to of introducing the resistance $r'20$ 55 will be assumed.

The relay 852, whose upper and lower windings are in series with the upper and lower windings of relay 851, respectively, is marginally adjusted so that it will deactivate 60 when its energizing path includes the resistance $r'20$. Therefore, upon depressing key K20 the relay 852 will deactivate, the relay 851 sustaining. Upon the initiation of the 65 call, wherein the connector H30 is seized, its shaft will be automatically stepped vertical-

ly into alignment with the level containing the group to which the calling line belongs, as has been described. The condenser 935, which may be of low capacity, will cause inductive impulses to be applied through the 70 lower winding of relay 912 to conductor 910 audible to the calling party, while impulses are being applied from the source D30 through spring 890, at the time shaft is being automatically stepped vertically, so that 75 at the cessation of these impulses, the calling party will know that the connector H30 is ready to receive directive impulses for setting its wipers upon any desired accessible line of his group, or by way of extending 80 the connection to an out-going trunk directly from his line switch. The said impulses having ceased, the key K20 will be depressed, whereupon relay 852 will deactivate, so that 85 a circuit may be traced from impulse source D30, off-normal springs, upper armatures of relays 851, 889, 865, springs 890, 897, armatures 898, 899 and 900 to the winding of the rotary magnet R30, the rotary magnet operating to step the wipers rotarily until the 90 off-normal spring set ON'30 has been operated for objects before set forth. It will be noted in this connection, that incidental to the relay 892 deactivating following the stepping of the shaft vertically, wherein the 95 wiper 886 receives ground from segment 885, a ground path is completed through the upper armature of relay 892, armature 936, upper armature of relay 852, outer winding of relay 895 to grounded battery, the latter said 100 relay actuating and locking through its lower inside armature to ground on make contact armature 867. Under this condition, wherein the upper armature of relay 895 is attracted, the lower armature of relay 852 is not receiving ground through wiper 886, and therefore, should the calling party restore the key K20, wherein the relay 852 would be operationally energized, there would be no ground 105 applied to the winding of relay 889 to attract its upper armature by way of opening the impulse path from source D30. That is to say, a momentary depression of the key K20 will suffice to initiate the automatic operation of the rotary magnet R30, and to operate the 110 set of off-normal springs ON'30. Another function of the connector H30 is that, should the key K20 be prematurely depressed while the shaft is stepping vertically and the relay 892 is actuated because thereof, its lower 115 armature will short-circuit the lower armature and cooperating contact of relay 852, so in the event that the said relay 852 is deactivated, the relay 889 will not be disabled 120 against actuating at the time wiper 886 receives ground from segment 885, so that the impulses from source D30 will cease and allow the relay 892 to deactivate. Subsequent 125 impulses applied from the source D30 will be by way of the armature 898 of relay 892 130

to the rotary magnet R30 in lieu of through the winding of the latter said relay to the vertical magnet V30. So it will appear that if the key K20 is depressed immediately upon initiating the call and so maintained until 5 relay 892 deactuates, no disabling of the connector H30 will occur, and its wipers will be automatically raised into alignment with the level containing the group to which the calling line belongs, as if the key K20 had not been depressed, and upon the deactuation of 10 relay 892 its period thereafter will forthwith automatically rotate by way of operating the off-normal spring set ON'30. If the key K20 15 should be released before the relay 892 deactuates, there will be no circuit including the upper armature of relay 852 to energize the relay 895 to cause relay 889 to deactuate to complete the traced path from the source D30 20 to the rotary magnet R30.

The wiper 887 is reserved for use where one or more of the levels have two groups, and under which condition the shaft will automatically step into alignment with the 25 proper level and then forthwith automatically rotate to one step preceding the first set of bank contacts of the group containing the calling line. There will thus be a dead bank contact set preceding the inside group 30 of the level. The functioning of the connector H30 under this condition, will be discussed presently.

Attention is directed to the assembly shown in Fig. 33, but wherein the alternative Figs. 35 31 and 32 will be concerned in lieu of Fig. 27. Figs. 31 and 32 are similar, however, Fig. 31 shows the method of connecting the group wherein two groups occupy a single level of the local connector H30, and the concerned group occupies the first division of 40 the level, while Fig. 32 shows the method of connecting the group wherein two groups occupy a single level and the concerned group occupies the second division of the level, the 45 second level being concerned.

Under the condition of substituting Fig. 31 for Fig. 27, in the assembly shown in Fig. 33, and assuming that the lines which register with adjacent sheets are continuations of 50 the registering lines (ignoring other lines), it will appear that conductor a879 will receive ground from the upper armature of relay 783 in line switch D28 by way of wiper 875 and bank contact 876, conductor 879, 55 and that this ground will continue over conductor 938 to bank contacts 939 and 940, and to segment 941, accessible to connector H30. It will thus appear that upon the connector 60 H30 being seized, its shaft will be stepped vertically in the manner as hereinbefore described, until wiper 886 receives ground from segment 941, wherein the relay 889 will actuate by way of opening the impulse circuit 65 from the source D30, in the manner as here-

inbefore described. If the calling party sends impulses corresponding with digit "2," the wipers 881 to 884 will be set upon the second set of bank contacts 939, 942, 943 and 70 944, respectively, corresponding to the substation S, and signaling current applied in the manner as has been described. In this connection it will be understood, that the said second set of bank contacts would correspond to and be in multiple relation with 75 the corresponding second set of bank contacts 731 to 734 of element A25, and likewise, the corresponding set of element B26. That is to say, the corresponding numerical positions in the levels of the elements A25 and 80 B26 and the second level of the connector H30 will refer to the same local lines, respectively, though obviously the connection of any line may be omitted where desired by way of restricting service.

It will now be assumed that Fig. 32 will be substituted for Fig. 27 in the assembly shown in Fig. 33, and assuming that the lines which register with the adjacent sheets are continuations of registering lines, it will appear 90 that ground received from the upper armature of relay 783 in line switch D28 will be applied through wiper 875, bank contact 876, conductors 879, b879, 945 to bank contacts 946 to 948, and to segment 949. The 95 bank contact set corresponding to 946 is dead, for it will appear, that upon the initiation of the call, the wipers will be caused to be automatically set upon this set of bank contacts, preparatory to being directly moved 100 therefrom to a desired set.

Under the condition of the connector H30 being seized by line switch D28, wherein Fig. 32 is interposed, it will appear that wiper 886 will not receive ground from segment 885 nor segment 941. It will not receive ground from other segments in view of the construction wherein the segments engageable to wiper 886 are not engageable to wiper 887, and vice versa. The segments are 105 in parallel positions and the wipers are so connected to the shaft that when the shaft rotates it will disengage them from the segments upon which they may be resting. It will appear that upon the wipers being stepped into alignment with the second bank level (relay 982 being operated), ground will be communicated from segment 949, wiper 887, upper armature of relay 892, spring 893, lower armature of relay 852, armature 894 to the winding of relay 889, the latter said relay actuating by way of opening the path from the source D30. In view of segment 941 not constituting ground and that relay 892 will deactuate consistent with its period due to the said opening of the path from source D30, wiper 886 will not receive ground at this time, so that the lower armature of relay 889 will not apply ground to spring 893 to maintain relay 889. The latter said relay will 115 120 125 130

therefore deactivate consistent with its release period following the deactivation of relay 892. A circuit can now be traced from source D30, upper armatures of relays 851, 889, 865, 5 springs 890, 897, armatures 898, 899, and 900 to the rotary magnet R30, operative to rotating the shaft. The wipers 886 and 887 will be disengaged from segments 941 and 949, respectively, and when the wiper 881 encounters 10 grounded bank contact 946, this ground will be communicated through the spring 893, lower armature of relay 852, armature 894 to the winding of relay 889, the latter said relay actuating by way of opening the traced path from the source D30, so that the wipers 881 to 884 are now resting 15 upon bank contacts 946, 950, 951, 952, respectively. Upon the lower armature of relay 889 attracting against spring 893, the ground received from bank contact 946 will be applied through wiper 881, upper armature of relay 895, spring 893, lower armature of relay 852, armature 894 to the winding of relay 889, maintaining the latter said relay. 20 The connector H30 is now in position to receive directive impulses sent from the calling substation S20. It is assumed that the calling party sends impulses corresponding to digit "2" as assumed when Fig. 31 was substituted for Fig. 27, the wipers 881 to 884 will be rotated into engagement with bank contacts 948, 953, 954 and 955, respectively, corresponding to the line leading to substation S, the connector H30 functioning as before, signaling current being applied effective to the bell at substation S. Upon the 25 party at substation S responding wherein the relay 895 will actuate and lock in the manner as has been described, ground is removed from spring 886 and its resting contact and ground then applied to it from the co-operating armature, which receives ground from bank contact 948 by way of wiper 881. In view of the latter statement it will appear that if the bank contact 948 does not 30 constitute ground, the relay 865 will become de-energized whereupon conductor 868 will become ungrounded causing the line switch D28 to unseize and the connector H30 to be restored to normal by reason of the fact that the locking circuit for relay 895 has become 35 opened at armature 867, whereupon a path can be traced from grounded spring 866, lower armatures of relays 851, 865, off-normal springs to the release magnet Re30. Under 40 this condition should the party maintain the receiver off the switch-hook at the substation S20, the line switch will forthwith re-seize the connector H30 and cause it to automatically function to set its wipers 881 to 884 upon bank contacts 946, 950, 951 and 952, respectively, as before. If the calling party should now restore the receiver to the switch-hook, the last before traced path to the re-

lease magnet Re30 will be established to restore the shaft to normal.

In view of the foregoing, it will appear that when the Fig. 31 is substituted for Fig. 27 in the assembly shown in Fig. 33, and the call is initiated from substation S20, and the wipers of connector H30 are set into alignment with the second level of bank contacts, the sending of digit "5", for example, will cause the wipers 881 to 884 to be set upon bank contacts 948, 953, 952 and 955, respectively, which were last reached by calling digit "2". Under this condition, bank contact 948 will not constitute ground because the digit called refers to a bank contact set 75 irrelevant to the group containing the calling line. The connector will be caused to continue to rotate and operate the off-normal spring set ON'30 because the relay 889 will deactivate and establish a path from the source 80 D30 through the upper armatures of relays 851, 889, 865, to spring 890, effective to the rotary magnet R30, so that the connection cannot be completed.

Going back to the condition, wherein the 90 wipers 881 to 884 were set upon bank contacts 946, 950, 951 and 952, respectively, if the key K20 is depressed to cause relay 852 to deactivate, the relay 895 will be caused to actuate and lock from the ground received from bank 95 contact 946, wiper 881, upper armature of relay 892, armature 936, upper armature of relay 852 to the outer winding of relay 895, in the manner as before described. The energizing circuit of relay 889 will thus be 100 opened at the upper armature of relay 895, whereupon the source D30 will be applied through the upper armatures of relays 851, 889, 865, springs 890, 897, armatures 898, 899, 900, to the rotary magnet R30, the wipers 105 continuing to rotate until the path from source D30 is opened at the off-normal springs, regardless of the fact that relay 852 may become subsequently operatively energized. In this connection it will be observed 110 that the relay 889 will be re-energized and will (partially), actuate forthwith upon its spring 893 engaging its resting contact, but that due to the adjustments of the springs, in view of the slow-releasing characteristic 115 of the latter said relay the upper armature thereof will not become attracted from its resting contact before the spring 893 disengages its resting contact. And while there will be a "buzzer" action set up, the upper 120 armature will remain effectively retracted, so that the rotary magnet will receive impulses from source D30 (whereby the off-normal set ON'30 will be operated).

Referring to Fig. 36, showing the assembly 125 of the figures wherein the trunk terminating in the passing call connector elements M10 and N11 extends to a manual exchange, instead of an automatic exchange, previously described. It will be noted that Fig. 35 has 130

been substituted for Fig. 8 and that Fig. 34 has been substituted for all figures to the left of Fig. 8 of the assembly shown in Fig. 24.

Assuming that the operator inserts plug AP34 of the well known cord-pair J34 into local springjack LJ34, a circuit can be traced from grounded battery in repeating coil C34, winding of shunted relay 960, sleeve of plug, sleeve of springjack, conductor 961, make-before-break spring 962, conductor 963, resistance r35, conductors c62, 62, to the grounded lower winding of relay 50, and from the upper battery winding thereof, conductors 51, c51, 964, make-before-break spring 965, conductor 967, tip of springjack, tip of plug, winding of repeating coil C34 to ground, the relay 50 and its dependent relay 63 actuating. A path can be traced from grounded resting contact, armature 968, conductors c68, 68, off-normal set RO10, armatures 69, 70, 72, 73, 74, winding of relay 75, armature 76 to the rotary magnet R10, the rotary magnet operating in the manner as described wherein it was grounded through armature 67 in Fig. 8, to set the wipers 77 to 80 upon bank contacts 152 to 155, respectively, and applying signaling current from source G9, operative to the signal bell at substation S20, as when, and under the condition of the call first described, initiated from substation S. Upon the party at substation S20 responding, the element M10 will function as described under the referred-to condition, wherein substation S20 responded, causing relay 121 to actuate and lock, and conductor 194 to become grounded. This ground will now be conducted over conductor c194 to the winding of slow-releasing relay 969, causing it to actuate and lock over conductors c202', 202', to off-normal spring 94, resistance r35 being thus short-circuited.

Relay 960 in the cord-pair J34 is marginally adjusted, so that it does not actuate nor sustain with the resistance r35 included in its energizing path, but is operative and will sustain under the condition of the latter said resistance being excluded therefrom, so under the condition of the response, the relay 960 will actuate, extinguishing the supervisory lamp 970, which was caused to glow through the ring of the plug AP34 and grounded winding of cut-off relay 971, in the well known manner. The operator is thus apprised of the response. In this connection it will appear that if the relay 969 is caused to deactivate, the lamp 970 will re-glow, and as this can only occur when conductor 202' to which conductor c202' is attached becomes ungrounded wherein both elements M10 and N11 have their shafts at normal. It will indicate that there is no local line related to the trunk through the passing call connector, so that the connection can be taken down, it being assumed, of course, that the plug CP34 may be inserted into springjack CJ34 by way of completing a connection with substation

S34, and signaling current source G34 applied through the agency of key R34.

The party at substation S20 may now pass the call to substation SJ20 or to any other substation, as was described before, and the general functioning will be the same as when the call emanated from the automatic exchange. Should the operator withdraw the plug AP34, thus deenergizing relay 50, it and its dependent relays will deactivate (causing the battery and ground windings of relays 972 and 50 to be opposed, respectively), and cause the circuits to be restored to normal condition, as when the party at substation S disconnected, in the first hereinbefore description.

It will now be assumed that the operator inserted the plug AP34 into toll springjack TJ34 in lieu of springjack LJ34, it being borne in mind, of course, that generally similarly arranged switching cord-pairs to that shown in J34 would, in the commercial use of the invention, be provided, perhaps at a remote point, accessible to the springjack LJ34. However, for the purpose of this description, it will, for the present, be assumed that the plug AP34 is a toll switching plug, inserted into the toll springjack TJ34. It will be noted that the springjacks TJ34 and LJ34 are in multiple relation, however, in the case of springjack TJ34 a set of auxiliary contacts is provided, which will cause conductor 973 to become grounded upon the plug being inserted. The latter operation will cause the relay 974 to become actuated, by way of attracting armature 968, to disable the automatic rotary feature of the element M10, in the manner as described wherein relay 695 of Fig. 8 was caused to actuate, when the call emanated from the toll switchboard, in previous descriptions. The upper inside armature and the lower armature of relays 974 will serve to short circuit the windings of the retardation coil 975 for the object corresponding to that wherein the windings of the retardation coil 191 in Fig. 8 were short-circuited. In order to now initiate the rotary automatic functioning of the element M10, the operator will manipulate the key R'34 and thereby apply current from the signaling source G'34 in bridge of conductors 963 and 964, effective to the relay 976. The operation of the latter said relay will open the energizing path of relay 974, thus causing armature 968 to retract and apply ground to the rotary magnet R10 in the manner as described wherein the relay 692 of connector J6 was caused to remove ground from relay 695 of Fig. 8, for a similar purpose. Under the condition of the call emanating from the toll springjack TJ34, the strength of the battery applied through the back-bridge relays 188 and 269 will therefore be augmented, as when the call was described as originating at the

toll switchboard through springjack CJ4 in Fig. 4.

- If it is now assumed that the party at substation SJ20 initiates the call and thereafter sends digit "0" as hereinbefore described, and thereby causes line conductors 246 and 247 to be extended through wipers 483 and 484 to bank contacts 482 and 485, conductors 481 and 486, and 480 and 487, respectively, a circuit 5 can be traced from conductors 487, c487, make-before-break spring 976, conductor 961, right armature of relay 971, winding of line relay 972 to ground, and from conductors 480, c480, outer winding of electro-polarized relay 977, make-before-break spring 978, conductor 967, left armature of relay 971, winding of relay 972 to grounded battery, relays 972 and 977 actuating; the former to cause calling signal lamp 979 to glow. 10 When the line switch Q13 seizes, due to the wiper 363 thereof not encountering ground on bank contact 451, since the path therefrom over conductors 496, 495, c495, c64 to 64 is open, the ground from armature 360 in the 15 said line switch will be applied over the traced path to conductor 64 and to the lower armature of relay 977. Then, as will appear presently, the conductor 64 will again become grounded by reason of relay 63 in element 20 M10 actuating, before the armature 360 in the line switch Q13 has had time to deactivate, so the latter said line switch will be maintained seized because no lapse of ground has 25 occurred to the wiper 363.
- The relay 977 will actuate under the condition of the outer winding being energized, only sufficiently to attract its lower armature, whereby ground will be applied from conductor c64, lower armatures of relays 980, 30 977, armature 981 to operatively energize slow-releasing relay 982. It will also energize the inner winding of relay 977, differentially to that of the outer winding thereof. The two upper armatures of relay 977 have 35 restraining springs which will prevent them from engaging their cooperating contacts unless the two windings energize cumulatively. The inner winding of relay 977 will not alone attract or sustain any of its armatures. 40
- Under the condition of relay 982 actuating, conductor c86 will receive battery potential from armature 983 in lieu of normally applied ground potential, so the bank contact 45 82 will be unguarded. Incidental to the actuation of relay 982, a circuit path is closed from the lower winding of relay 50, conductors 62, c62, resistance r35, conductor 963, spring 962, lower armature of relay 982, conductors 964, c51, 51, to the upper winding of relay 50, relay 50 and its dependent relay 63 actuating. In view of armature 968 resting upon its grounded contact, the shaft of element M10 will forthwith initiate its rotary 50 operation, and in further view of the first
- bank contact set being unguarded, and constituting battery potential, will seize thereon, in the manner as hereinbefore described under a generally similar condition. Signaling current will be applied over conductors 497 and 498, conductors c497 and c498, to armatures 984 and 985, respectively. The latter armatures being free, there will be no operative effect from the signaling current. The operator will respond by inserting plug 55 AP34 into springjack LJ34.
- It will appear that whereas conductors 961 and 967 were applied to ground and battery, respectively, through the winding of relay 972, that they are now applied to battery and ground, respectively, through the windings of the repeating coil C34, and therefore, the current traversing the receiver at substation SJ20 has been reversed in direction, and the windings of relay 977 are energizing cumulatively so that the two upper armatures have been drawn into engagement with their cooperating contacts, respectively. Relay 980 60 will be operatively energized, and locked to conductor c202' by way of its lower inside armature, and the relay 987 will be operatively energized and locked through its lower armature to conductors c86. The upper armature of relay 987 will remove the ground received from conductor c64, which is applied over conductors c495, 495, to maintain the line switch Q13, and substitutes therefore, ground received from armature 115 in element M10, wiper 78, bank contact 82, conductors 86, c86. So the line switch Q13 is 65 now maintained from armature 115 in element M10 in lieu of from the upper armature of relay 63 thereof. The upper armature of relay 980 will short-circuit the outer winding of relay 977, causing the three armatures thereof to retract out of engagement with their cooperating contacts.
- Conductors 961 and 967, which were heretofore traced to conductors 487 and 480, respectively, and which included the receiver at substation SJ20, are now disconnected therefrom. Conductor 961 is now connected through spring 962 to conductor 963, resistance r35, conductors c62, 62, to the lower winding of relay 50. Conductor 967 is now 70 connected through spring 965, conductors 964, c51, 51, to the upper winding of relay 50. The conductor 487 is now continued over conductor c487, spring 976, armature 984, conductors c497, 497, bank contact 83, wiper 79, armatures 129, 126, upper winding of relay 188, conductors 189, c189, upper winding of retardation coil 975 to grounded battery. The conductor 480 is now continued over conductor c480, upper armature of relay 980, 75 spring 978, armature 985, conductors c498, 498, bank contact 84, wiper 80, armatures 138, 139, lower winding of relay 188, armature 140 to upper grounded armature of relay 188. The traced path from substation SJ20 to the 80

- windings of the back-bridge relay 188 and the traced path from the plug AP34 to the windings of the line relay 50 are united through the condensers 146 and 150, so the operator can manipulate listening key LC34 and place her operator's circuit S'34 into talking relation with the party at substation SJ20. The party at substation SJ20 can now pass the call in the manner as has been previously described, wherein he became in talking relation with substation S7. Moreover, the circuits with relation to elements M10 and N11 will function as if the out-going call has been an in-coming call.
- If it is assumed that the operator withdraws the plug AP34, wherein the windings of relay 972 will be reassociated with the line conductors 961 and 967, relay 50 will become deenergized by reason of the battery windings and the ground windings of relays 979 and 50 being opposed, respectively. This will cause the circuits with relation to elements M10 and N11 to be restored to normal, as has been described. Should the call be terminated by the party at substation SJ20 replacing the receiver, the relay 969 in Fig. 35 will remain locked until conductor 202' becomes ungrounded, in the manner as hereinbefore described, when the call concerned an automatic main exchange in lieu of a manual exchange. In view of relay 987 remaining locked only until bank contact 82 becomes ungrounded, it will insure that the relay 987 will deactivate and apply ground from armature 983 to bank contact 82, and from conductor 64 to the private bank contacts attached to conductor c495, as long as conductor 64 constitutes ground. So a line switch hunting for an exchange trunk will find the one corresponding to the elements M10 and N11 busy, though the initial calling substation may have been disconnected therefrom. The relay 980 will unlock as soon as ground is removed from conductor c202'. This will insure that the conductors c480 and c487 are free as far as attached bank contacts are concerned, and that relay 977 cannot become re-actuated after the short is removed from its outer winding.
- It will be manifest that in view of the relay 121 in element M10 remaining locked until relay 63 thereof deactuates, that if the elements of the passing call connector restore before the operator withdraws the plug to terminate the service, the main element remains disabled against rotating on its normal level. However, upon the plug being withdrawn, whereby the relay 121 will unlock, the passing call connector becomes normal, so that upon the plug being re-inserted into the springjack the shaft of the element M10 will forthwith hunt on its normal level. On the other hand, if the plug is withdrawn while the passing call connector has one or both of its elements off-normal, the latter

said connector will restore. Due to the battery and ground windings of relays 50 and 972 being then opposed, respectively, neither said relay will actuate, so a false call will not appear before the operator.

In view of the descriptions with reference to the assemblies shown in Figs. 24 and 36, it is thought it will not be necessary to enter into a detailed description wherein Fig. 16 is substituted for line switch R14 and Figs. 75 and 6 are introduced.

With reference to the assembly shown in Fig. 37, it is thought that in view of the previous descriptions with reference to Figs. 24 and 36, the operation of the circuits indicated by Fig. 37 will be manifest.

Referring to Fig. 14, the dotted line a—b indicates where a trunk involving conductors corresponding to 64, 56 and 57, may be connected. This expedient would be employed where certain of the substations of a group are arranged for direct, out-going trunk connections, wherein the two-way trunks will not be seized for out-going calls and therefore, passing operations will not be possible from such substations. Of course, under this arrangement the conductors 481, 486 and 496, leading upward from the connections to the bank contacts of line switch R14, and other line switches of its group thus arranged, would be disassociated, so that when the digit "0" is sent, after initiating a call, the out-going trunk will be seized, there being no relation between the line switch R14 (and similarly arranged line switches of its group), and the two-way trunk.

Attention is directed to the fact, that the arrangement in elements A25 and B26 involving the cams B25, B'25, may also be applied to the elements M10 and N11, as well as to connectors L6, L7, U18, Y23 and H30, the device having a wide application in the art. Likewise, the re-ringing feature employed in elements M10 and N11 wherein the passing party will be re-called if the connection has been passed to a busy line and the passing party hangs up, may be applied to elements A25 and B26, though obviously the device involving cams B25 and B'25 would not be employed under the latter condition.

Attention is called to the various line switches wherein a slow-releasing relay as 573 in line switch D3 and relays 624 and 607 in line switch T16 are shown as slow-releasing. These may be quick-releasing relays. With reference to switch-arm 990 in line switch D3, it will be noted if it is moved into the dotted position, when the relay 573 actuates, it will open the winding of relay 47 at the lower armature of the relay 573, so that the relay 47 will deactivate. Where the relay 47 is short-circuited, as set forth in the descriptions, its armatures will require stiff adjustment in order to overcome the tendency for the relay to release slowly, due

to the short-circuit condition. With reference to the line switch T16, the switch-arm 991 and the lower armatures of relays 624 and 607, will have a similar function to the switch-arm 990 and the lower armature of relay 573, in that, if either relay 624 or 607 actuates, under the condition of arm 991 being in the position shown dotted, the winding of relay 631 will be opened instead of short-circuited as would ensue where the arm 991 in the position shown solid.

Having illustrated and described one exemplified organization of the invention, as applied to and embodied in an exchange system, it will be manifest that the elements may be otherwise combined, or that they may be modified in various details by amplification or curtailment, by those skilled in the art to which it belongs, without departing from its scope as defined by the claims.

I claim:—

1. In a telephone system, a calling line, called lines, a trunk line extending to a selective switch mechanism, means for linking the calling line to the trunk line, means for causing the said switch mechanism to initiate selective operation to extend the established connection to a first called one of the lines, means on the said first called line for directly operating the said switch mechanism to connect the trunk to an idle second one of the called lines, and a signal operated for indicating if a response on the said second called line is not obtained.

2. In an automatic telephone system, a trunk line having a near and a far portion, a first selective switch terminating the near portion of the trunk line, a calling line and line switch thereof, a second selective switch accessible from the line switch, means for operating the line switch to extend a connection from the calling line to the said second switch, means for operating the said second switch in a predetermined manner, means automatically responsive to the said operation of the said second switch for disconnecting the line switch from its connection with the said second switch and for initiating its hunting operation to connect to the near portion of the trunk line, and means for causing the said first switch to become interposed in the said connection between the line switch and the near portion of the trunk line wherein the line switch is a link of the connection, without effectively destroying the said connection between the calling line and the near portion of the trunk line.

5. In an automatic telephone system, a trunk line having a near and a far portion, a first selective switch terminating the near portion of the trunk line, a calling line and line switch thereof, a second selective switch accessible from the line switch, means controlled over the calling line for operating the line switch to extend a connection from the

calling line to the said second switch, means controlled from the calling line for operating the said second switch in a predetermined manner, means automatically responsive to the said operation of the said second switch for disconnecting the line switch from its connection with the said second switch and for initiating its hunting operation to connect to the near portion of the trunk line, and means thereafter controlled over the calling line for causing the said first switch to become interposed in the said connection between the line switch and the near portion of the trunk line wherein the line switch is a link of the connection, without effectively destroying the said connection between the calling line and the near portion of the trunk line.

4. In an automatic telephone system, a trunk line having a near and a far portion, a first selective switch terminating the near portion of the trunk line, a calling line and line switch thereof, a second selective switch accessible from the line switch, means for operating the line switch to extend a connection from the calling line to the said second switch, means for operating the said second switch in a predetermined manner, means automatically responsive to the said operation of the said second switch for disconnecting the line switch from its connection with the said second switch and for initiating its hunting operation to connect to the near portion of the trunk line, and means automatically applied for causing the said first switch to become interposed in the said connection between the line switch and the near portion of the trunk line wherein the line switch is a link of the connection, without effectively destroying the said connection between the calling line and the near portion of the trunk line.

5. In an automatic telephone system, a trunk line having a near and far portion, a first selective switch terminating the near portion of the trunk line, a calling line and line switch thereof, a directive switch accessible from the line switch, means for operating the line switch to extend a connection from the calling line to the said directive switch, means for operating the said directive switch in a predetermined manner, means automatically responsive to the said operation of the directive switch for disconnecting the line switch from its connection with the said directive switch and for thereupon connecting the calling line through the disconnected said line switch to the near portion of the trunk line, and automatically applied means for causing the operation of the said first switch whereby it will become interposed in the said connection between the line switch and the near portion of the trunk line wherein the line switch is a link of the connection, without effectively destroying the said connection.

- nection between the calling line and the near portion of the trunk line.
6. In an automatic telephone system, a trunk line having a near and a far portion, a first selective switch terminating the near portion of the trunk line, a second selective switch terminating the far portion of the trunk line, a calling line and line switch thereof, a directive switch accessible from the line switch, a called line accessible from the said second switch, means controlled over the calling line for causing the operation of the line switch to extend a connection from the calling line to the directive switch, means controlled from the calling line for operating the connected directive switch, means automatically responsive to predetermined operation of the directive switch for disconnecting the line switch from its connection with the directive switch and for thereupon connecting the calling line through the disconnected said line switch to the near portion of the trunk line, means controlled from the calling line for operating the said second switch into connection with the called line to complete a connection from the calling line to the called line, and means effective consequent upon extending the connection to the called line for interposing the said first switch in the established connection at a point intermediate of the line switch and the near portion of the trunk line wherein the line switch is a link of the connection, without effectively destroying the connection between the calling line and the called line.
7. In an automatic telephone system, a trunk line having a near and a far portion, a first selective switch terminating the near portion of the trunk line, a second selective switch terminating the far portion of the trunk line, a calling line and line switch thereof, a directive switch accessible from the line switch, a called line accessible from the said second switch, means controlled over the calling line for causing the operation of the line switch to extend a connection from the calling line to the directive switch, means controlled from the calling line for operating the said second switch into connection with the said first called line to complete a connection from the calling line to the said first called line, means for interposing the said first element of the said first switch in the established connection at a point intermediate of the line switch and the near portion of the trunk line wherein the line switch is a link of the connection, without effectively destroying the connection between the calling line and the said first and said second called lines.
8. In an automatic telephone system, a trunk line having a near and a far portion, a first selective switch having first and second independently operable connective elements terminating the near portion of the trunk line, a second selective switch terminating the far portion of the trunk line, a calling line and a line switch thereof, a directive switch accessible from the line switch, a first called line accessible from the said second switch, a second called line accessible from the said second element, means controlled over the calling line for operating the line switch to extend a connection from the calling line to the directive switch, automatic means for operating the directive switch in a predetermined manner, means responsive to the said operation of the directive switch for disconnecting the line switch from its connection with the directive switch and for thereupon connecting the calling line through the disconnected said line switch to the near portion of the trunk line, means controlled from the calling line for operating the said second switch into connection with the said first called line to complete a connection from the calling line to the said first called line, means for interposing the said first element of the said first switch in the established connection at a point intermediate of the line switch and the near portion of the trunk line wherein the line switch is a link of the connection, without effectively destroying the connection between the calling line and the said first called line.
9. In an automatic telephone system, a calling line and line switch thereof, a trunk line, a branch of the trunk line, a first switch for the trunk line, a second switch, means for operating the line switch to effect a connection between the calling line and said second switch, means controlled over the calling line for directly operating the said second switch, means automatically responsive to a predetermined said operation of the said second switch to disconnect the line switch from its said connection and for then causing its connection to the trunk line over the said branch, and means for interposing the said first switch as a link in the said branch without effectively destroying the connection between the calling line and trunk line.
10. In an automatic telephone system, a calling line and line switch thereof having a single set of movable terminals, a branch of the trunk line, a first switch for the trunk line,

a second switch, means for operating the line switch to effect a connection between the calling line and said second switch through said terminals, means controlled over the calling line for directively operating the said second switch, means automatically responsive to a predetermined said operation of the said second switch to disconnect the line switch from its said connection and for then causing its connection through said terminals over the said branch to the trunk line, and means for interposing the said first switch as a link in the said branch without effectively destroying the connection between the calling line and trunk line.

11. In an automatic telephone system, a calling line and line switch thereof, a trunk line, a branch of the trunk line, a first switch for the trunk line, a second switch, means for operating the line switch to effect a connection between the calling line and said second switch, means controlled over the calling line for directively operating the said second switch, means automatically responsive to a predetermined said operation of the said second switch to disconnect the line switch from its said connection and for then causing its connection to the trunk line over the said branch, and auxiliary means controlled from the calling line for interposing the said first switch as a link in the said branch without effectively destroying the connection between the calling line and trunk line.

12. In an automatic telephone system, a calling line and line switch thereof, a first, second and third group of trunks accessible from the switch, means for initiating the hunting operation of the switch for connecting the calling line to only an idle line of the said first group, a first and a second relay corresponding to the second and third trunk groups respectively, a conductor for the respective relays, conductors of the trunk connected to corresponding to the said second and third trunk groups cooperated with the said conductors of the corresponding relays consequent to the said connection, and directively controlled means including one or the other of the said relays and corresponding conductors for causing the switch to disconnect from its connected trunk line and to thereupon hunt for and connect only with an idle line of either the second or third said group in correspondence with the operation of the said directively controlled means.

13. In an automatic telephone system, a calling line and line switch thereof, a first, second and third group of trunks accessible from the switch through a single set of common connecting terminals, means for initiating the hunting operation of the switch for connecting the calling line to only an idle line of the said first group, a first and a second relay corresponding to the second and third trunk groups respectively, a conductor for the

relays respectively, conductors of the said trunk connected to corresponding to the said second and third trunk groups cooperated with the said conductors of the corresponding relays consequent to the connection, a directively controlled means including one or the other of the said relays and corresponding conductors for causing the switch to disconnect from its connected trunk line and to thereupon hunt for and connect only with an idle line of either the second or third said group in correspondence with the operation of the said directively controlled means.

14. In an automatic telephone system, a calling line and line switch thereof, a first, second and third group of trunks accessible from the switch, a directive switch terminating each trunk of the said groups, a called line corresponding to each said trunk group respectively, means for operating the line switch for connecting the calling line to only an idle trunk of the said first group, means for thereafter directly operating the switch of the connected said trunk to extend the calling line towards the corresponding called line, means for differently directly operating the said switch of the connected said trunk to disconnect the line switch from its connection with the corresponding trunk and to initiate its hunting operation for an idle trunk to which to connect the calling line, means dependent upon which of two alternative said different directive operations is effected by the trunk switch which will render idle trunks of only the second or only the third trunk group subject to connection with the calling line by the line switch regardless of the busy or idle condition of any of the trunks, and means thereafter operative for directly operating the switch of the connected trunk to extent the connection from the calling line to a corresponding called line wherein the directive operation is controlled from the calling line.

15. In an automatic telephone system, a calling line and line switch thereof, a first, second and third group of trunks accessible from the switch through a single set of common terminals, a directive switch terminating each trunk of the said groups, a called line corresponding to each said trunk group respectively, means for operating the said terminals of the line switch for connecting the calling line to only an idle trunk of the said first group, means for thereafter directly operating the switch of the connected said trunk to extend the calling line towards the corresponding called line, means for differently directly operating the said switch of the connected said trunk to disconnect the line switch from its connection with the corresponding trunk and to initiate its hunting operation for an idle trunk to which to connect the calling line, means dependent upon which of two alternative said different direc-

tive operations is effected by the trunk switch which will render idle trunks of only the second or only the third trunk group subject to connection with the calling line by the line switch regardless of the busy or idle condition of any of the trunks, and means thereafter operative for directly operating the switch of the connected trunk to extend the connection from the calling line to a corresponding called line, wherein the directive operation is controlled from the calling line.

16. In an automatic telephone system, a calling line and line switch thereof, a first, second and third trunk accessible from the switch, a directive switch terminating each said trunk, a called line corresponding to each said trunk respectively, means for operating the line switch for connecting the calling line to only the said first trunk, means for thereafter directly operating the switch of the connected said trunk to extend the calling line towards the corresponding called line, means for differently directly operating the said switch of the connected said trunk to disconnect the line switch from its connection with the corresponding trunk and to initiate its operation to connect the calling line to one of the other said trunks, means dependent upon which of two alternative said different directive operations is effected by the trunk switch which will render only the second or only the third trunk subject to connection with the calling line by the line switch, and means effective consequent upon effecting the last said connection operative for directly operating the switch of the connected trunk to extend the connection from the calling line toward the called line corresponding to the connected trunk line wherein the directive operation is controlled from the calling line.

17. In an automatic telephone system, a calling line and line switch thereof, a first, second and third trunk accessible from the switch through a single set of common terminals, a directive switch terminating each said trunk, a called line corresponding to each said trunk respectively, means for operating the line switch for connecting the calling line to only the said first trunk, means for thereafter directly operating the switch of the connected said trunk to extend the calling line towards the corresponding called line, means for differently directly operating the said switch of the connected said trunk to disconnect the line switch from its connection with the corresponding trunk and to initiate its operation to connect the calling line to one of the other said trunk lines, means dependent upon which of two alternative said different directive operations is effected by the trunk switch which will render only the second or only the third trunk subject to connection with the calling line by the line switch, and means effective consequent upon

effecting the last said connection operative for directly operating the switch of the connected trunk to extend the connection from the calling line toward the called line corresponding to the connected trunk wherein the directive operation is controlled from the calling line.

18. In an automatic telephone system, a calling line and line switch thereof, a first and a second trunk accessible from the switch, a directive switch terminating each said trunk, a called line corresponding to each said trunk, means for operating the line switch for connecting the calling line to only the said first trunk, means for thereafter directly operating the switch of the connected said trunk to extend the calling line towards the corresponding called line, means for differently directly operating the said switch of the connected said trunk to disconnect the line switch from its connection with the trunk and to thereby initiate its operation to connect the calling line to the said second trunk, and means thereafter operative for directly operating the switch of the connected second trunk to extend the connection from the calling line toward the corresponding called line wherein the directive operation is controlled from the calling line.

19. In an automatic telephone system, a calling line and line switch thereof, a first and a second trunk accessible from the switch through a single set of common terminals, a directive switch terminating each said trunk, a called line corresponding to each said trunk, means for operating the line switch for connecting the calling line to only the first trunk, means for thereafter directly operating the switch of the connected said trunk to extend the calling line towards the corresponding called line, means for differently operating the said switch of the connected said trunk to disconnect the line switch from its connection with the trunk and to thereby initiate its operation to connect the calling line to the said second trunk, and means thereafter operative for directly operating the switch of the connected second trunk to extend the connection from the calling line toward the corresponding called line wherein the directive operation is controlled from the calling line.

20. In an automatic telephone system, a calling line, a called line, a plurality of linking switches, means for directly linking a connection from the calling line to the called line involving a switch train consisting of all the said switches, means automatically applied incident to effecting the connection toward the said called line dependent upon an alternative said directive linking operation for causing a said switch of the linked connection to be reoperated and the connection then extended through the reoperated switch in the direction of the called line,

- and means for directively completing the connection to the called line wherein a train involving only a portion of the said switches will be all the switches included in the completed connection to the called line.
21. In an automatic telephone system, a calling line, a called line, a plurality of groups of linking switches, means for directively linking a connection from the calling line to the called line involving a switch train consisting of a single switch of each said group, means automatically applied incident to effecting the connection toward the called line dependent upon an alternative said directive operation for causing a switch of the linked connection to be reoperated and the connection then extended through the re-operated switch in the direction of the called line, and means for directively completing the connection to the called line wherein a train involving a single switch of only a portion of the said groups will be all the linking switches included in the completed connection to the said called line.
22. In a telephone system, a calling and a called line, automatic switch mechanism for connecting said lines, a source of signaling current for application to the called line, a source of inductive current, means for at will applying the inductive current over the calling line after the said lines are connected for applying the signaling current to the called line consequent to the termination of the application of the inductive current, and automatically applied means for maintaining the said application of the signaling current.
23. In a telephone system, a calling and a called line, automatic switch mechanism for connecting said lines, a source of signaling current for application to the called line, a source of inductive current, means for placing a busy-guard on the called line, means for barring connection with the called line consequent to the busy-guard, means effective for restoring the switch mechanism consequent to operating the switch mechanism with connective relation to the busy-guarded called line, and means thereafter responsive to a single application of the inductive current over the calling line for causing the switch mechanism to operate into connective relation with the called line.
24. In a telephone system, a calling and a called line, automatic switch mechanism for connecting said lines, a busy-tone source, means for placing a busy-guard on the called line, means for barring connection with the called line consequent to the busy-guard, means effective for restoring the switch mechanism consequent to operating the switch mechanism with connective relation to the busy-guarded called line, and means for sustainingly applying the busy-tone source audible on the calling line incident to the said restoration.
25. In a telephone system, a calling and a called line, automatic switch mechanism for connecting said lines, a source of signaling current for application to the called line, a source of inductive current, means for placing a busy-guard on the called line, means for barring connection with the called line consequent to the busy-guard, means effective for restoring the switch mechanism consequent to operating the switch mechanism with connective relation to the busy-guarded called line, means thereafter responsive to a single application of the inductive current over the calling line for causing the switch mechanism to operate into connective relation with the called line, means effective consequent upon the switch mechanism being again operated into connective relation with the called line if it is busy-guarded for again restoring the switch mechanism, means effective if the line is not busy-guarded when the switch mechanism is operated into said connective relation for effecting the said connection between the calling and the called lines, and means thereafter responsive to applying a single application of the inductive current over the calling line for applying the signaling current to the called line and for thereafter maintaining it applied.
26. In a telephone system, a calling and a called line, automatic switch mechanism for connecting said lines, a busy-tone source, a source of inductive current, means for placing a busy-guard on the called line, means for barring connection with the called line consequent to the busy-guard, means for restoring the switch mechanism consequent to operating the switch mechanism with connective relation to the busy-guarded called line, means effective for sustainingly applying the busy-tone source audible on the calling line incident to the said restoration, and means thereafter responsive to a single application of the inductive current over the calling line for terminating the application of the busy-tone and for causing the switch mechanism to operate into connective relation with the called line.
27. In a telephone system, a calling line and a group of called lines, automatic switch mechanism for operating in hunting relation to the group for connecting the calling line to an idle one of the lines of the said group, a source of inductive current, automatically applied means for restoring the switch mechanism consequent to encountering all the lines of the group busy, and means responsive to a single application of the inductive current over the calling line for causing the switch mechanism to again hunt with respect to the lines of the group.
28. In a telephone system, a calling line and a group of called lines, automatic switch mechanism for operating in hunting relation to the group for connecting the calling line

- to an idle one of the lines of said group, a source of inductive current, a tone source, automatically applied means for restoring the switch mechanism consequent to encountering all the lines of the group busy, automatically applied means for applying the tone source audible on the calling line incident to the said restoration, and means responsive to a single application of the inductive current over the calling line for terminating the application of the tone source and for causing the switch mechanism to again hunt with respect to the lines of the group. 70
15. 29. In a telephone system, a calling line and a group of called lines, a busy-tone source, automatic switching mechanism for operating in hunting relation to the group for connecting the calling line to an idle one of the lines of said group, automatically applied means for causing the switch mechanism to periodically hunt over the lines of the group until an idle line is found and connected to, and automatically applied means effective consequent to the switch having hunted over all the lines of the group when busy for automatically applying and maintaining the said application of the busy-tone source to the calling line only until an idle line of the group is found and connected with. 80
20. 30. In an automatic telephone system, a calling line and a group of called lines, automatic switch mechanism for operating in hunting relation to the group for connecting the calling line to an idle one of the lines of said group, means for initiating the said hunting operation, a source of inductive current, means automatically applied for restoring the switch mechanism consequent to encountering all the lines busy, and means responsive to a single application of the inductive current over the calling line for causing the switch mechanism to again hunt 85 with respect to the lines of the group. 90
25. 31. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, and means effective consequent to a said connection to a called line whereby thereafter again applying a single application of the inductive current over the calling line will cause the signaling current to be applied to the called line. 95
30. 32. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, and means effective consequent to effecting a connection to a line of the group whereby again applying one application of the inductive current will cause the switch mechanism to again initiate the said hunting operation, and means made effective consequent to effecting a connection to a line of the group whereby again applying one application of the inductive current will cause the switch mechanism to again hunt with respect to the lines of the group. 100
35. 33. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, means effective consequent to the said connection to a called line whereby thereafter again applying and then terminating a single application of the inductive current over the calling line will cause the signaling current to be applied to the called line. 105
40. 34. In an automatic telephone system, a calling line and a group of called lines, automatic switch mechanism for operating in hunting relation to the group for connecting the calling line to an idle one of the lines of said group, a source of inductive current, means responsive to a single application of the inductive current over the calling line for initiating the said hunting operation, automatically applied means for restoring the switch mechanism if all the lines of the group are busy, and means whereby again applying one application of the inductive current will cause the switch mechanism to again initiate the said hunting operation. 110
45. 35. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, automatically applied means for restoring the switch mechanism if all the lines of the group are busy, means whereby again applying one application of the inductive current will cause the switch mechanism to again initiate the said hunting operation, and means made effective consequent to effecting a connection to a line of the group whereby again applying one application of the inductive current will cause the switch mechanism to again hunt with respect to the lines of the group. 115
50. 36. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, and means made effective consequent to effecting a connection to a line of the group whereby again applying one application of the inductive current will cause the switch mechanism to again hunt with respect to the lines of the group. 120
55. 37. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, and means made effective consequent to effecting a connection to a line of the group whereby again applying one application of the inductive current will cause the switch mechanism to again hunt with respect to the lines of the group. 125
60. 38. In an automatic telephone system, a calling line and a group of called lines, automatic switch mechanism for operating in hunting relation to the group for connecting the calling line to an idle one of the lines of said group, a source of inductive current, a source of signaling current, means responsive to a single application of the inductive current over the calling line for initiating the said hunting operation, and means made effective consequent to effecting a connection to a line of the group whereby again applying one application of the inductive current will cause the switch mechanism to again hunt with respect to the lines of the group. 130

the signaling current to be applied to the connected line.

36. In an automatic telephone system, a calling and a called line, automatic switch mechanism for connecting the said lines, a source of inductive operating current, a source of signaling current, means for at will applying a single application of the operating current for any duration to the calling line to 10 effect the connection of the lines, and means made operative consequent to the connection whereby then reoperating the first said means as before to apply a single application of the operating current to the calling line for any 15 duration will be effective to apply the signaling current to the called line.

37. In an automatic telephone system, a calling and a called line, automatic switch mechanism for connecting the said lines, a 20 source of inductive operating current, a source of signaling current, means for at will applying a single application of the operating current for any duration to the calling line to effect the connection of the lines, means 25 made operative consequent to the connection whereby then reoperating the first said means as before to apply a single application of the operating current to the calling line for any duration will be effective to sustainingly apply 30 the signaling current to the called line, and means controlled over the called line for terminating the application of the signaling current.

38. In a telephone system, a calling and a 35 called line, automatic switch mechanism for connecting said lines, a source of signaling current for application to the called line, another source of current, means for at will applying the said another source of current over 40 the calling line after the said lines are connected but before any operation has thereafter occurred on the called line for applying the signaling current to the called line consequent to the termination of the application of 45 the said another source of current, and automatically applied means for maintaining the said application of the signaling current.

39. In a telephone system, a calling and a 50 called line, automatic switch mechanism for connecting said lines, a source of signaling current for application to the called line, another source of current, means for placing a busy-guard on the called line, means for barring connection with the called line consequent to the busy-guard, means effective for 55 restoring the switch mechanism consequent to operating the switch mechanism with connective relation to the busy-guarded called line, and means thereafter responsive to a 60 single application of the said another source of current over the calling line for causing the switch mechanism to again operate into connective relation with the called line.

40. In a telephone system, a calling line 65 and a group of called lines, automatic switch

mechanism for operating in hunting relation to the group for connecting the calling line to an idle one of the lines of said group, a source of current, a tone source, automatically applied means for restoring the switch mechanism consequent to encountering all the lines of the group busy, automatically applied means for applying the tone source audible on the calling line incident to the said restoration, and means responsive to a single application of the said source of current over the calling line for terminating the application of the tone source and for causing the switch mechanism to again hunt with respect to the lines of the group.

41. In an automatic telephone system, a calling line and a group of called lines, automatic switch mechanism for operating in hunting relation to the group for connecting the calling line to an idle one of the lines of the said group, means for initiating the said hunting operation, a source of current, means automatically applied for restoring the switch mechanism consequent to encountering all the lines busy, and means responsive to a single application of the said source of current over the calling line for causing the switch mechanism to again hunt with respect to the lines of the group.

42. In an automatic telephone system, a calling line and a group of called lines, automatic switch mechanism for operating in hunting relation to the group for connecting the calling line to an idle one of the lines of said group, a source of current, a source of signaling current, means responsive to a single application of the said source of current over the calling line for initiating the said hunting operation, and means effective consequent to a said connection to a called line whereby thereafter applying a single application of the said source of current over the calling line will cause the source of signaling current to be applied to the called line.

43. In an automatic telephone system, a calling line and terminating line switch thereof, two groups of trunk lines, switch mechanism specific to each trunk line of the said groups, a called line accessible from each said trunk group respectively, means for operating the line switch to only connect the calling line with an idle trunk line of a specific one of said groups, means for then operating the switch of the connected trunk line 120 to extend the connection towards the corresponding called line, means operated alternative to operating the switch of the connected trunk line to extend the connection towards the corresponding called line for 125 causing the line switch to disconnect from the connected trunk line, means automatically applied responsive to the said operation of the last said means for causing the line switch to connect with only an idle trunk 130

line of the other said group, and means for thereafter operating the said switch of the last connected trunk line for progressing the connection in the direction of the corresponding called line.

44. In an automatic telephone system, a calling line and terminating line switch thereof, two trunk lines, switch mechanism specific to each said trunk line, a called line accessible from each said trunk respectively, means for operating the line switch to connect the calling line with one of said trunk lines, means for then operating the switch of the connected trunk line to extend the connection towards the corresponding called line, means operated alternative to operating the switch of the connected trunk line to extend the connection towards the corresponding called line for causing the line switch to disconnect from the connected trunk line, means automatically applied responsive to the said operation of the last said means for causing the line switch to connect with the other trunk line, and means for thereafter operating the said switch of the last connected trunk line for progressing the connection in the direction of the corresponding called line.

45. In an automatic telephone system, a calling line and line switch thereof, a first numerical order selective switch, a second selective switch of the next higher numerical order than said first numerical order switch, a called line, a trunk line leading from the line switch to the said first selective switch, a trunk line leading commonly from the line switch and the said first selective switch to the said second selective switch, means for initiating the operation of the line switch to extend the calling line to the said first selective switch, means for then operating the said second selective switch to further extend the calling line towards the called line, means for alternatively operating the said first selective switch to disconnect the line switch from its connection with the said first selective switch, and means automatically applied responsive to the last said means for causing the line switch to connect with the commoned trunk line extending to the said second selective switch, and means for then operating the said second selective switch to further extend the calling line towards the called line wherein the said first selective switch is idle.

46. In an automatic telephone system, a calling line and line switch thereof, a first numerical order selective switch, a second selective switch of the next higher numerical order than said first numerical order switch, a called line, a trunk line leading from the line switch to the said first selective switch,

a trunk line leading commonly from the line switch and the said first selective switch to the said second selective switch, means for operating the line switch to extend the calling line to the said first selective switch, means for then operating the said first selective switch to extend the calling line to the said second selective switch, means for then operating the said second selective switch to further extend the calling line towards the called line, means for disconnecting the line switch from its connection with the said first selective switch, and means automatically applied responsive to the last said means for causing the line switch to connect with the commoned trunk line extending to the said second selective switch, and means for then operating the said second selective switch to further extend the calling line towards the called line wherein the said first selective switch is idle.

47. In an automatic telephone system, a calling line and line switch thereof, a first numerical order selective switch, a second selective switch of the next higher numerical order than said first numerical order switch, a called line, a trunk line leading from the line switch to the said first selective switch, a trunk line leading commonly from the line switch and the said first selective switch to the said second selective switch, means for operating the line switch to extend the calling line through a set of movable terminals of the line switch to the said first selective switch, means for then operating the said first selective switch to extend the calling line to the said second selective switch, means for then operating the said second selective switch to further extend the calling line towards the called line, means for disconnecting the line switch from its connection with the said first selective switch, and means automatically applied responsive to the last said means for causing the line switch to operate its said set of movable terminals into connection with the commoned trunk line extending to the said second selective switch, and means for then operating the said second selective switch to further extend the calling line towards the called line wherein the said first selective switch is idle.

48. In an automatic telephone system, a calling line and line switch thereof, a first numerical order selective switch, a second selective switch of the next higher numerical order than said first numerical order switch, a called line, a trunk line leading from the line switch to the said first selective switch, a trunk line leading commonly from the line switch and the said first selective switch to the said second selective switch, means for operating the line switch to extend the calling line through a set of movable terminals of the line switch to the said first selective switch, means for then operating the said first selective switch to extend the calling line to the said second selective switch, means for then operating the said second selective switch to further extend the calling line towards the called line, means for disconnecting the line switch from its connection with the said first selective switch, and means automatically applied responsive to the last said means for causing the line switch to connect with the commoned trunk line extending to the said second selective switch, and means for then operating the said second selective switch to further extend the calling line towards the called line wherein the said first selective switch is idle.

- first selective switch to extend the calling line to the said second selective switch, means for then operating the said second selective switch to further extend the calling line towards the called line, means for alternatively operating the said first selective switch to disconnect the line switch from its connection with the said first selective switch, and means automatically applied responsive to 5 the last said means for causing the line switch to operate its said set of movable terminals into connection with the commoned trunk line extending to the said second selective switch, and means for then operating the 10 said second selective switch to further extend the calling line towards the called line wherein the said first selective switch is idle. 15
49. In an automatic telephone system, a calling line and line switch thereof, a first numerical order selective switch, switch mechanism, a second selective switch of a higher numerical order than the said first numerical order switch, a called line, a trunk line leading from the line switch to the said first selective switch, a trunk line leading from the said first selective switch to the said switch mechanism, a trunk line leading commonly from the line switch and the said switch mechanism to the said second selective switch, 20 means for operating the line switch to extend the calling line to the said first selective switch, means for then operating the said first selective switch and for thereafter operating the said switch mechanism to extend the calling line to the said second selective switch, means for then operating the 25 said second selective switch to further extend the calling line towards the called line, means for alternatively operating the said first selective switch for disconnecting the line switch from its connection with the said first selective switch, and means automatically applied responsive to the last said means for causing the line switch to connect with the 30 commoned trunk line extending to the said second selective switch, and means for then operating the said second selective switch to further extend the calling line towards the called line wherein the said first selective switch and the said switch mechanism are idle. 35
50. In an automatic telephone system, a calling line and line switch thereof, a first numerical order selective switch, switch mechanism, a second selective switch of a higher numerical order than the said first numerical order switch, a called line, a trunk line leading from the line switch to the said first selective switch, a trunk line leading from 40 the said first selective switch to the said switch mechanism, a trunk line leading commonly from the line switch and the said switch mechanism to the said second selective switch, and means for operating the line switch to extend the calling line to the said second selective switch, means for then operating the said second selective switch to further extend the calling line towards the called line, means for disconnecting the line switch from its connection with the said first selective switch, and means automatically applied responsive to the last said means for causing the line switch to operate its said set of movable terminals into connection with the commoned trunk line extending to the said second selective switch, and means for then operating the said second selective switch to further extend the calling line towards the called line wherein the said first selective switch is idle. 45
52. In an automatic telephone system, a calling line and line switch thereof, a first numerical order selective switch, switch mechanism, a second selective switch of a higher numerical order than the said first numerical order switch, a called line, a trunk line leading from the line switch to the said first selective switch, a trunk line leading from 50 the said first selective switch to the said switch mechanism, a trunk line leading commonly from the line switch and the said switch mechanism to the said second selective switch, and means for operating the line switch to extend the calling line to the said second selective switch, means for then operating the said second selective switch to further extend the calling line towards the called line wherein the said first selective switch is idle. 55

tive switch, means for operating the line switch to extend the calling line through a set of movable terminals of the line switch to the said first selective switch, means for then operating the said first selective switch and for thereafter operating the said switch mechanism to extend the calling line to the said second selective switch, means for then operating the said second selective switch to further extend the calling line towards the called line, means for alternatively operating the said first selective switch for disconnecting the line switch from its connection with the said first selective switch, and means automatically applied responsive to the last said means for causing the line switch to operate its said set of movable terminals into connection with the commoned trunk line extending to the said second selective switch, and means for then operating the said second selective switch to further extend the calling line towards the called line wherein the said first selective switch is idle.

53. In an automatic telephone system, a calling line and line switch therefor, a train of numerical order connective switches, a called line, means for directly successively operating all the respective switches of the train to link a connection from the calling line to the called line, means responsive to operating one of said switches in a predetermined alternative manner to destroy the portion of the linked connection including the switch antecedent to the said one switch, means automatically responsive to the last said means for causing the said antecedent switch to operate to link the connection to a succeeding said switch of the train, and means for further extending the connection towards the called line over switches of the said train wherein the completed connection to the called line will include but a portion of the said switches of the said train as all the switch links thereof.

54. In an automatic telephone system, a calling line and line switch therefor, a train of numerical order connective switches each having a set of movable connecting terminals, a called line, means for directly successively operating all the respective switches of the train to link a connection from the calling line to the called line, means responsive to operating one of said switches in a predetermined alternative manner to destroy the portion of the linked connection including the switch antecedent to the said one switch, means automatically responsive to the last said means for causing the said antecedent switch to operate to link the connection through the same set of movable connecting terminals as used in the initial linking to a succeeding said switch of the train succedent to the switch to which it was antecedent to in the said initial linking, and means for fur-

ther extending the connection towards the called line over switches of the said train wherein the completed connection to the called line will include but a portion of the said switches of the train as all the switch links thereof.

55. In an automatic telephone system, a calling line and line switch therefor, a train of numerical order connective switches, a called line, means for directly successively operating all the respective switches of the train to link a connection from the calling line to the called line, means responsive to operating one of said switches in a predetermined alternative manner to destroy the portion of the linked connection including the switch antecedent to the said one switch, means automatically responsive to the last said means for causing the said antecedent switch to operate to link the connection to a succeeding said switch of the train succedent to the switch to which it was antecedent to, and means for further extending the connection towards the called line over switches of the said train wherein the completed connection to the called line will include but a portion of the said switches of the said train as all the switch links thereof.

56. In an automatic telephone system, a calling line and line switch therefor, a train of numerical order connective switches, a called line, means for directly successively operating all the respective switches of the train to link a connection from the calling line to the called line, means responsive to a predetermined operation of the directive means to destroy the portion of the linked connection including a switch antecedent to the last operated said switch, means automatically responsive to the last said means for causing the said antecedent switch to operate to link the connection to a succeeding said switch of the train succedent to the switch to which it was antecedent to, and means for further extending the connection towards the called line over switches of the said train wherein the completed connection to the called line will include but a portion of the said switches of the train as all the switch links thereof.

57. In an automatic telephone system, a calling line and line switch therefor, a train of numerical order connective switches having movable connecting terminals, a called line, means for directly successively operating all the respective switches of the train to link a connection from the calling line to the called line, means responsive to a predetermined operation of the directive means to destroy the portion of the linked connection including a switch antecedent to the last operated said switch, means automatically responsive to the last said means for causing the said antecedent switch to operate to link the connection through the same set of mov-

able connecting terminals as used in the initial linking to a succeeding said switch of the train succedent to the switch to which it was antecedent to, and means for further extending the connection towards the called line over switches of the said train wherein the completed connection to the called line will include but a portion of the said switches of the train as all the switch links thereof.

58. In a telephone system, a first and a second calling line, a called line, automatic switch mechanism for alternatively connecting the first or the second calling line with the called line, means for extending one or the other of the said calling lines to the said switch mechanism, and means dependent upon which calling line is thus connected to the switch mechanism which will cause the switch mechanism to automatically initiate its operation to effect the connection to the called line or which will render the switch mechanism only subject to directive operation for effecting the said connection.

59. In a telephone system, calling lines, a first selective switch having alternative sets of leading-in terminals, a second selective switch accessible from the said first switch, means for connecting a calling line through a set of said terminals and for thereafter operating the said first switch into connection with the said second switch, and automatically applied means for initiating the operation of the said second switch consequent upon the connection thereto or for rendering it only subject to directive operation depending upon which set of said alternative terminals of the antecedent switch is connected with.

60. In an automatic telephone system, a first switch reached over a plurality of paths, a second switch accessible from the said first switch, means controlled over a connected one or another said path for operating the said first switch to effect a connection from the said first to the said second switch, automatically applied means for initiating the operation of the said second switch if the control is over a specific one said path, and means for only directly initiating the operation of the said second switch at will if the control is over another of said paths.

61. In an automatic telephone system, a first switch reached over a plurality of paths, a second switch accessible from the said first switch, means controlled over a connected one or another said path for operating the said first switch to effect a connection from the said first to the said second switch, and automatically applied means for differently altering the operation of said second switch responsive to effecting the said connection, depending upon whether the control is over a specific one or another said path.

62. In an automatic telephone system, a

first switch reached over a plurality of paths, a second switch accessible from the said first switch arranged to perform the functions of one or another kind of automatic telephone switches, means controlled over one or another said path for operating the said first switch to effect a connection from the said first to the said second switch, and automatically applied means for determining which said function the said second switch will perform dependent upon whether the control is over one or another said path.

63. In an automatic telephone system, a first switch reached over a plurality of paths, a second switch accessible from the said first switch arranged to perform one or another operative function, means for operating the said first switch to effect a connection from the said first to the said second switch, and automatically applied means for determining which said function the said second switch will perform dependent upon whether the connection is over one or another said path.

64. In an automatic telephone system, a first switch reached over a plurality of paths, a second switch accessible from the said first switch arranged to perform one or another operative function, means controlled over one or another said path for operating the said first switch to effect a connection from the said first switch to the said second switch, and automatically applied means for determining which said function the said second switch will perform dependent upon whether the connection is over one or another said path.

65. In an automatic telephone system, calling lines, a group of called lines, a switch having an automatically initiated primary movement for hunting with relation to the said group and an alternative directly initiated primary movement for hunting with relation to the said group, a switch mechanism, means for alternatively extending one or another of the calling lines to the switch mechanism, means thereafter controlled over the said extended calling line for operating the switch mechanism into connection with the switch, and means for determining what said primary movement the switch will perform depending upon which said calling line is connected to the switch mechanism.

66. In an automatic telephone system, calling stations and corresponding lines therefor, a group of called lines, a switch having an automatically initiated primary movement for hunting with relation to the said group and an alternative directly initiated primary movement for hunting with relation to the said group, a switch mechanism, means for alternatively extending one or another of the calling lines to the switch mechanism, means thereafter controlled over

- the said extended calling line from the corresponding station for operating the switch mechanism into connection with the switch, and means for determining what said primary movement the switch will perform depending upon which said calling station is connected to the switch mechanism.
67. In an automatic telephone system, a branched calling line and terminating automatic switch thereon, a called line, a signaling current source for application to the called line, means common to both said branches for controlling the operation of the said switch over one or another said branch for connecting the said lines, and means depending upon which branch of the calling line is used which will determine if the signaling current will be automatically applied to the called line responsive to connection thereto or if it will only be applied to the called line subject to directive control applied over the calling line at will.
68. In an automatic telephone system, a branched calling line and terminating automatic switch thereon, a called line, a signaling current source for application to the called line, an operator's plug and cord, a jack for each said branch, means whereby applying the said plug into either said jack will enable the switch to be operated over the calling line to connect the calling and called lines, and means depending upon which jack of the calling line is used which will determine if the signaling current will be automatically applied to the called line responsive to connection thereto or if it will only be applied to the called line subject to directive control over the calling line at will.
69. In an automatic telephone system, a branched calling line and terminating switch thereon, a called line, a signaling current source for application to the called line, a source of inductive current, an operator's plug and cord, a jack for each said branch, means whereby applying the said plug into either said jack will enable the switch to be operated over the calling line to connect the calling and called lines, and means depending upon which jack of the calling line is used which will determine if the signaling current will be automatically applied to the called line responsive to the connection thereto or if it will only be applied to the called line subject to directive control applied at will over the calling line, the said directive control involving the said source of inductive current.
70. In a telephone system, calling lines, a group of called lines, a first selective switch and a second selective switch, sets of leading-in terminals for the said first switch corresponding to the respective calling lines, means for extending a connection from a said calling line to its corresponding said terminals, means for then extending the connection to the said second switch, automatically applied means for causing the automatic selective operation of the said second switch to be initiated whereby the connection is further extended to an idle line of the said group, automatically applied means whereby the said second switch is restored if no idle line is encountered, automatically applied means for thereupon causing the automatic selective operation of the said second switch to become disabled against the said restoring if no idle line is encountered, dependent upon which calling line and corresponding set of leading-in terminals is concerned.
71. In a telephone system, groups of lines, a switch common to said groups, levels of bank terminals each level corresponding to a said group accessible from the switch, a set of movable terminals of the switch having a first movement in a primary relation to select a selected level and a second movement thereafter in a secondary relation into connection with a set of contacts of the selected level, means for connecting a calling line of any said group to the said switch, means automatically applied consequent to the said connection to the switch for causing the movable terminals to hunt into primary relation to the level containing the calling line, and means for directly operating the movable terminals in a secondary relation to complete a connection from the calling line to any set of bank terminals of the attained level.
72. In a telephone system, groups of lines, a switch common to said groups, levels of bank terminals each level corresponding to a said group accessible from the switch, a set of movable terminals of the switch having a first movement in a primary relation to select a selected level and a second movement thereafter in a secondary relation into connection with a set of contacts of the selected level, means for connecting a calling line of any said group to the said switch, means automatically applied consequent to the said connection to the switch for causing the movable terminals to hunt into primary relation to the level containing the calling line, and means then controlled over the calling line for directly operating the movable terminals in a secondary relation to complete a connection from the calling line to a set of bank terminals of the attained level.
73. In a telephone system, groups of lines, a switch common to said groups, levels of bank terminals each level corresponding to a said group accessible from the switch, a set of movable terminals of the switch having a first movement in a primary relation to select a selected level and a second movement thereafter in a secondary relation into connection with a set of contacts of the selected level, means for connecting a calling line of any said group to the said switch, means auto-

5 matically applied consequent to the said connection to the switch for causing the movable terminals to hunt into primary relation to the level containing the calling line, means
 10 for directively operating the movable terminals in a secondary relation to complete a connection from the calling line to a set of bank terminals of the attained level, and means for signaling to the calling line that
 15 the said automatically applied movement of the terminals ensues.

74. In a telephone system, groups of lines, a switch common to said groups, levels of bank terminals each level corresponding to
 15 a said group accessible from the switch, a set of movable terminals of the switch having a first movement in a primary relation to select a selected level and a second movement thereafter in a secondary relation into connection
 20 with a set of contacts of the selected level, means for connecting a calling line of any said group to the said switch, means automatically applied consequent to the said connection to the switch for causing the movable terminals
 25 to hunt into primary relation to the level containing the calling line, and means automatically applied responsive to the movable terminals being operated into connection with a set of contacts of the level which set does
 30 not correspond to a line of the group containing the calling line which will be effective for disabling the connection.

75. In a telephone system, groups of lines, a selective switch common to the said groups, levels of bank terminals each level corresponding to a said group accessible from the switch, a set of movable terminals of the switch having a first movement in a primary relation to a selected level and a second movement in a secondary relation into connection
 40 with a set of contacts of the selected level, a calling one of said lines and terminating line switch therefor, means for operating the line switch to connect the calling line to the selective switch, means automatically applied consequent to the said connection to the selective switch for causing the movable terminals of the selective switch to hunt into primary relation to the level containing the
 45 calling line, and means for then directively operating the movable terminals of the selective switch in a secondary relation to complete a connection from the calling line to a set of bank terminals of the attained level.

76. In a telephone system, groups of lines, a selective switch common to the said groups, levels of bank terminals each level corresponding to a said group accessible from the switch, a set of movable terminals of the
 50 switch having a first movement in a primary relation to a selected level and a second movement in a secondary relation into connection with a set of contacts of the selected level, a calling one of said lines and terminating line switch therefor, means controlled over

the calling line for operating the line switch to connect the calling line to the selective switch, means automatically applied consequent to the said connection to the selective switch for causing the movable terminals of the selective switch to hunt into primary relation to the level containing the calling line, and means controlled over the calling line for then directively operating the movable terminals of the selective switch in a secondary relation to complete a connection from the calling line to a set of bank terminals of the attained level.

77. In a telephone system, groups of lines, a selective switch common to the said groups, levels of bank terminals each level corresponding to a said group accessible from the switch, a set of movable terminals of the switch having a first movement in a primary relation to a selected level and a second movement in a secondary relation into connection with a set of contacts of the selected level, a calling one of said lines and terminating line switch therefor, means for operating the line switch to connect the calling line to the selective switch, means automatically applied consequent to the said connection to the selective switch for causing the movable terminals of the selective switch to hunt into primary relation to the level containing the calling line, means for then directively operating the movable terminals of the selective switch in a secondary relation to complete a connection from the calling line to a set of bank terminals of the attained level, and means including the line switch of the calling line for rendering only lines of the group containing the calling line being connected with by the said movable terminals without being automatically disconnected consequent to effecting the connection.

78. In a telephone system, groups of lines, a selective switch common to the said groups, levels of bank terminals each level corresponding to a said group accessible from the switch, a set of movable terminals of the switch having a first movement in a primary relation to a selected level and a second movement in a secondary relation into connection with a set of contacts of the selected level, a calling one of said lines and terminating line switch therefor, means for operating the line switch to connect the calling line to the selective switch, means automatically applied consequent to the said connection to the selective switch for causing the movable terminals of the selective switch to hunt into primary relation to the level containing the calling line, means for then directively operating the movable terminals of the selective switch in a secondary relation to complete a connection from the calling line to a set of bank terminals of the attained level, and means for rendering only lines of the group containing the calling line being connected

with by the said movable terminals without being automatically disconnected consequent to effecting the connection.

79. In a telephone system, groups of lines, 5 a selective switch common to the said groups, levels of bank contacts, each level corresponding to a said group accessible from the switch, a set of movable terminals of the switch having a first movement into a predetermined 10 relation to a selected level and a second movement in the same direction as before into alignment with the level and a third movement into connection with a set of contacts of the selected level, a calling one of said 15 lines, means for connecting the calling line with the selective switch, means automatically applied consequent to the said connection to the selective switch for causing the movable terminals of the selective switch to 20 hunt into a primary relation to the level containing the calling line, and means for then directly operating the movable terminals into alignment with the selected level and thereafter into connection with a set of 25 bank contacts of the level to complete a connection from the calling line to a set of bank contacts of the attained level.

80. In a telephone system, groups of lines, a selective switch common to the said groups, 30 levels of bank contacts, each level corresponding to a said group accessible from the switch, a set of movable terminals of the switch having a first movement in a predetermined primary relation to a selected level and a 35 second movement in the same direction as before into alignment with the level and a third movement into connection with a set of contacts of the selected level, a calling one of said lines, means for connecting the calling 40 line with the selective switch, means automatically applied consequent to the said connection to the selective switch for causing the movable terminals of the selective switch to hunt into primary relation to the level 45 containing the calling line, and means controlled over the calling line for then directly operating the movable terminals into alignment with the selected level, and means for thereafter operating the movable terminals into connection with a set of bank contacts of the level to complete a connection 50 from the calling line to a set of bank contacts of the attained level.

81. In a telephone system, groups of lines, 55 a selective switch common to the said groups, levels of bank contacts, a plurality of levels corresponding to a said group accessible from the switch, a set of movable terminals of the switch having a first movement in a predetermined primary relation to a selected group 60 and a second movement in the same direction as before into alignment with a selected level of the group and a third movement into connection with a set of bank contacts of the selected level, a calling one of said lines, means

for connecting the calling line to the selective switch, means automatically applied consequent to the said connection to the selective switch for causing the movable terminals thereof to hunt into primary relation to the group containing the calling line, means for directly operating the said movable terminals into alignment with a selected level of the group, and means for operating the movable terminals into connection with a set of bank contacts of a level to complete a connection from the calling line to a set of the attained level.

82. In a telephone system, groups of lines, a selective switch common to the said groups, 80 levels of bank terminals each level corresponding to a plurality of said groups accessible from the switch, a set of movable terminals of the switch having a first movement in a primary relation to a selected level and a second movement in a secondary relation into connection with a set of bank terminals of the selected level, a calling one of said lines and terminating line switch therefor, means for operating the line switch to connect the calling line to the selected switch, means automatically applied consequent to the said connection to the selective switch for causing the movable terminals to hunt into primary relation to the level and then to the group of bank terminals of the level containing the calling line, and means for directly operating the movable terminals in a secondary relation to complete a connection from the calling line to a set of bank terminals 90 of the attained group.

83. In a telephone system, groups of lines, a selective switch common to the said groups, levels of bank terminals each level corresponding to a plurality of said groups accessible from the switch, a set of movable terminals of the switch having a first movement in a primary relation to a selected level and a second movement in a secondary relation into connection with a set of bank terminals of the selected level, a calling one of said lines and terminating line switch therefor, means for operating the line switch to connect the calling line to the selected switch, means automatically applied consequent to the said connection to the selective switch for causing the movable terminals to hunt into primary relation to the level and then to the group of bank terminals of the level containing the calling line, means for directly operating the movable terminals in a secondary relation to complete a connection from the calling line to a set of bank terminals of the attained group, and means for rendering only lines of the group containing the calling line 120 subject to being connected with by the movable terminals without disabling the connection.

84. In a telephone system, groups of lines, a selective switch common to the said groups,

levels of bank contacts each level corresponding to a plurality of said groups accessible from the switch, a set of movable terminals of the switch having a first movement in a primary relation to a selected group and a second movement in a secondary relation into connection with a set of bank contacts of the selected group, a calling one of said lines and line switch therefor, a first and a second choice group of trunks each said group terminating at the line switch, means for operating the line switch to connect the calling line over a trunk of the said first choice group to the selective switch, means automatically applied consequent to the said connection to the selective switch for causing the movable terminals thereof to hunt into primary relation to the level and then hunt to the group of bank contacts of the level containing the calling line, means for then directly operating the movable terminals in a secondary relation to complete a connection from the calling line to a set of bank contacts of the attained group or alternatively operate the selective switch to cause the line switch to disconnect from the selective switch and thereupon hunt with respect to the said second choice group of trunks to thereby connect the calling line with a trunk of the second choice group in lieu of the primary connection over a trunk of the first choice group.

85. In a telephone system, groups of lines, a selective switch common to the said groups, levels of bank terminals each level corresponding to a plurality of said groups accessible from the switch, a set of movable terminals of the switch having a first movement in a primary relation to a selected level and a second movement in a secondary relation into connection with a set of bank terminals of the selected level, a calling one of said lines and terminating line switch therefor, a resistor for the calling line, a first and a second choice group of trunks terminating at the line switch, means for operating the line switch to connect the calling line to the selective switch, means automatically applied consequent to the said connection to the selective switch for causing the movable terminals to hunt into primary relation to the level and to the group of bank terminals of the level containing the calling line, means for directly operating the movable terminals in a secondary relation to complete a connection from the calling line to a set of bank terminals of the attained group, and alternative means including the resistor on the calling line to initiate the automatic operation of the movable terminals to cause the line switch to disconnect from the selective switch and thereupon hunt with respect to the second choice group.

86. In a telephone system, groups of lines, a selective switch common to the said group, levels of bank terminals each level corresponding to a plurality of said groups ac-

cessible from the switch, a set of movable terminals of the switch having a first movement in a primary relation to a selected level and a second movement in a secondary relation into connection with a set of bank terminals of the selected level, a calling one of said lines and terminating line switch therefor, three groups of trunks terminating at the line switch, means for operating the line switch to connect the calling line to the selective switch over a trunk of a predetermined one of said three groups, means automatically applied consequent to the said connection to the selective switch for causing the movable terminals of the selective switch to hunt into primary relation to the level and to the group of bank terminals of the level containing the calling line, means for thereafter directly operating the movable terminals in a secondary relation to complete a connection from the calling line to a set of bank terminals of the attained group or for alternatively directly operating the selective switch to cause the line switch to disconnect from the selective switch responsive to the latter said directive operation and to thereupon hunt with respect to the second or the third said group depending upon the said directive operation of the selective switch.

87. In a telephone system, a plurality of groups of lines, a selective switch having movable terminals common to said groups, bank terminals of said groups accessible from the movable terminals of the selective switch, a calling one of said lines and line switch therefor, means for operating the line switch into connection with the selective switch, automatically applied means effective consequent to the said connection of the calling line through the line switch to the selective switch for causing the selective switch to operate into predetermined relation with the specific group containing the calling line, and means whereby then applying one directive operation from the calling line will set the movable terminals of the selective switch upon the bank terminals of the corresponding line of the group containing the calling line.

88. In a telephone system, a plurality of groups of lines, a selective switch having movable terminals common to said groups, bank terminals of said groups accessible from the movable terminals of the selective switch, a calling line belonging to any of said groups and line switch therefor, means for operating the line switch to connect the calling line with the selective switch, automatically applied means effective consequent to the said connection of the calling line with the selective switch for causing the selective switch to operate into predetermined relation with respect to the specific group containing the calling line, and means whereby then applying one directive operation from the calling line will set the movable terminals upon the

bank terminals of the corresponding line of the group containing the calling line.

89. In a telephone system, a plurality of groups of lines, a selective switch having a set of movable connecting terminals common to said groups, bank terminal sets each corresponding to a line of the said groups accessible from the said set of movable terminals, a line of a random said group, means for connecting the said line of the random group with the selective switch, automatically applied means effective consequent to the said connection of the line and the selective switch for causing the selective switch to hunt into predetermined relation with respect to the said random group, and means whereby directly operating the selective switch in correspondence with the numerical bank position of a set of bank terminals of the said random group irrespective of the position of the said random group will set the movable terminals of the selective switch upon a set of bank terminals of a line of the random group positioned in correspondence to the directive operation.

90. In a telephone system, a plurality of groups of lines, a selective switch having a set of movable connecting terminals common to said groups, bank terminal sets each corresponding to a line of the said groups accessible from the said set of movable terminals, a line of a random said group, means for connecting the said line of the random group with the selective switch, automatically applied means effective consequent to the said connection of the line and the selective switch for causing the selective switch to hunt into predetermined relation with respect to the said random group, means whereby directly operating the selective switch in correspondence with the numerical bank position of a set of bank terminals of the said random group irrespective of the position of the said random group will set the movable terminals of the selective switch upon a set of bank terminals of a line of the random group positioned in correspondence to the directive operation, and means whereby if the movable terminals are caused to be set upon a bank set of any group other than the random group the connection will be barred against completion.

91. In a telephone system, a plurality of groups of lines, a selective switch having a set of movable connecting terminals common to said groups, bank terminal sets each corresponding to a line of the said groups accessible from the said set of movable terminals, a line of a random said group and line switch therefor, means for operating the line switch to connect the said line of the random group with the selective switch, automatically applied means effective consequent to the said connection of the line and the selective switch for causing the selective

switch to hunt into predetermined relation with respect to the said random group, and means whereby directly operating the selective switch in correspondence with the numerical bank position of a set of bank terminals of the said random group irrespective of the position of the said random group will set the movable terminals of the selective switch upon a set of bank terminals of a line of the random group positioned in correspondence to the directive operation.

92. In a telephone system, a plurality of groups of lines, a selective switch having a set of movable connecting terminals common to said groups, bank terminal sets each corresponding to a line of the said groups accessible from the said set of movable terminals, a line of a random said group and a line switch therefor, means for operating the line switch to connect the said line of the random group with the selective switch, automatically applied means effective consequent to the said connection of the line and the selective switch for causing the selective switch to hunt into predetermined relation with respect to the said random group, means whereby directly operating the selective switch in correspondence with the numerical bank position of a set of bank terminals of the said random group irrespective of the position of the said random group will set the movable terminals of the selective switch upon a set of bank terminals of a line of the random group positioned in correspondence to the directive operation, and means whereby if the movable terminals are caused to be set upon a bank set of any group other than the random group the connection will be barred against completion.

93. In an automatic telephone system, a selective switch, a plurality of groups of lines accessible as called lines from the selective switch through a common set of connecting terminals, lines of said groups having common access as calling lines to the selective switch, means for extending a random one of last said lines into connection with the selective switch, means for thereafter operating the said movable terminals of the selective switch into connective relation with any line of said groups, and means for barring the selective switch against completing a connection unless the called line belongs to the same group as the calling line.

94. In an automatic telephone system, a selective switch, a plurality of groups of lines accessible as called lines from the selective switch, lines of said groups having common access as calling lines to the selective switch, means for extending a random one of last said lines into connection with the selective switch, means for thereafter operating the selective switch into connective relation with any line of said groups, and means for barring the selective switch against comple-

- ing a connection unless the called line belongs to the same group as the calling line.
95. In a telephone system, a line and first switch therefor, a relay of the switch operated over the line in a first manner to cause the operation of the switch, a second switch normally having access to the line, a busy-test terminal of the line for presenting a busy condition for guarding the line against seizure by the said second switch, and means for operating the relay over the line in a second manner to cause the busy-test terminal to present a busy condition without causing the said operation of the said first switch.
96. In a telephone system, a line and first switch therefor, a relay of the switch operated over the line in a first manner to cause the operation of the switch, a resistor for serial inclusion with a conductor of the line, a second switch normally having access to the line, a busy-test terminal of the line for presenting a busy condition for guarding the line against seizure by the said second switch, and means including the resistor for operating the relay over the line in a second manner to cause the busy-test terminal to present a busy condition without causing the said operation of the said first switch.
97. In a telephone system, a talking and switch operating line having not to exceed two conductors and a first switch therefor, a relay of the switch operated over the line in a first manner to cause the operation of the switch, a second switch normally having access to the line, a busy-test terminal for presenting a busy condition for guarding the line against seizure by the said second switch, and means for operating the relay over the line in a second manner to cause the busy-test terminal to present a busy condition without causing the said operation of the said first switch.
98. In a telephone system, a talking and operating line having not to exceed two conductors and first switch therefor, a called line, a resistor, a busy-test terminal for the line, a relay of the switch, a second switch for connection to the line, means responsive to connecting the conductors of the calling line through a path of low resistance for causing the relay to operate in a first manner to cause the switch to operate to connect the calling line with the called line and for causing the said terminal to present a busy condition for guarding the calling line against seizure by the second switch, and means for alternatively connecting the conductors of the calling line through a path including the resistor which will cause the relay to operate in a second manner to cause the said terminal to present a busy condition without causing the switch to operate.
99. In a telephone system, a line and first hunting switch therefor at rest, a second switch normally having access to the line,
- a busy-test terminal of the line for presenting a busy condition for guarding the line against seizure by the second switch, means controlled over the line for causing the said first switch to hunt from rest and coincidentally cause the busy-test terminal to present a busy condition, and means alternatively controlled over a conductor of the line to cause the busy-test terminal to present a busy condition while not causing the hunting operation of the said first switch.
100. In a telephone system, a talking and operating first line having not to exceed two conductors and first switch therefor, a second switch, a second line accessible from the first said switch, a busy-test terminal of the said first line for guarding the line against seizure by the said second switch, branches of the said first line, means whereby consequent upon effecting a connection to the said first line over one said branch will automatically cause the switch to operate to extend a connection from the said first line to the said second line and apply a busy condition to the busy-test terminal, and means whereby effecting a connection over the other said branch will be non-effective to operate the switch but will apply the busy condition to the busy-test terminal.
101. In a telephone system, a talking and switch-operating line having not to exceed two conductors and switch therefor, lines accessible from the switch, a second switch normally having access to the line, a busy-test terminal of the line for guarding it against seizure by the said second switch, means controlled over the line for operating the switch into connection with one of said lines and for causing the busy-test terminal to guard the said line against being seized by the second switch, and means controlled over the said line for causing the busy-test terminal to guard the said line without rendering the switch in operative condition.
102. In a telephone system, called lines, a trunk line extending to a selective switch mechanism, a source of signaling current, means for causing the said mechanism to operate for connecting the trunk to one of said called lines, means controlled over the said connected called line for causing the said mechanism to operate to connect the trunk line to another said called line while maintaining the first said connection, and automatically applied means effective at a predetermined time after the last said connection is established for applying the signaling current to the first connected called line.
103. In a telephone system, called lines, a trunk line extending to a selective switch mechanism, a source of signaling current for application to a calling line, means for causing the said mechanism to operate for connecting the trunk to one of said called lines, means controlled over the said connected

- called line now operating as a calling line for causing the said mechanism to operate to connect the trunk line to another said called line while maintaining the first said connection, 5 automatically applied means effective at a predetermined time after the last said connection is established and an operation manually effected on the last calling line for applying the signaling current to the last calling line, and manually controlled means on the last calling line for disabling the application of the signaling current without destroying the connection between the trunk line and the last called line.
104. In a telephone system, subscriber lines, a trunk line extending to a selective switch mechanism, a source of signaling current, means for causing the said mechanism to operate for connecting the trunk to one of 15 said subscriber lines, means controlled over the said connected line for causing the said mechanism to operate to connect the trunk line to another said subscriber line while maintaining the first said connection, and 20 means responsive to a manual operation on the first said connected subscriber line dependent upon a specific condition of the last called line for applying the signaling current to the said first connected line.
105. In an automatic telephone system, a calling line, a called line, switch mechanism for connecting the lines, a source of signaling current, and means differently effective dependent upon the idle or busy condition of 25 the connected called line and a manually controlled operation on the calling line for thereupon applying the signaling current upon the calling line or for applying the signaling current after a predetermined delayed 30 period thereafter respectively.
106. In an automatic telephone system, a calling line, a called line, switch mechanism for connecting the lines, a source of signaling current, means differently effective dependent upon the idle or busy condition of 35 the connected called line and a manually controlled operation on the calling line for thereupon applying the signaling current upon the calling line or for applying the signaling current after a predetermined delayed 40 period thereafter respectively and means manually controlled from the called line after the manual operation on the calling line and within the said predetermined period, for disabling the said application of 45 signaling current.
107. In a telephone system, a calling and a called line, switch mechanism for connecting the lines, a source of signaling current, automatically applied means for periodically applying the signaling current to the called line, means on the called line for terminating the said applications of the signaling current, and means controlled at will from the 50 calling line for limiting the number of said 55 applications of signaling current thereafter applied regardless of control on the called line.
108. In a telephone system, a calling and a called line, means for connecting the lines, a source of current, means for periodically applying the current to the called line, means on the called line for terminating the said applications of the current, and means controlled at will from the calling line for limiting the number of said applications of current thereafter applied regardless of control on the called line.
109. In a telephone system, a calling and a called line, switch mechanism for connecting the lines, a source of current, means for periodically applying the source of current to the connected called line, means for disconnecting the calling line from the switch mechanism while maintaining the connection from the switch mechanism to the called line, and automatically applied means effective at the termination of a predetermined number of said applications of the current source to the called line for destroying the connection between the said mechanism and the called line.
110. In a telephone system, a calling line and called lines, a step-by-step switch, means controlled from the calling line for operating the switch to extend a connection from the calling line to a first called line, a directive device on the said called line, and means responsive to a single operation of the directive device for operating the switch to extend the connection from the calling line to a second called line to form a Y connection between the lines.
111. In a telephone system, a calling line and called lines, a step-by-step switch, means controlled from the calling line for operating the switch to extend a connection from the calling line to a first called line, a directive device on the said called line, means responsive to a single operation of the directive device for operating the switch to extend the connection from the calling line to a second called line to form a Y connection between the lines, and means whereby the first called line can directly disconnect from the connection leaving the calling and last called line connected.
112. In a telephone system, a branched calling line and terminating duplex connector, called lines, two sources of signaling current, means for initiating a call to and operating the connector over either said branch to connect the calling line with a first one of the called lines and apply signaling current thereto, means on the said called line for then operating the connector to connect the calling line with a second one of the called lines and apply signaling current thereto forming a Y connection between the calling line and the said first and second

- called lines, means for disconnecting one of the called lines from the connection while maintaining the other two lines connected, means for then operating the connector to connect the calling line with a third called line and apply signaling current thereto forming a Y connection between the calling line and the remaining said called line and said third called line, and means depending upon which said branch the call is initiated over which will determine which said source of signaling current will be the one applied. 113. In an automatic telephone system, a calling line and a called line, switch mechanism for connecting said lines, signaling current, means for applying signaling current to a connected called line, and means whereby if a response is not thereafter made on the called line signaling current will be applied to the calling line. 114. In an automatic telephone system, a calling line and a called line, switch mechanism for connecting said lines, a first and a second source of signaling current, means for intermittently applying current to a connected called line from said first source, and means for applying said second source to the calling line if a response is not obtained on the called line before a predetermined number of said applications of said first source to the called line. 115. In an automatic telephone system, a calling line and a called line, switch mechanism for connecting said lines, signaling current, means for intermittently applying signaling current to the called line, and means for applying signaling current to the called line if a response is not obtained on the called line before a predetermined number of said applications of signaling current is applied to the called line. 116. In a telephone system, a calling line, a called line and manual station thereon, a connecting station and signal device thereat, line connecting apparatus, signaling current, means at the connecting station for directly connecting the calling and called lines, means for thereafter signaling the station of the called line by the signaling current, and means for operating the signal device at the connecting station if a response is not obtained at the manual station. 117. In a telephone system, a calling line, a called line, switch mechanism for connecting said lines, signaling current, means for applying the signaling current to the connected called line, and automatically applied means for destroying the connection if no response is obtained on the called line within a predetermined time. 118. In a telephone system, a plurality of groups of lines, a selective switch having movable terminals common to said groups, a set of bank terminals for each of the lines of the group accessible from said movable terminals, a calling random one of said lines, means for connecting a calling line to the selective switch, automatically applied means responsive to the said connection for causing the movable terminals of the selective switch to hunt for the group containing the calling line and position thereat, directive means for thereafter operating the movable terminals with correspondence to a set of bank terminals, a tone source, and automatically applied means for applying the tone source to the calling line responsive to the termination of the said hunting operation indicative that the switch is then subject to directive operation. 119. In a telephone system, called lines, a trunk line extending to a selective switch mechanism, a source of signaling current for application to a calling line, means for causing the said mechanism to operate for connecting the trunk to one of said called lines, means controlled over the said connected called line now operating as a calling line for causing the said mechanism to operate to connect the trunk line to another said called line while maintaining the first said connection, and automatically applied means effective at a predetermined time after the last said connection is established and an operation manually effected on the last calling line for applying the signaling current to the last calling line. 120. In a telephone system, a trunk line and terminating switch mechanism, a first and a second source of signaling current, a first and a second called line, means for operating the switch mechanism to extend a call from the trunk to the first called line, means for then responding on the first called line by operating a circuit closer, means for then operating the switch mechanism to introduce the second called line to form a Y connection of the lines and apply the first source of signaling current to the second called line, means for then restoring the said circuit closer without destroying the connection between the lines, and automatically applied means responsive at a predetermined time after the said restoring of the circuit closer if no response has occurred on the last called line for applying the said second source of signaling current to the first called line. 121. In a telephone system, a trunk line and terminating switch mechanism, a first and a second source of signaling current, a first and a second called line, means for operating the switch mechanism to extend a call from the trunk to the first called line, means for then responding on the first called line by operating a circuit closer, means for then operating the switch mechanism to introduce the second called line to form a Y connection of the lines and apply the first source of signaling current to the second called line. 122. In a telephone system, a plurality of groups of lines, a selective switch having movable terminals common to said groups, a set of bank terminals for each of the lines of the group accessible from said movable terminals, a calling random one of said lines, means for connecting a calling line to the selective switch, automatically applied means responsive to the said connection for causing the movable terminals of the selective switch to hunt for the group containing the calling line and position thereat, directive means for thereafter operating the movable terminals with correspondence to a set of bank terminals, a tone source, and automatically applied means for applying the tone source to the calling line responsive to the termination of the said hunting operation indicative that the switch is then subject to directive operation.

means for then restoring the said circuit closer without destroying the connection between the lines, automatically applied means responsive at a predetermined time after the said restoring of the circuit closer if no response has occurred to the last called line for applying said second source of signaling current to the first called line, and means responsive to reoperating the said circuit closer within the said predetermined time for disconnecting the first called line while maintaining the connection between the trunk and the said second called line.

122. In a telephone system, a trunk line and terminating switch mechanism, a first and a second source of signaling current, a first and a second called line, means for operating the switch mechanism to extend a call from the trunk to the first called line, means for then responding on the first called line by operating a circuit closer, means for then operating the switch mechanism to introduce the second called line to form a Y connection of the lines and apply the first source of signaling current to the second called line, means for then restoring the said circuit closer without destroying the connection between the lines, automatically applied means responsive at a predetermined time after the said restoring of the circuit closer if no response has occurred to the last called line for applying said second source of signaling current to the first called line, and means effective consequent to a response of the said second called line for disconnecting the said first called line from the connection if the response occurs within the predetermined period.

123. In a telephone system, a trunk line and terminating switch mechanism, a first and a second source of signaling current, a first and a second called line, means for operating the switch mechanism to extend a call from the trunk to the first called line, means for then responding on the first called line by operating a circuit closer, means for then operating the switch mechanism to introduce the second called line to form a Y connection of the lines and apply the first source of signaling current to the second called line, means for then restoring the said circuit closer without destroying the connection between the lines, automatically applied means responsive at a predetermined time after the said restoring of the circuit closer if no response has occurred on the last called line for applying the said second source of signaling current to the first called line, and means operating coincidently with the last said means for restoring the switch mechanism from the said second called line into condition for being again operated as before.

124. In an automatic telephone system, a calling line, a switch terminating the calling line, a source of inductive current, a

wiper of the switch, terminals of lines accessible from the wiper, means whereby responsive to applying said inductive current to the calling line will cause the wiper to move directly from its normal idle position in a hunting operation over said terminals, and means for causing the wiper to remain upon the terminal of the first idle line encountered in the hunting operation.

125. In an automatic telephone system, a calling line, a switch terminating the calling line, a source of inductive current, a wiper of the switch, terminals of lines accessible from the wiper, means whereby responsive to applying said inductive current to the calling line will cause the wiper to move directly from its normal idle position in a hunting operation over said terminals, means for causing the wiper to remain upon the terminal of the first idle line encountered in the hunting operation, a source of signaling current, and means whereby thereafter at will again applying the inductive current to the calling line will cause the signaling current to be applied to the line the wiper remained upon.

126. In an automatic telephone system, a calling line, a switch terminating the calling line, a source of inductive current, a wiper of the switch, the terminal of a called line accessible from the wiper, and means whereby responsive to applying the inductive current to the calling line will cause the wiper to move directly in a single direction from the normal idle position to the terminal of the called line.

127. In an automatic telephone system, a calling line, a switch terminating the calling line, a source of inductive current, a wiper of the switch, the terminal of a called line accessible from the wiper, means whereby responsive to applying the inductive current to the calling line will cause the wiper to move directly in a single direction from the normal idle position to the terminal of the called line, a source of signaling current, and means whereby thereafter at will again applying the inductive current to the calling line will cause the signaling current to be applied to the called line.

128. In a telephone system, a calling and a called line, automatic switch mechanism for connecting said lines, a source of signaling current for application to the called line, a source of inductive current, and means for at will applying the inductive current over the calling line after the said lines are connected for applying the signaling current to the called line consequent to the termination of the application of the inductive current.

129. In a telephone system, a calling and a called line, automatic switch mechanism for connecting said lines, a source of signaling current for application to the called

130

line, a source of inductive current, means for placing a busy-guard on the called line, means for barring connection with the called line consequent to the busy-guard, means thereafter responsive to a single application of the inductive current over the calling line for causing the switch mechanism to connect with the called line, and means thereafter responsive to a single application of the inductive current for causing the signaling current to be applied to the called line.

130. In an automatic telephone system, a selective switch, three or more groups of lines accessible from said switch, groups of calling lines, means whereby a said calling line can be extended to said switch, means for thereafter operating the switch into selective relation to a random one of said accessible groups, and means operative depending upon to which said group the said connected calling line belongs and which said accessible group has been selected by the switch for determining if the switch will or will not be barred from completing connection with a line of the selected group.

131. In an automatic telephone system, a selective switch, three or more lines accessible from said switch, calling lines, means whereby a said calling line can be extended to said switch, means for thereafter operating the switch into selective relation to a random one of said accessible lines, and means operative depending upon which said connected line is calling and which said accessible line has been selected by the switch for determining if the switch will or will not be barred from completing connection with the selected line.

132. In a telephone system, a calling line, a plurality of called lines, selective switch mechanism for selecting a random one of said called lines to pair the calling line with the selected line, signaling current, means for applying the signaling current to the selected line, and means operated responsive to a predetermined elapsed time ensuing for disabling first said means.

133. In a telephone system, a calling line, a plurality of called lines, selective switch mechanism for selecting a random one of said called lines to pair the calling line with the selected called line, and means operated responsive to predetermined elapsed time ensuing for destroying said paired relation although no control for said means from over the called line by a manual operation thereon has occurred.

134. In a telephone system, a calling line, a plurality of called lines, selective switch mechanism, a connective terminal of the selective switch mechanism, means for operating the terminal from idle position for selecting a random one of said called lines to pair the calling line with the selected called line, and means operated responsive to pre-

determined elapsed time ensuing for moving said connective terminal from the position assumed by said selection.

135. In a telephone system, a calling line, a plurality of called lines, selective switch mechanism, a connective terminal of the selective switch mechanism, means for operating the terminal from normal idle position for selecting a random one of said called lines to pair the calling line with the selected called line, and means operated responsive to predetermined elapsed time ensuing for moving said connective terminal from the position assumed by said selection to said normal idle position.

136. In an automatic telephone system, a calling line, a called line, a plurality of automatic numerical switches, means whereby responsive to sending any one of a plurality of trains of series differing in the number of series constituting the respective trains will operate certain of said switches to link a switch train from the calling line to the called line, means whereby there will be more said switches in the switch train linked responsive to the lowest number of impulse series, and means whereby all the switches linked responsive to the highest number of impulse series may also be linked responsive to the lowest number of impulse series.

137. In an automatic telephone system, a calling line, a called line, alternative calling numbers for the called line, a plurality of automatic numerical switches for linking a connection from the calling line to the called line, means operated over the calling line responsive to sending varied series of impulses in a train wherein the respective series correspond to a digit in the respective alternative calling numbers of the called line for operating as many said switches as there are digits in the calling numbers for linking a connection from the calling line to the called line, and means whereby depending upon the particular digits sent corresponding to one of said calling numbers but not of another of said calling numbers will cause one of said operated switches to be bypassed and restored subject to service in other calls without disabling the establishment of said connection from the calling line to the called line.

138. In an automatic telephone system, a calling line, a called line, a plurality of automatic numerical switches for linking a connection from the calling line to the called line, means for sending a train of impulse series over the calling line for correspondingly successively operating each of said switches wherein each said switch operated is enabled to link the connection in the direction of the called line, and means whereby one of said operated switches may be bypassed and restored subject to service in other calls without disabling the completion of the connection from the calling line to the called line re-

sponsive to sending said train and wherein there may be no other switches involved because of said bypassing.

139. In an automatic telephone system, a plurality of groups of outgoing trunks, a selective switch having selective access to said groups, a plurality of incoming calling lines, means for extending connection from a random one of said calling lines to said switch, and means whereby depending upon the particular one of said calling lines connected to said switch for causing said switch to thereupon operate to thereby select a particular said group with correspondence to the particular calling line connected to the switch.

140. In an automatic telephone system, a selective switch, a group of lines accessible from said switch, means for normally barring the seizure of a certain one of said lines by the switch although the line is idle, means for seizing a non-barred idle line of the group by the switch, means for preventing seizure of a busy line of the group by the switch, and automatic means directed at will by a manual operation for removing said normal bar from said certain line and placing a bar upon said normally non-barred idle line whereby calls intended for said normally non-barred idle line will be diverted to said normally barred line.

141. In an automatic telephone system, a selective switch, a group of lines accessible from said switch, means for normally barring the seizure of a certain one of said lines by the switch although the line is idle, means for seizing a non-barred idle line of the group by the switch, means for preventing seizure of a busy line of the group by the switch, automatic means involving a locking relay directly locked at will over an operating circuit by a manual operation for removing said normal bar from said certain line and placing a bar upon said normally non-barred idle line whereby calls intended for said normally non-barred idle line will be diverted to said normally barred line, and means for unlocking said relay responsive to an operation like manually applied to lock it.

142. In an automatic telephone system, an automatic connector switch controlled by an operator for selecting a subscriber's line, a controlling device at the operator's switchboard, a wiper connecting relay in said switch responsive to the actuation of said device, and a ringing relay in said connector responsive to a second actuation of said device, said wiper connecting relay not responding to said second actuation of said device.

143. In an automatic telephone system, a calling line, a called line, switch mechanism, a calling device, means for directly operating the switch mechanism over the calling line responsive to the operation of the calling device whereby the switch mechanism

will extend connection from the calling line into selective relation to the called line, other switch mechanism having access to the called line in common with first said switch mechanism, a source of inductive current, means for applying said source of inductive current over the calling line to thereby directly operate the switch mechanism to effect connection from the calling line to the said selected called line, means for barring the called line against connection to by last said switch mechanism upon last said connection being effected, and means whereby at will again applying said source of inductive current to the calling line will thereby cause said source of signaling current to be applied to the called line.

144. In an automatic telephone system, a plurality of telephone lines, a plurality of numerical switches, a trunk circuit terminating in each numerical switch, non-numerical switches for extending a calling telephone line through a trunk circuit to an idle numerical switch, means controlled over the calling telephone line for directly operating said numerical switch, and means for causing said non-numerical switch to make a second selection of an idle trunk in accordance with the movement of said first mentioned numerical switch.

145. In a telephone system, a plurality of telephone lines, two groups of trunks, a non-numerical switch for the use of each telephone line for extending it on the initiation of a call to an idle trunk in one of said groups, a numerical switch for each trunk having movements in intersecting planes to select a wanted telephone line, means responsive to the control of said calling line for operating the selected numerical switch in one plane, means controlled by said operation of the selected numerical switch for causing said non-numerical switch of the calling line to seize a trunk and its numerical switch in a desired group, and means for then advancing the last selected numerical switch through movements in two planes to select the wanted telephone line.

146. In a telephone system, an automatic switch, lines accessible from said switch, a bar terminal of a predetermined one of said lines for preventing the corresponding one of said lines from being seized from the switch when selected by the switch only under the condition that a predetermined electrical potential exists on the bar terminal, and automatic means operated over said predetermined line for preventing the switch from seizing the predetermined line when selected by the switch, regardless of the electrical condition of said bar terminal.

147. In a telephone system, an automatic switch, lines accessible from said switch, a bar terminal of a predetermined one of said lines for preventing the corresponding one

of said lines from being seized from the switch when selected by the switch only under the condition that a predetermined electrical potential exists on the bar terminal,
5 automatic means operated over said predetermined line for preventing the switch from seizing the predetermined line when selected by the switch, regardless of the electrical condition of said bar terminal, and means for
10 causing the switch to seize an alternative line under last stated condition.

In witness whereof, I hereunto subscribe my name this 31st day of January A. D. 1922.

HERBERT M. FRIENDLY.
